UNITED STATES PATENT OFFICE.

ELLIS H. MILLS, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 30, 1920. Serial No. 433,987.

To all whom it may concern:

Be it known that I, ELLIS H. MILLS, a citizen of the United States, residing at East Orange, in the county of Essex and State of New Jersey, have invented certain new and useful Improvements in Telephone-Exchange Systems, of which the following is a full, clear, concise, and exact description.

This invention relates to a telephone exchange system and more particularly to a system in which connections are established between subscribers' lines by means of mechanical switching devices.

In systems of the above mentioned character a central office sending mechanism is employed which controls the selective movements of the mechanical switching devices in accordance with the directory numbers of desired lines which numbers the calling subscribers cause to be registered on the registers of the sending mechanism through the operation of the impulse dials associated with the substations of their lines. If the subscribers' lines are equipped with coin boxes it is desirable to further provide central station means for operating the coin boxes to collect or refund the deposited coins as connections are successfully or unsuccessfully established. Since calling subscribers may set the registers of the office sender for establishing all connections listed in the telephone directory it may often occur that subscribers may attempt to obtain connections to which they are not entitled without the deposit of additional coins or coins of larger denominations. On the other hand it may be desirable to permit connections to certain lines without necessitating the deposit of a coin, as, for example, connections to an operator's position, to the police station, fire headquarters, hospitals, etc.

In order therefore that there may be an automatic supervision of the toll controlling means which automatically functions in accordance with the nature of the established connection or in accordance with its routing, it is proposed to associate the service charging controlling means directly with the office sender so that the setting of the sender by the calling subscriber may determine whether the attempted connection shall proceed with or without the deposit of a coin, or whether the connection shall be rerouted to an operator's position where the deposit

of the necessary charge may be properly supervised.

It is the usual practice in systems of this general character to provide central office sending mechanisms which are available for the use of a group of subscribers' lines and to associate an idle mechanism with the mechanical switching devices employed to establish a desired connection by means of a suitable switching device for only such a period as is necessary to enable the switching devices to be adjusted, and to then disassociate such mechanism and render it available for controlling other connections which may be initiated in the same group of lines. Inasmuch as the charging of the call against the calling subscriber is not accomplished until after it has been determined whether the attempted connection is successful, that is, until after the called subscriber responds, and as at this time the office sender and associated toll controlling means are disassociated from the established connection, it is therefore necessary to reassociate an idle sender and toll controlling means temporarily with the established connection. This is preferably accomplished upon the termination of the established connection.

It is an object of the invention to establish a method of and to provide means for permitting the establishment of certain connections without the deposit of a coin.

A further object of the invention is to provide means for routing connections to an operator's position when subscribers attempt to establish certain connections.

A further object of the invention is the provision of means for testing to determine whether the substation service charging device has functioned properly in response to the central office controlling mechanism.

One feature of the invention resides in the provision of coin collecting and refunding mechanism associated with the office sender which is controlled by the operation of the sender in accordance with the nature of the established connection.

A further feature of the invention resides in the provision of means associated with the office sender for rerouting a connection to an operator's position if the calling subscriber attempts to call certain numbers. The office sender in accordance with this invention is provided with a group of code

and numerical registers which are set by the calling subscriber in accordance with the district or office designation and the listed numerical designation of the desired line 5 and with translator register relays which are variously operated through the medium of a translator switch from the setting of the code registers. Certain of the register relays cause the setting of a class switch associated with the sender; other relays control the functioning of the sender to control the setting of the district and office switches, and others serve as zoning and routing relays which operate a special route switch. 10 These zoning and routing relays, when operated to advance the route switch, cancel the effect of the district and office registration which the calling subscriber has caused to be established and set up a new routing for 15 rerouting the attempted connection to an operator's position.

A still further feature resides in the provision of means associated with the office sender for delaying the operation of the 20 sender immediately prior to its control of units selection until after the calling subscriber has deposited the necessary coin, and the further provision of means comprising a special register relay for cancelling the 25 effect of the sender delay means when the calling subscriber attempts certain connections, as, for example, to an operator's position, to the police station, fire headquarters, etc. in order to permit such connections to 30 be established regardless of the deposit of a coin.

These and other features of the invention may be more readily understood by reference to the following description considered in connection with the accompanying drawing in which Fig. 1 shows one of a group of lines terminating in a full mechanical office of the exchange, and a rotary line switch individual to such line by 40 means of which the subscriber's line may be connected to an idle district selector switch; Fig. 2 shows a district selector and a sender finder switch together with the circuits and controlling mechanism associated therewith; Fig. 3 shows an office selector switch together with the circuits and controlling mechanism associated therewith; Fig. 4 shows an incoming selector switch provided with mechanism for applying ringing current to the terminals of a called line together with the circuits and mechanism for controlling said switch; Fig. 5 shows the mechanism and circuits of a final selector switch and the line of a subscriber to which 45 the selector switch has access; Fig. 6 shows a time measure switch and translator control sequence switch associated with the central office sending mechanism; Fig. 7 shows a portion of the circuit of a sending mechanism comprising a stepping relay, a group

of counting relays, a sequence switch for controlling the circuits of the sender, and a class sequence switch for altering the circuits of the sender in accordance with the class of the call which is to be established; Fig. 8 shows the code registers which are set in accordance with the first three code or office designation digits dialled by the calling subscriber, and a steering switch which successively associates the code registers and numerical registers shown in Fig. 9 with the impulse circuit extending to the calling subscriber's line; Fig. 9 shows the numerical registers which are set by the calling subscriber in accordance with the numerical designation of the desired line; Fig. 10 shows groups of translator register relays which are variously operated by the translator switch and pulse machine shown in Fig. 11 in accordance with the setting of the code registers for determining the setting of the class switch shown in Fig. 7, the setting of the district selector switch shown in Fig. 3, and for setting the sequence switch of the district selector to determine the connection of the repeating coil into the talking circuit; Fig. 11 shows a translator switch and a development of the pulse machine drum for setting the register relays; Fig. 12 shows a time measure switch and associated mechanism for applying collection and refunding current to the calling subscriber's line for charging the call against the subscriber, and signalling mechanism associated with a sender monitor's position for supervising the operation of the sender; Fig. 13 shows circuits of a route switch under the control of the translator relays of Fig. 10 for determining the routing of calls and Fig. 14 is a diagram showing the manner in which the several sheets of the drawing should be arranged to show as much of a complete organization of circuits as is necessary to illustrate the manner in which connections may be established.

The calling subscriber's line K is of the usual type of coin box line provided with a transmitter, receiver, call bell and coin box, and since the line terminates in a full mechanical exchange it is also equipped with an impulse sending dial S of the usual type.

The subscriber's line terminates in an individual trunk finding switch of the well-known rotary step-by-step type, which through a plurality of wipers has access to a group of trunk lines terminating in district selector switches. The switch is provided with a stepping magnet for advancing the wipers over terminals of trunk lines in search of an idle trunk and for advancing the wipers around to normal position upon the release of the established connection.

The district selector, office selector, incoming selector, and final selector switches,

diagrammatically disclosed in Figs. 1 to 5 inclusive, are of the type shown in the patent to E. B. Craft and J. N. Reynolds, 1,123,696, issued January 5, 1915.

5 The translator switch TS, shown in Fig. 11, is of the same type as the switch shown in the aforesaid patent but is equipped with ten sets of brushes arranged in five pairs, the brush sets comprising each pair being 10 arranged to be tripped together. In Fig. 11 only one pair of the brushes has been disclosed.

The sender finder switch SF, shown in Fig. 2, the time measure switch TM, shown 15 in Fig. 6, the sender monitor's time measure switch M, shown in Fig. 12, the register steering switch RS, shown in Fig. 8, and the registers A, B, C, TH, H, T and U, shown in Figs. 8 and 9, are of the well-known step-by-step type. With the exception 20 of sender finder switch SF, the wipers of these switches are restored to normal position by being advanced by their respective stepping magnets forwardly to normal position. Finder switch SF has no normal 25 position, the wipers thereof resting in contact with the bank terminals last employed, when the switch is idle.

The pulse machine PM, shown in Fig. 30 11, comprises a drum of insulating material in which a plurality of circumferential rows of contact segments are embedded, these segments being connected to a source of current through a common slip ring 1125. 35 A plurality of brushes engage the several rows of segments and are arranged to be variously connected to the contacts in the ten banks of translator switch TS through a suitable distributing frame (not shown) 40 for conducting impulses of current from the several segments of the drum to the bank terminals of the translator switch.

For controlling the circuits associated 45 with the several selector switches and the circuits of the office sender, auxiliary switches are employed. These switches may be of the type disclosed in the patent to J. N. Reynolds and C. F. Baldwin, 1,127,808, issued February 9, 1915, and known in the 50 art as sequence switches. Each sequence switch comprises a rotatable shaft driven from a constantly rotating source of power through a magnetic clutch member and carries a plurality of circuit closing cams, which, at different radial positions of the 55 shaft, cause the closure of a plurality of contacts. The cam contacts associated with each sequence switch are closed only in the 60 positions indicated by the numerals associated with each contact, with the exception of the master contacts 201, 301, 401, 501, 601, 701, 751 and 1301 associated respectively with sender switches 200, 300, 400, 500, 600, 700, 750 and 1300, these latter contacts 65 being opened in the positions indicated by

the numerals appearing adjacent such contacts and closed in all other positions.

The different pieces of apparatus employed in the system having now been briefly described, it is thought that a clearer 70 understanding of the invention may be had from a description of the method employed in establishing various connections from the station of the calling subscriber K. The following connections will be described in 75 the order indicated:

I. The establishment of full mechanical connections in the local area.

II. The establishment of free connections.

III. The attempted establishment of a 80 connection outside the local area.

IV. The establishment of a connection for special service, as telegraph service.

V. The establishment of calls for either toll or long distance service. 85

I. THE ESTABLISHMENT OF A FULL MECHANICAL CONNECTION IN LOCAL AREA.

The calling subscriber, upon initiating a call, removes his receiver from the switch hook and closes a circuit for the line relay 101 of the trunk hunting switch 100, which circuit may be traced from grounded battery through the right-hand winding of relay 101, the innermost lower armature and back 90 contact of cut-off relay 102, over line conductor 103, through the substation of subscriber's line K, and thence back over line conductor 104 to ground at the upper armature and back contact of cut-off relay 102. The line relay energizes in this circuit and closes a circuit for the stepping magnet 105 95 of the switch 100, which circuit may be traced from grounded battery through the winding and armature contacts of magnet 105, conductor 106, the lowermost armature and back contact of relay 102, the right-hand armature and front contact of relay 101, conductor 107, and thence to ground 100 through the wiper 108 and the normal terminal of the bank to which this wiper has access. The magnet 105, upon energizing in this circuit, advances the wipers 108, 109, 110, 111, 112 and 113 of switch 100 to the second contacts of the respective banks to 105 which they have access. As the second contact which wiper 108 now engages is permanently connected to ground, magnet 105 continues to step the wipers to the third set of contacts leading to the first of the group 110 of trunks to which the switch 100 has access. 115

If the first trunk of the group is busy there will be a ground potential on the test terminal thereof appearing in the lowermost bank of the switch, and the switch will 120 therefore continue stepping until an idle trunk is found upon the test terminal of which battery potential appears. When this battery potential is encountered a circuit is closed from battery through the right-hand 125

contacts of sequence switch cam 202 of the district selector to which the first idle trunk extends, through the inner left-hand armature and back contact of sleeve relay 226, 5 over test conductor 114, wiper 108, conductor 107, the left-hand armature, front contact and left-hand winding of relay 101, conductor 115, and thence to ground through both windings of relay 102. Relays 101 and 10 102 are then energized in this circuit. The energization of relay 102 opens the circuit of the stepping magnet 105 at its lowermost armature and back contact and at its upper armature and front contact and intermediate 15 armature and front contact this relay extends the conductors 103 and 104 of the subscriber's line to the wipers 111 and 113 of the switch 100, and thence to the trunk conductors 116 and 117 leading to the selected 20 district selector. Relay 102, at its intermediate armature and front contact, closes a circuit extending through the left-hand winding of sleeve relay 226 of the district selector switch through the normal contacts of the 25 left-hand armature of slow releasing relay 227, the lower right-hand contact of sequence switch cam 203 (1 to 2½), sleeve conductor 118, wiper 109, conductor 120, the intermediate armature and front contact of 30 relay 102, and thence to ground through the upper winding of relay 102. The sleeve relay 226 of the district selector switch energizes in this circuit.

For making the calling subscriber's line 35 busy to all calls incoming thereto, battery potential is connected to the multiples of test terminal 121 appearing in the banks of all final selector switches having access to this line, over conductor 122, through wiper 40 110 and the off-normal segment 123 to grounded battery. Wiper 112 through the grounded off normal segment 124 prepares a circuit extending over conductor 125 preparatory to restoring the finder switch 100 45 to normal when relay 102 becomes deenergized upon the termination of the connection.

Upon the energization of sleeve relay 226 50 a circuit is established for the line relay 228 of the district selector switch 250, which circuit extends from grounded battery through the right-hand winding of this relay, the upper contacts of sequence switch cam 204, the right-hand armature and front contact of relay 226, and thence to ground through 55 the upper right-hand contact of sequence switch cam 205 (17 to 15). At its inner left-hand armature and front contact relay 226 connects ground potential to the test conductor 114 of the selected trunk to mark the 60 trunk busy to other line switches, and at the back contact of this armature disconnects the source of battery potential which up to the time the selector switch was seized 65 marked the selector switch as idle. The

locking circuit of line relay 101 is now opened and the line relay deenergizes.

Relay 228, upon energizing, closes a circuit for driving the sequence switch 200 of the district selector switch out of its normal 70 position 1 into position 2, this circuit extending from grounded battery through the magnet winding of sequence switch 200, the lower right-hand contact of sequence switch cam 206 (1), the inner right-hand armature 75 and front contact of relay 228, and thence to ground at the upper right-hand contact of sequence switch cam 207 (7½ to 6). The sequence switch magnet energizes in this circuit and under the control of master cam 80 201 drives the sequence switch into position 2, in which position a circuit is closed from grounded battery through the left-hand winding of relay 227, and thence to ground 85 through the upper left-hand contact of sequence switch cam 205 (2 to 11). Relay 227, upon energizing, closes a locking circuit for sleeve relay 226 extending through the left-hand winding of relay 226, the alternate 90 contact of the left-hand armature of relay 227, and thence to the sleeve conductor 118, over the upper right-hand contact of sequence switch cam 203 (1¾ to 16), this circuit being maintained through position 16 95 of the sequence switch or until relay 227 becomes deenergized. Upon reaching position 2 the sequence switch connects a new holding ground to the test conductor 114 at the lower left-hand contact of sequence switch cam 205, which holding ground is maintained through position 18½ of the sequence 100 switch.

As soon as the sequence switch reaches position 1¾, a circuit is closed for the stepping magnet 229 of the sender finder SF extending from grounded battery through the interrupter contacts and winding of magnet 229, the lower left-hand contact of sequence switch cam 208, the inner right-hand armature and front contact of relay 228, and to ground at the right-hand contact of sequence switch cam 207. A circuit is also closed at 105 this time through the winding of stepping magnet 229, the winding of cut-in relays 230 and 244 in parallel and thence to ground at the upper left-hand contact of sequence switch cam 209 (2 to 11). Relays 230 and 244 do not energize at this time, however, 110 since their windings are shunted by ground connected through the armature of relay 228. 115

As soon as sequence switch 200 leaves position 1 the initial energizing circuit of relay 228 is opened at the upper contacts of sequence switch cam 204, but this relay remains locked over a circuit extending from grounded battery through its left-hand winding, its left-hand armature and front contact, the lower right-hand contact of sequence switch cam 210 (1 to 6), the lower 120 left-hand contact of sequence switch cam 125 130

211 (1 to 24), the outer left-hand armature and front contact of relay 226, test wiper 231 of the sender finder switch, and to ground on busy terminals of the bank over 5 which this wiper moves. As soon, however, as an idle sender mechanism is found, the wiper 231 will find no ground potential on the terminal corresponding to such idle sender mechanism and the line relay 228 10 will thereupon deenergize, opening at its inner right-hand armature and front contact the circuit extending through the stepping magnet 229, and closing at its inner right-hand armature and back contact a 15 circuit for driving sequence switch 200 out of position 2 and into position 3. This circuit may be traced from grounded battery through the magnet winding of sequence switch 200, the upper left-hand contact of 20 sequence switch cam 206 (2), the inner right-hand armature and back contact of relay 228, and thence to ground at the right-hand contact of sequence switch cam 207.

As soon as line relay 228 deenergizes, the 25 shunt around the windings of relays 230 and 244 is removed at the inner right-hand armature and front contact of relay 228, and relays 230 and 244 thereupon energize in series with stepping magnet 229, the current 30 flowing through this circuit, however, not being sufficient to cause the energization of the stepping magnet. Relay 230, upon energizing, closes a circuit extending from ground through the inner right-hand armature and front contact of this relay, over 35 wiper 231 and the terminal upon which it is resting, conductor 625, and thence to grounded battery through the left-hand winding of differential relay 626. Relay 40 626 energizes in this circuit and closes a circuit for advancing the time measure switch TM out of its normal position. This circuit may be traced from grounded battery through the winding of stepping magnet 627, wiper 628 and the normal terminal 45 of the bank with which it is associated, interrupter 629, the outer left-hand armature and back contact of relay 630, and thence to ground at the armature and front contact of relay 626. Stepping magnet 627 advances the wipers of the time measure 50 switch into position 2 under the control of interrupter 629 for measuring off a suitable time interval before relay 630 becomes energized to apply the dialing tone to the calling subscriber's line.

As soon as the time measure switch TM reaches position 2 a circuit is established 55 for relay 630 which may be traced from grounded battery through the winding of this relay, bank terminal 631, wiper 632, and thence, to ground. Relay 630 energizing in this circuit closes a locking circuit for itself extending through its winding, its intermediate left-hand armature and front 60 contact, and thence to ground at the armature and front contact of relay 626. At the back contact of its outer left-hand armature relay 630 opens the previously traced stepping circuit through the stepping magnet 627 of the time measure switch and closes 65 a new stepping circuit which may be traced from grounded battery through the winding of stepping magnet 627, the armature and back contact of magnet 627, wiper 633, 70 the second position terminal 634 with which the wiper 633 is now in engagement, the outer left-hand armature and front contact of relay 630, and thence to ground at the armature and front contact of relay 626. 75 Stepping magnet 627 is now energized in this circuit and by means of its ownself-interrupting armature contact advances the wipers of time measure switch TM to position 6, in which position the circuit of 80 magnet 627 is opened at wiper 633. As soon as the time measure switch leaves its normal position busy ground potential is applied to the test conductor 625 multiplied 85 into the bank terminals of all sender finder switches SF having access to the seized sender. This busy potential is applied to conductor 625 over a circuit which may be traced from ground through wiper 635, the off normal terminals of the bank with which 90 wiper 635 is associated, the right-hand differential winding of relay 626, and thence to test conductor 625, and serves to hold the selected sender busy until the sender is released by its disassociation from the district 95 selector by which it was initially seized.

Relay 630, upon energizing, also closes a dialing circuit for associating the registers of the sender with the calling subscriber's line, which may be traced from grounded 100 battery through the winding of stepping relay 800, conductor 801, the outer left-hand armature and back contact of relay 1200, the outer left-hand armature and back contact of relay 1201, conductor 1203, the right-hand armature and front contact of relay 630, conductor 637, wiper 236, the inner left-hand armature and front contact of relay 230, conductor 235, the lower left-hand contact of sequence switch cam 213, the winding of relay 234, trunk conductor 116, wiper 111 of the trunk finding switch 100, the innermost armature and front contact of relay 102, line conductor 103, through the calling subscriber's sending dial S, line conductor 104, the upper armature and front contact of relay 102, wiper 113, trunk conductor 117, the lower left-hand contact of sequence switch cam 212, conductor 233, 110 the outer left-hand armature and front contact of relay 230, wiper 232, conductor 636, inner left-hand armature and front contact of relay 630, conductor 1202, the outer right-hand armature and back contact of relay 1201, the outer right-hand armature and 115 120 125 130

back contact of relay 1200, conductor 1204, and thence to ground through the right-hand winding of balancing retardation coil 638. The stepping relay 800 energizes in 5 this circuit and at its left-hand armature and front contact closes a circuit for the slow releasing relay 802, this circuit extending from grounded battery through the winding of relay 802, and thence to ground 10 through the left-hand armature and front contact of relay 800. A circuit is now closed for sending a dialing tone to the calling subscriber's line, which circuit may be traced from ground through the make contacts 15 of the right-hand armature of relay 802, conductor 803, wiper 804, normal bank terminal 805, conductor 806, through the left-hand winding of balancing coil 638, and thence to ground 20 through the secondary winding of tone coil 689. The tone current flowing in this circuit is inductively transmitted to the substation of the calling subscriber through the right-hand winding of balancing coil 638 and over the circuit previously 25 traced.

Upon the initial energization of relay 626 a circuit was also established for initiating the operation of the monitoring time measure switch M. The starting circuit for starting 30 the switch M may be traced from grounded battery through the winding of starting relay 1205, the normally closed contacts associated with its inner left-hand armature, wiper 1206 of the switch M and 35 the normal bank terminal upon which it is resting, conductor 1207, thence to ground at the armature and front contact of relay 626. Relay 1205 energizing in this circuit establishes a locking circuit for itself independent 40 of the wiper 1206, which may be traced through its winding, the make contact of its inner left-hand armature, conductor 1208, and thence to ground on conductor 1207. At its intermediate right-hand armature, relay 1205 establishes a circuit for slow 45 to release relay 1209 which may be traced from ground through the intermediate right-hand armature and front contact of relay 1205, the inner left-hand armature and back 50 contact of relay 1210, wiper 1277 of the switch M, the normal bank terminal upon which it is resting, the winding of relay 1209, conductor 1211, the right-hand armature and back contact of the coin translator 55 register relay 1035, conductor 1036, and thence to battery at the outer right-hand armature and back contact of zone relay 1302. Relay 1209, upon energizing, closes a locking circuit for itself extending from 60 conductor 1211, through its winding, its left-hand armature and front contact, the outer right-hand armature and back contact of coin collect relay 1212, conductor 1213, the armature and back contact of coin test relay 65 1214, the inner left-hand armature and back

contact of relay 1215, and thence to ground at the outer right-hand armature and front contact of relay 1205. At its right-hand armature and front contact relay 1209 establishes a circuit for relay 1216, which may be traced 70 from battery on conductor 1211, through the winding of relay 1216, and thence to ground at the right-hand armature and front contact of relay 1209, and a circuit for relay 1210 which may be traced 75 from grounded battery through the right-hand winding of relay 1210, wiper 1217 of the switch M, the normal bank terminal upon which the wiper is resting, and thence to ground at the right-hand armature and front contact of relay 1209. The energization 80 of relay 1216 is without effect at this time.

Relay 1210, upon energizing, establishes a stepping circuit for the stepping magnet 85 1218 of the switch M, which may be traced from grounded battery through the winding of magnet 1218, the right-hand armature and front contact of relay 1210, wiper 1217 and the normal bank terminal upon which it is resting, and thence to ground at the right-hand armature and front contact of relay 1209. Stepping magnet 1218 advances the 90 wipers of switch M one step when the energizing circuit of relay 1210 is opened at the switch wiper 1217 and the previously traced circuit through the winding of stepping magnet 1218 is opened at the armature contact of relay 1210. With relay 1210 deenergized and switch M in position 1 a new driving 95 circuit for the switch M is established through the winding of stepping magnet 1218 and the slow interrupter 1219, which may be traced from grounded battery 100 through the winding of magnet 1218, the right-hand armature and back contact of relay 1210, interrupter 1219, the inner left-hand armature and back contact of relay 1220, the No. 1 terminal in the bank with which wiper 1277 is associated, wiper 1277, 105 the inner left-hand armature and back contact of relay 1210, and thence to ground at the intermediate right-hand armature and front contact of relay 1205. Under the influence 110 of the slow interrupter 1219, switch M is advanced into position 3 measuring off time sufficient to enable the calling subscriber to dial the first digit. If the calling subscriber fails to dial the first digit within the time measured by the advance of switch 115 M to position 3, a circuit is established for displaying a signal on the sender monitoring lamp 1221, which circuit may be traced from grounded battery through the lamp 1221, the outer left-hand armature and back 120 contact of relay 1215, bank terminal 1222, wiper 1223, the outer left-hand armature and back contact of relay 1210, and thence to ground at the intermediate right-hand 125 armature and front contact of relay 1205. 130

At the same time a signal is displayed by the pilot lamp 1224, the lamp 1224 being illuminated over a circuit which may be traced from grounded battery through lamp 1224, the right-hand armature and back contact of relay 1220, bank terminal 1225, wiper 1277, the inner left-hand armature and back contact of relay 1210, and thence to ground at the intermediate right-hand armature and front contact of relay 1205. The monitoring operator noting the illumination of lamps 1221 and 1224 takes the necessary steps to ascertain the trouble on the calling line or the reason why the calling subscriber 15 has failed to commence dialing.

Assuming that the calling subscriber does proceed to dial the first digit of the number of the desired connection within the specified time interval, and further assuming that the subscriber desires a connection with a subscriber's line L which is listed in the directory as "L I S penard 9532," and that the called line is to be reached through a district selector switch 250, an office selector switch 350, an incoming selector 450, and a final selector 550, the subscriber proceeds to dial three letters corresponding to the office designation of the desired line and then dials four digits representing the number of the line in such office. In the case assumed the calling subscriber will dial the letters L I S and will then dial the numerals 9532. The three letters which represent the office code will not only cause the setting of the district selector switch and office selector switch to choose the desired office, but will also cause the selection of a proper talking path for efficient speech transmission between the offices and 40 the setting of the class sequence switch 750 for determining the adjustment of the circuit of the sender in accordance with the class of the call which is being extended.

45 *Setting the code and numerical registers.*

In response to the first interruption of the impulse circuit by the calling subscriber in accordance with the first letter of the office designation, the stepping relay 800 deenergizes and closes a circuit for the stepping magnet 807 of the first code register A, which stepping circuit may be traced from grounded battery through the left-hand armature and back contact of preliminary pulse relay 808, conductor 809, the winding of slow release relay 810, conductor 811, the winding of stepping magnet 807, the back contact and outer right-hand armature of relay 808, the normal bank terminal 60 812 of the register steering switch RS, wiper 813 normally in engagement therewith, conductor 814, the upper contacts of route switch cam 1303 (1), conductor 1304, the left-hand armature and front contact of slow releasing relay 802, and thence to

ground through the armature and back contact of stepping relay 800. In response to this impulse the stepping magnet 807 advances the wipers of the register A one step as soon as the circuit of the stepping magnet 807 is again opened upon the reenergization of stepping relay 800, and in response to successive interruptions of the first code letter L, the register A advances its wipers into contact with the fifth set of terminals 70 of its banks. To insure that the stepping magnet 807 shall remain energized long enough upon each deenergization of stepping relay 800 to cause a complete step of the register, a circuit is closed through relay 80 841 in parallel with the winding of stepping magnet 807, which circuit may be traced from grounded battery through the inner right-hand armature and back contact of relay 808, the winding of relay 841, wiper 842, the normal terminal of the bank with which it is associated, the armature and back contact of stepping magnet 807, and thence to ground at the armature and back contact of relay 800 over the circuit previously traced. Relay 841 energizes in this circuit and closes a locking circuit for itself independent of the armature contacts of relay 800, which locking circuit extends over the circuit previously traced through the 85 winding of relay 841, through the armature and back contact of magnet 807, the outer right-hand armature and back contact of relay 808, bank terminal 812, wiper 813, thence to ground through the left-hand armature and front contact of relay 841. Relay 841 and stepping magnet 807 are thus maintained energized until stepping magnet 807 has moved its armature to substantially the 90 full extent of its movement when the circuit through relay 841 is opened at the armature contacts of magnet 807. Relay 841, at its right-hand armature and front contact, closes a holding circuit for slow releasing relay 802 for holding this relay energized independent of the energization of relay 800. 95

The slow releasing relay 810, which was also energized in the circuit of stepping magnet 807 of the register A, maintains its 100 energization because of its slow releasing characteristic until the series of impulses transmitted through the magnet 807 ceases, whereupon this relay deenergizes. Upon its initial energization relay 810 closes a circuit 105 extending from grounded battery through the make contacts of its left-hand armature and the winding of slow releasing relay 815, and this latter relay through its armature and front contact connects ground potential to the test conductor 625 independently of the off normal contacts and wiper 635 of time measure switch TM for insuring that the office sender shall be maintained 110 busy during the setting of register A. At its 115 120 125 130

right-hand armature and front contact relay 810 also closes a circuit extending from grounded battery through the winding of slow releasing relay 816 through the winding of stepping magnet 817 of the register steering switch RS, conductor 818, through the right-hand armature and front contact of relay 810, and thence to ground over conductor 803, and the front contact and the 10 right-hand armature of relay 802. As soon as relay 810 deenergizes upon the cessation of impulses flowing through the circuit of stepping magnet 807, the circuit previously traced through relay 816 and stepping magnet 817 is opened, causing the deenergization 15 of stepping magnet 817 and the advancement of the wipers of the register steering switch from engagement with the normal terminals of the respective banks to which 20 they have access into engagement with the No. 1 terminals of the banks. The movement of wiper 813 now transfers the control circuit extending from the armature of stepping relay 800, over conductors 1304 and 25 814 from the winding of stepping magnet 807 of register A, through the winding of stepping magnet 819 of the register B. Slow releasing relay 816 which was energized in series with the stepping magnet 30 817 during its energization maintains a ground potential connected to the test conductor 625 for holding the sender busy during the advancement of the steering switch.

As soon as the steering switch advances 35 its wipers to the No. 1 terminals of its banks a circuit is established for continuing the advance of the monitoring time measure switch M out of position 3. The circuit may be traced from grounded battery 40 through the right-hand winding of relay 1210, wiper 1217, the No. 3 terminal of the bank with which it is associated, conductor 1226, the No. 1 terminal with which the wiper 804 of the register steering switch RS is in 45 engagement, wiper 804, conductor 803, and thence to ground at the right-hand armature and front contact of relay 802. Relay 1210 energizes in this circuit and closes a circuit for the stepping magnet 1218 of the switch 50 M, which may be traced from grounded battery through the winding, armature and back contact of stepping magnet 1218, the right-hand armature and front contact of relay 1210, wiper 1217, and thence to ground 55 over the circuit previously traced at the right-hand armature and front contact of relay 802. Stepping magnet 1218 now advances the wipers of switch M from position 3 to position 5 when the stepping circuit is 60 interrupted at wiper 1217. As soon as wiper 1217 leaves position 4 the circuit of relay 1210 is opened and relay 1210 deenergizes, establishing a new driving circuit for switch M for advancing the wipers of the switch 65 under the control of the slow interrupter

1219. This driving circuit may be traced from grounded battery through the winding of stepping magnet 1218, the right-hand armature and back contact of relay 1210, interrupter 1219, the inner left-hand armature and back contact of relay 1220, Nos. 4, 5 and 6 terminals of the bank associated with wiper 1277, wiper 1277, the inner left-hand armature and back contact of relay 1210, and thence to ground at the intermediate right-hand armature and front contact of relay 1205.

During the advancement of the wipers of switch M from position 4 into position 7 an interval of time is measured sufficient to 70 enable the calling subscriber to completely dial the number of the desired connection. If the subscriber has not completed dialing at the time the switch M reaches position 7, the switch stops in position 7 and a circuit 75 is established through resistance for the sender monitoring lamp 1221 for lighting the lamp dimly to indicate unfinished dialing. The circuit of lamp 1221 may be traced from grounded battery through the lamp, 80 the outer left-hand armature and back contact of relay 1215, resistance element 1227, the No. 7 terminal of the bank with which the wiper 1223 is associated, wiper 1223, the outer left-hand armature and back contact 85 of relay 1210, and thence to ground at the intermediate right-hand armature and front contact of relay 1205. At the same time the monitoring pilot lamp 1224 is illuminated 90 over the previously traced circuit. The 95 operator noting the dim illumination of lamp 1221 then proceeds to take the necessary steps to ascertain the trouble.

With the register steering switch RS in 100 position 1 the second series of interruptions 105 corresponding to the second code letter of the office designation causes the setting of the code register B in a manner similar to the setting of register A, the stepping circuit of the magnet 819 of the register B extending from grounded battery, through the left-hand armature and back contact of relay 808, conductor 809, the winding of slow releasing relay 810, conductor 811, the winding of stepping magnet 819, conductor 820, bank terminal 821, wiper 813 in engagement therewith, conductor 814, thence as previously traced to ground at the armature and back contact of stepping relay 800. Under the assumption that the second code letter is I, 110 the wipers of the code register B take a setting on the No. 4 terminals of the banks with which the respective wipers make contact. Upon the termination of the interruptions 115 of the second code letter, the slow releasing relay 810 deenergizes and in the manner previously described causes the movement of the register steering switch RS into position 2, 120 in which position the control circuit previously traced through the stepping magnet 125 130

819 of the code register B is opened and the control circuit is extended through the stepping magnet 822 of the code register C.

With the wipers of the register steering switch RS in engagement with the second position terminals of the respective banks of the switch, a circuit is established for relay 639, which may be traced from grounded battery through the right-hand winding of this relay, conductor 640, the outer right-hand armature and back contact of zone relay 1305, conductor 1306, terminal 823, wiper 804 in engagement therewith, conductor 803, and thence to ground at the right-hand armature and front contact of relay 802. Relay 639, upon energizing, closes a locking circuit for itself extending from grounded battery through its left-hand winding, inner left-hand armature and front contact, and thence to ground through the wiper 635 of the time measure switch TM and the off normal terminals of the bank to which this wiper has access. At its inner left-hand armature and front contact relay 639 closes a circuit for the control relay 641 of the translator control sequence switch 600. This circuit extends from grounded battery through the left-hand winding of relay 641, the contact of sequence switch cam 602 (1 to 2), the inner left-hand armature and front contact of relay 639, and thence to ground at wiper 635.

Setting the translator switch.

Relay 641, upon energizing, closes a circuit for driving the translator control sequence switch 600 out of position 1 and into position 2, this circuit extending from grounded battery through the magnet winding of sequence switch 600, the left-hand contact of sequence switch cam 603 (1), and thence to ground through the armature and front contact of relay 641. In its movement from position 1 to position 2 this sequence switch is under the control of master contact 601 which insures that the sequence switch will move completely from position 1 to position 2. Upon reaching position 2 the sequence switch closes a circuit for the up-drive magnet 1100 of the translator switch TS, which circuit extends from grounded battery through the winding of magnet 1100, conductor 1101, the contact of sequence switch cam 604 (2), and thence to ground at the armature and front contact of relay 641. In response to its energization, magnet 1100 presses the depending portion of the switch shaft 1102 of the translator switch against the constantly rotating updrive drum 1103, thereby causing the switch shaft 1102 and the brush sets carried thereby to be moved upwardly. This upward movement continues until the test brush 1104 encounters a terminal in the test bank 1105, which has been grounded through bank terminals of code registers A and B. As soon as brush 1104 engages such terminal a circuit is closed through the right-hand winding of the differentially wound control relay 641, which may be traced from grounded battery 70 through the right-hand winding of this relay, the left-hand contacts of sequence switch cam 605, conductor 1106, test brush 1104 of the translator switch, terminal 1107, conductor 1108, terminal 824 and wiper 825 of the register A, conductor 826, terminal 827 and wiper 828 of the register B, conductor 829, and thence to ground at the lower left-hand contact of sequence switch cam 606 (1 to 3). Current flowing through the 80 right-hand winding of relay 641 differentially balances the relay, which thereupon deenergizes opening at its armature and front contact the circuit previously traced through the up-drive magnet 1100 of the 85 translator switch to thereby arrest the upward movement of the switch. The brush shaft of the switch is now positioned with a certain pair of brush sets in cooperative relation with tripping fingers on the tripping spindle 1109. Relay 641, upon deenergizing, also closes a circuit for driving the translator control sequence switch 600 out of position 2 and into position 3, this circuit 90 extending from grounded battery through the magnet winding of sequence switch 600, the upper left-hand contact of sequence switch cam 607 (2), and thence to ground at the armature and back contact of relay 641. Upon leaving position 2 the initial energizing circuit extending through the left-hand winding of relay 641 is opened at the contact of sequence switch cam 602, but this circuit is again established as soon as the sequence switch reaches position 3 and the 100 relay 641 therefore again energizes. Upon reaching position 3 a circuit is established for the tripping magnet 1110 of the translator switch TS extending from grounded battery through the winding of the tripping magnet, conductor 1111, and thence to ground through the upper contact of sequence switch cam 608 (3 to 5). The tripping magnet, upon energizing, rotates the 105 tripping spindle 1109, preparatory to tripping the pair of brush sets of the switch TS which have been positioned in operative relation to a pair of tripping fingers on the tripping spindle. It will be assumed that brush sets 1112 and 1113, shown in Fig. 11 110 of the drawing, are the brush sets which are to be tripped.

Control relay 641, upon reenergizing, with sequence switch 600 in position 3, again closes the previously traced circuit for driving sequence switch 600 out of position 3 and into position 4. When sequence switch 600 reaches position 4 a circuit is again closed for the updrive magnet 1100 of the translator switch TS, as previously traced, 125 130

When the up-drive magnet is thus energized the switch shaft 1102 is driven upwardly, and during the first portion of its upward movement, since at this time the tripping spindle 1109 has been rotated, the selected pair of brushes 1112 and 1113 are tripped. During the subsequent upward movement of the switch shaft the brushes of the tripped brush sets are caused to wipe over the terminals of the banks to which they have access until the test brush 1104 engages a terminal in the test bank 1105 corresponding to the setting of the code registers. A circuit is now established extending from battery through the right-hand winding of control relay 641, the left-hand contacts of sequence switch cam 605, conductor 1106, test brush 1104, bank terminal 1114, conductor 1115, terminal 830 and wiper 831 of the code register B, conductor 832, terminal 833 and wiper 834 of the code register A, conductor 835, and thence to ground at the lower left-hand contact of sequence switch cam 608 (1 to 5). Upon the closure 25 of this circuit through the right-hand winding of relay 641, relay 641 deenergizes opening at its armature and front contact the previously traced circuit extending through the updrive magnet 1100 of the switch TS to arrest the upward movement of the switch shaft and to position the selected sets of brushes beneath the groups of bank terminals corresponding to the settings of code registers A and B. Relay 641 also 30 closes the previously traced circuit extending through its armature and back contact for driving sequence switch 600 out of position 4 and into position 5. Upon leaving position 4 the initial energizing circuit extending through the left-hand winding of relay 641 is opened at the contact of sequence switch cam 602, but this circuit is again established as soon as the sequence switch reaches position 5. Relay 641, upon 35 reenergizing, closes the previously traced circuit for driving sequence switch 600 out of position 5 and into position 6.

With sequence switch 600 in position 6 and relay 641 energized, the previously traced circuit extending through the winding of updrive magnet 1100 of the translator switch TS is again established and the updrive magnet again causes the upward movement of the switch shaft to move the selected sets of brushes over the selected group of terminals in the bank to which the brushes have access, or until test brush 1104 engages a terminal in the bank 1105 upon which ground potential has been placed over a circuit extending through a wiper of the code register C. Upon the engagement of test brush 1104 with the terminal 1116, a circuit is established through the right-hand winding of relay 641, which

may be traced from grounded battery 65 through the right-hand winding of relay 641, the left-hand contacts of sequence switch cam 605, conductor 1106, test brush 1104, terminal 1116, conductor 1117, terminal 836 and wiper 837 of the code register C, which was set by the calling subscriber in response to the third letter S in the same manner as the registers A and B, thence over conductor 838 and to ground at the lower left-hand contact of sequence switch cam 609 (5 to 8). The current flowing through the right-hand winding of relay 641 now differentially balances the relay causing its deenergization. Relay 641, upon deenergizing, opens the previously traced circuit extending through the winding of updrive magnet 1100 to arrest the upward movement of the switch TS, and at its armature and back contact closes the previously traced circuit for driving sequence switch 600 out of position 6 and into position 8. In passing out of position 6 the initial energizing circuit of relay 641 is opened at the contact of sequence switch cam 602, and in passing into position 7 a circuit is established for relays 1118 and 1119, which circuit may be traced from grounded battery through the windings of these relays in parallel, conductor 1120, the right-hand armature and back contact of relay 1121, conductor 1122, and thence to ground through the upper right-hand contact of sequence switch cam 606 (7 to 14). Relays 1118 and 1119, upon energizing, connect the brushes of brush sets 1112 and 1113 to the windings of translator register control relays 1000, 1001, 1002, 1003, 1004, and 1005.

During the setting of the translator switch TS and immediately following the setting 105 of the code registers A, B, and C, the calling subscriber has proceeded to dial the four numerical digits of the number of the desired line, causing the setting of the wipers of the thousands register TH upon the ninth 110 set of terminals in the respective banks to which these wipers have access, the setting of the wipers of the hundreds register H upon the fifth set of terminals in the respective banks to which these wipers have access, the setting of the wipers of the tens register T upon the third set of terminals in the banks to which these wipers have access, and the setting of the wipers of the units register U upon the second set of contacts 120 in the banks to which these wipers have access. Following the setting of the units register U, the steering switch RS moves its wipers to position 7, in which position a circuit is established for advancing the time measure switch TM from position 6 into position 16, this circuit extending from grounded battery through the winding of

stepping magnet 627 of the time measure switch, wiper 628, terminals 6 to 15 of the bank with which this wiper is associated, interrupter 642, conductor 839, No. 7 terminal 840 in the bank with which wiper 804 of the steering switch RS is associated, wiper 804, conductor 803, and thence to ground through the make contacts of the right-hand armature of relay 802.

10 *Setting the translator register relays.*

Upon the connection of register control relays 1000 to 1005 inclusive with the brushes of the brush sets 1112 and 1113 of the translator switch TS, impulses are transmitted thereto from the pulse machine drum 1123. In the case assumed two impulses are transmitted from grounded battery through the brush 1124, ring 1125, segments 1126, brush 20 1127, bank terminal 1128, brush 1129 of the translator switch, conductor 1130, the inner left-hand armature and front contact of relay 1118, conductor 1131, thence to ground through the winding of class register control 25 relay 1000. Similarly, a circuit is established from grounded battery through brush 1124, ring 1125, segment 1132, brush 1133, bank terminal 1134, brush 1135 of the translator switch, conductor 1136, the inner right-hand armature and front contact of relay 1118, conductor 1137, thence to ground 30 through the winding of the district brush register control relay 1001. A circuit is closed for office brush register control relay 1002, which may be traced from grounded battery through brush 1124, ring 1125, segment 1132, brush 1133, bank terminal 1140 and brush 1141 of the translator switch, conductor 1142, the outer right-hand armature 35 and front contact of relay 1118, conductor 1143, and thence to ground through the winding of relay 1002. The circuit of the district group register control relay 1003 may be traced from grounded battery through brush 1124, ring 1125, segment 1138, brush 1139, bank terminal 1144 and brush 40 1145 of the translator switch, conductor 1146, the inner left-hand armature and front contact of relay 1119, conductor 1147, and thence to ground through the winding of relay 1003. The circuit of office group 45 register control relay 1004 may be traced from grounded battery through brush 1124, ring 1125, segment 1132, brush 1133, bank terminal 1148, brush 1149, conductor 1150, the inner right-hand armature and front 50 contact of relay 1119, conductor 1151, and thence to ground through the winding of relay 1004. The talking selection register 55 control relay 1005 is energized over a circuit extending from grounded battery through brush 1124, ring 1125, segment 1132, brush 1133, bank terminal 1152 and brush 1153 of the translator switch, conductor 1154, the

outer right-hand armature and front contact of relay 1119, conductor 1155, and thence to ground through the winding of relay 1005.

Control relay 1000, upon energizing, closes a circuit for energizing relays 1006 65 70 and 1007 extending from grounded battery through the windings of these relays in parallel, and thence to ground through the armature and front contact of relay 1000, and the impulses received from the drum 75 of the pulse machine by relay 1000 will thus be transmitted to the windings of relays 1006 and 1007. As soon as the impulse machine has rotated the drum to a point where brush 1127 engages the first segment 1126 80 and relays 1000, 1006 and 1007 are thus energized, a circuit will be closed for the class register relay 1008, which circuit may be traced from grounded battery through brush 1124, ring 1125, segment 1156, brush 85 1157, conductor 1158, the inner left-hand armature and front contact of relay 1006, conductor 1009, and thence through the right-hand winding of class register relay 1008 to ground. This relay, upon energizing, 90 closes a locking circuit for itself extending from grounded battery through the upper left-hand contact of sequence switch cam 610 (7 to 14), conductor 646, conductor 1010, and thence through the left-hand armature and front contact and left-hand winding of relay 1008 to ground. When the pulse machine drum rotates to a position in which the second segment 1126 is engaged with brush 1127, a circuit is established for 95 class register relay 1011, which may be traced from grounded battery through brush 1124, ring 1125, segment 1159, brush 1160, conductor 1161, the outer left-hand armature and front contact of relay 1006, and thence to ground through the left-hand winding of relay 1011. Relay 1011, upon energizing, locks up through its right-hand winding and right-hand armature and front 100 contact to the locking conductor 1010 in the 105 same manner as described in connection with relay 1008.

In view of the fact that the office to which the call is being extended is reached through both a district selector and an office selector 115 switch, the skip office register relay 1012 is not energized at this time.

In a manner similar to that above described, the other register relays are selectively set by the pulse machine through the operation of control relays 1001 to 1005 inclusive. The district brush register relay 1013, which was energized through the co-operation of control relay 1001, and pulse machine drum 1123, upon energizing, closes 120 a locking circuit for itself extending from grounded battery through the upper right-hand contact of sequence switch cam 610 125

(7 to 13), conductor 647, thence to ground through the inner left-hand armature and front contact and left-hand winding of relay 1013. The office brush register relay 1014, which was energized through the cooperation of relay 1002 and the pulse machine drum 1123 closes a locking circuit for itself extending to the battery lead 647. The district group register relay 1015 and the office group register relay 1016 are also energized and close locking circuits for themselves extending through their respective left-hand windings and inner left-hand armatures, and front contacts to conductor 647. The talking selection register relay 1017, which was energized through the operation of relay 1005 and the pulse machine drum closes a locking circuit for itself through its right-hand winding and inner right-hand armature and front contact to the battery lead 646.

At the beginning of the transmission of impulses from the pulse machine to the translator register control relays, the translator control sequence switch being in position 8 a circuit is established from grounded battery through brush 1124, ring 1125, timing segments 1162 of the pulse machine, brush 1163, conductor 1164, the right-hand contacts of sequence switch cam 605. (8), resistance element 643, conductor 649, conductor 735, the winding of the sender stepping relay 719, the armature and back contact of relay 720, conductor 721, the outer armature and back contact of relay 644, conductor 651, and thence to ground through resistance element 722. At this time a circuit is also closed for the No. 6 counting relay 723 extending from grounded battery through the winding of relay 723, armature and back contact of the upper No. 6' counting relay 724, lead 725, lead 725 Fig. 11, the outer left-hand armature and front contact of relay 1119, conductor 1165, the lower left-hand and upper right-hand contacts of sequence switch cam 702 (1), the armature and front contact of stepping relay 719, and thence to ground through the lower left-hand contact of sequence switch cam 703 (1). In response to the first timing impulse through the stepping relay 719, the circuit just traced through counting relay 723 is closed and counting relay 723 energizes closing a locking circuit for itself extending from grounded battery through its winding, the winding of upper counting relay 724, the armature and front contact of relay 723, and thence to ground over conductor 727 and the upper contact of sequence switch cam 609 (8). Counting relay 724 does not energize in this locking circuit in view of the fact that its winding is shunted by ground connected to one terminal of its

winding over lead 725 and through the 65 front contacts of stepping relay 719. As soon, however, as stepping relay 719 deenergizes following the transmission of the first timing impulse, the shunt is removed and relay 724 energizes, extending the circuit from lead 725, through the armature and front contact of relay 724, the armature and back contact of the upper No. 5' counting relay 728 to grounded battery through the winding of the lower No. 5 75 counting relay 729. In a similar manner counting relay 729 and the remaining counting relays of the series energize and lock up on succeeding impulses from the timing segments of the pulse machine, until the lower No. 0 counting relay No. 730 and the upper No. 0' counting relay 731 energize. At this time seven impulses have been counted out, thus insuring a complete revolution of the pulse machine drum for setting the translator register relays before relay 731, by its energization, initiates the movement of the sender sequence switch 700 out of the normal position 1 into position 2, in which position the fundamental circuit is closed for controlling the first selecting movement of the district selector 250.

Restoration of translator switch.

Upon the energization of counting relay 731, a circuit is closed for control relay 760 of the class switch, which may be traced from grounded battery through the right-hand winding of relay 760, over conductor 100 900, through the outer left-hand armature and front contact of relay 1118, conductor 1166, and thence to ground at the armature and front contact of counting relay 731. Relay 760, upon energizing, closes a circuit for relay 1121, Fig. 11, which may be traced from grounded battery through the winding of relay 1121, conductor 1167, and thence to ground at the armature and front contact of relay 760. Relay 1121, upon energizing, closes a locking circuit for itself extending through its right-hand armature and front contact, over conductor 1122, and thence to ground through the upper right-hand contact of sequence switch cam 606 115 (7 to 14). At its right-hand armature and back contact, relay 1121 opens the energizing circuit of relays 1118 and 1119, which thereupon deenergize, disconnecting the pulse machine from the winding of translator register control relays 1000 to 1005 inclusive. Upon the deenergization of relay 1118, the circuit of relay 760 is opened and relay 760 thereupon deenergizes, closing at its armature and back contact a circuit for driving the translator control sequence switch 600 out of position 8 and into position 9. This circuit may be traced from

grounded battery through the winding of sequence switch magnet 600, the right-hand contact of sequence switch cam 603 (8), conductor 652, the left-hand armature and 5 front contact of relay 1121, conductor 1168, and thence to ground at the armature and back contact of relay 760.

When the translator control sequence switch 600 reaches position 9 a circuit is 10 established for releasing relay 1169 of the translator switch TS, which circuit may be traced from grounded battery through the right-hand non-inductive winding of relay 1169, through the left-hand winding of this 15 relay, conductor 1170, and thence to ground through the lower right-hand contact of sequence switch cam 608 (9 to 18). Relay 1169, upon energizing, closes a circuit for 20 the downdrive magnet 1171 of the translator switch TS, this circuit extending from grounded battery through the winding of the downdrive magnet, and thence to ground through the armature and front contact of relay 1169. The energization of 25 magnet 1171 presses the depending portion of the switch shaft 1102 against the constantly rotating downdrive drum 1172, thereby driving the switch shaft downwardly into its normal position. When the 30 switch shaft 1102 reaches normal position the off normal contacts 1173 are closed, thereby connecting ground potential to a point between the right-hand non-inductive and left-hand windings of relay 1169, shunting 35 out the energizing winding of this relay and causing the relay to deenergize. Through the restoration of the translator switch shaft 1102 the tripped brush sets are again restored to their normal untripped 40 positions in the well-known manner. The translator switch TS and circuits associated therewith are now in normal condition.

Setting the class switch.

45 In position 9 of the translator control sequence switch 600 a circuit is also established for moving the sender sequence switch 700 out of position 1 and into position 2. This circuit may be traced from 50 grounded battery through the winding of the magnet of sequence switch 700, conductor 732, the lower right-hand contact of sequence switch cam 704 (1), conductor 733, the outer right-hand armature and front 55 contact of the energized district brush register relay 1013, the outer right-hand armature and front contact of the energized office brush register relay 1014, the outer left-hand armature and front contact of energized 60 district group register relay 1015, the outer right-hand armature and front contact of energized office group register relay 1016, the outer right-hand armature and front contact of energized talking selection

register relay 1017, and thence over conductor 1019 to ground through the lower right-hand contact of translator control sequence switch cam 609 (8½ to 9).

Upon the energization of class register relay 1008 and 1011 circuits were closed for 65 driving the class switch 750 out of the position in which it was standing at the time into position 4, position 4 being the position assigned for all full mechanical calls. Assuming that the class switch 750 was standing in position 12 at the time class register relays 1008 and 1011 were energized, the 70 circuit for driving the class switch out of position 12 and into position 14 may be traced from grounded battery through the 75 magnet of class switch 750, the lower right-hand contact of class switch cam 752 (6 to 13), conductor 901, the right-hand armature and back contact of relay 1037, conductor 1038, contacts of sequence switch cam 1807 80 (1), conductor 1020, conductor 1167, and thence to ground through the armature and front contact of relay 760, relay 760, having 85 been energized as previously described, immediately following the transmission of 90 impulses from the pulse machine drum for setting the translator register relays. Class switch 750, upon reaching position 14, is driven through position 18 into position 1 95 over a circuit extending from grounded battery through the magnet winding of 100 switch 750, the upper left-hand contact of cam 752 (13 to 18), conductor 902, the right-hand armature and back contact of class register relay 1021, and thence over 105 the circuit previously traced to ground at the armature and front contact of relay 760. Upon reaching position 1 the class switch is driven into position 3 over a circuit extending from grounded battery through the magnet winding of switch 750, the lower right-hand contact of cam 753 (1 to 2), conductor 761, the right-hand armature and front contact of class register relay 1008, and thence over the circuit previously traced through 110 the armature and front contact of relay 760. In position 3 a circuit is closed for driving the class switch into position 4, which circuit may be traced from grounded battery through the magnet winding of switch 750, 115 the upper left-hand contact of cam 753 (3), conductor 762, the left-hand armature and front contact of class register relay 1011, and thence to ground at the armature and front contact of relay 760, as previously 120 traced. Upon reaching position 4 no circuit is closed through armature contacts of the class register relays for further advancing the class switch, and the class switch is therefore arrested in position 4.

125

District brush selection.

The sender sequence switch 700 is now

standing in position 2, the register control sequence switch 600 in position 9, and the sequence switch 200 of the district selector 250 in position 3. A fundamental circuit is now established from grounded battery through the left-hand winding of relay 228 of the district selector, the left-hand contacts of sequence switch cam 210, conductor 262 the outer right-hand armature and front contact of relay 230, wiper 237 of the sender finder switch SF and the terminal of the bank with which this wiper is associated, conductor 645, the armature and back contact of relay 647, the left-hand contact of translator control sequence switch cam 611 (9 to 12), conductor 654, contact of sequence switch cam 705 (2), left-hand winding of polarized overflow relay 734, conductor 735, winding of sender stepping relay 719, the armature and back contact of relay 720, the upper contacts of sender sequence switch cam 706 (15 to 5) and (18 to 12), conductor 736, the right-hand contact of translator control sequence switch cam 612 (5 to 9), conductor 737, the contacts of sender sequence switch cam 707 (1 to 4), and thence to ground through resistance element 722. Line relay 228 of the district selector switch and the stepping relay 719 of the office sender are energized in this circuit.

Relay 228, upon energizing, closes a circuit for driving sequence switch 200 of the district selector out of position 3 and into position 4. This circuit extends from grounded battery through the magnet winding of sequence switch 200, the lower right-hand contact of sequence switch cam 206 (3), the inner right-hand armature and front contact of relay 228, and thence to ground at the right-hand contact of sequence switch cam 207 (7 $\frac{1}{2}$ to 6). With the district selector sequence switch 200 in position 4 a circuit is now closed for the updrive magnet 238, which extends from grounded battery through the winding of magnet 238, the right-hand contact of sequence switch cam 208 (4), and thence to ground through the inner right-hand armature and front contact of relay 228 and the right-hand contact of sequence switch cam 207. Magnet 238, upon energizing, presses the depending portion of the switch shaft 239 against the constantly rotating updrive drum 240, thereby causing the upward movement of the switch shaft. Upon the movement of sequence switch 200 out of position 3 the initial energizing circuit of relay 228, which extended through its left-hand winding and the lower left-hand contact of sequence switch cam 210, is opened at the lower left-hand contact of cam 210, but a locking circuit for relay 228 is closed at this time through its left-hand winding, its left-hand armature and front contact and to

the fundamental circuit previously traced through the lower right-hand contact of sequence switch cam 210 (1 to 6).

As the switch shaft 239 approaches its first brush selection position, the brush 241 engages the first conducting portion of the commutator segment 242 and a shunt circuit is established around the winding of the sender stepping relay 719 which may be traced from grounded battery through the left-hand winding, left-hand armature and front contact of relay 228, the lower right-hand contact of sequence switch cam 210, the upper left-hand contact of sequence switch cam 211 (3 $\frac{3}{4}$ to 4), conductor 243, segment 242, brush 241, and thence to ground at the lower contact of sequence switch cam 209 (9 to 7). Relay 228 is maintained energized over this shunt circuit but sender stepping relay 719 is caused to deenergize. As the switch shaft 239 continues in its upward movement the brush 241 engages an insulating portion of the segment 242 and the shunt circuit previously traced is opened whereby the sender stepping relay 719 again energizes. Thus, during the upward movement of the switch shaft the sender stepping relay 719 is intermittently energized and deenergized.

Under the assumption that the district brush translator register relays have been so set by code impulses dialed by the calling subscriber as to energize only the district brush relay 1013, a circuit is established upon the first energization of stepping relay 719 following the establishment of the fundamental circuit, which may be traced from grounded battery through the lower No. 2 counting relay 737, the armature and back contact of the upper No. 2' counting relay 738, lead 739, lead 739 Fig. 10, the inner right-hand armature and front contact of district brush register relay 1013, the right-hand armature and back contact of district brush register relay 1022, conductor 1023, the lower contact of route switch cam 1308 (1), the upper left-hand contact of sequence switch cam 708 (2), conductor 740, the right-hand contact of translator control sequence switch cam 613 (9 to 12), conductor 741, the left-hand contacts of sender sequence switch cam 704 (2), the armature and front contact of stepping relay 719 to ground through the lower right-hand contact of sequence switch cam 703. Counting relay 737, upon energizing in this circuit, closes a locking circuit for itself extending from grounded battery through the winding of relay 737, the winding of upper counting relay 738, the armature and front contact of relay 737, conductor 742, and thence to ground through the upper right-hand contact of sender sequence switch cam 703 (2). The upper counting relay 738 does not energize until relay 719 deenergizes at the time 130

the brush 241 of the district switch engages the first conducting portion of segment 242. Upon the energization of relay 738, lead 739 is extended through the armature and front contact of relay 738, the armature and back contact of the No. 1' counting relay 744, and thence to grounded battery through the winding of the No. 1 counting relay 743. Upon the second deenergization of stepping relay 719, relay 744 becomes energized and connects lead 739 to the counting relay 730, and in response to the next deenergization of stepping relay 719 the No. 0' counting relay 731 is energized closing a circuit for driving the sender sequence switch 700 out of position 2 and into position 4. This circuit may be traced from grounded battery through the winding of sequence switch magnet 700, through the upper left-hand contact of sequence switch cam 704 (2), and thence to ground at the armature and front contact of relay 731. Sequence switch 700, upon leaving position 2, opens the locking circuits of all counting relays which have been locked up, at the upper right-hand contact of sequence switch cam 703 (2). At the time the upper No. 0' counting relay 731 energized in response to the last deenergization of stepping relay 719, relay 720 was energized in parallel therewith opening at its armature and back contact the previously traced fundamental circuit extending through the windings of stepping relay 719 and line relay 228 of the district selector 250. As soon thereafter as the brush 241 engages the next insulating portion of commutator segment 242, the circuit of relay 228 now being opened, this relay deenergizes, closing a circuit for driving the district selector sequence switch 200 out of position 4 and into position 5, this circuit extending from grounded battery through the magnet winding of sequence switch 200, the upper left-hand contact of sequence switch cam 206 (4), the inner right-hand armature and back contact of relay 228, and thence to ground at the right-hand contact of sequence switch cam 207. As soon as relay 228 deenergizes, the circuit previously traced through the updrive magnet 238 is opened at the inner right-hand armature and front contact of relay 228 and the upward movement of the switch shaft is arrested. With sequence switch 200 of the district selector in position 5 and the sender sequence switch 700 in position 4, the fundamental circuit previously traced is again established and relays 228 and 719 again energize. Relay 228, upon energizing, causes the movement of the district selector sequence switch 200 from position 5 into position 6, the initial energizing circuit of relay 228 being opened, as previously described, at the lower left-hand contact of sequence switch cam 210 as soon as the sequence switch leaves posi-

tion 5, but relay 228 remaining energized over the fundamental circuit through its left-hand winding, left-hand armature and front contact and the lower right-hand contact of sequence switch cam 210. 70

During the brush selection movement of the district switch from the time the sequence switch 200 reached position 3, a circuit is established through the right-hand winding of the differential relay 227, the 75 upper contact of sequence switch cam 214, the right-hand armature and front contact of relay 244, which energized in parallel with relay 230, the lower contact of sequence switch cam 215 (3 to 10), wiper 245, the 80 inner left-hand armature and back contact of advance relay 648, resistance element 650, and thence to ground at the contact of translator control sequence switch cam 614 (2 to 18). The resistance element 650 included in this circuit is of such value that the current flowing in the right-hand winding of relay 227 is not sufficient to cause the differential relay 227 to become unbalanced and relay 227 therefore is maintained energized over the previously traced initial energizing circuit. The circuit just traced is maintained until the district selector sequence switch leaves position 10 following the completion of the setting of 90 all the selector switches and is established for a purpose which will hereinafter be described. 95

District group selection. 100

Upon reaching position 6 the circuit previously traced for the updrive magnet 238 is again established through the upper right-hand contact of sequence switch cam 208 (6), and the inner right-hand armature 105 and front contact of relay 228, and in the manner previously described the switch shaft 239 is again driven upwardly. Since at this time, however, the tripping spindle 246 has been rotated by the tripping magnet 247, which was energized in position 5 of sequence switch 200 over a circuit extending from grounded battery through the winding of magnet 247, and to ground through the lower right-hand contact of sequence switch cam 205 (5 to 7), the third 110 set of brushes is now tripped upon the initial upward movement of the switch shaft 239, and during the continued upward movement of the shaft the brushes travel over the bank with which they are associated. The remaining four sets of brushes on the switch shaft are not tripped at this time and therefore are functionless. As the switch shaft approaches its first group 115 selection position the brush 248 engages the first metallic portion of the group selection segment 249 of the commutator, and a circuit is closed in shunt of the winding of the sender stepping relay 719, which 120

- may be traced from grounded battery through the left-hand winding, left-hand armature and front contact of relay 228, right-hand contacts of sequence switch cam 210, segment 249, brush 248, and thence to ground at the lower contact of sequence switch cam 209. Relay 228 is maintained energized over this circuit but sender stepping relay 719 becomes deenergized. As the switch shaft continues in its upward movement and the brush 248 engages the first insulating portion of commutator segment 249, the shunt circuit is opened and sender stepping relay 719 again energizes. In this manner, during the upward movement of the switch shaft in its group selection movement, the sender stepping relay 719 intermittently energizes and deenergizes.
- Upon the first energization of stepping relay 719, a circuit is closed for the No. 0 counting relay 730, it being assumed that the calling subscriber has dialed such a code as to energize the district group register relay 1015, which circuit may be traced from grounded battery through the winding of relay 730, the contact of sender sequence switch cam 709 (4 to 8), lead 745, lead 745 Fig. 10, the outer left-hand armature and back contact of district group register relay 1024, the outer left-hand armature and back contact of district group register relay 1025, the right-hand armature and front contact of district group register relay 1015, conductor 1026, the lower contact of route switch cam 1309 (1), the upper right-hand contact of sequence switch cam 708 (4), conductor 740, the right-hand contacts of translator control sequence switch cam 613 (9 to 12), conductor 741, the lower left-hand and upper right-hand contacts of sequence switch cam 702, contacts of relay 719, and thence to ground through the lower left-hand contact of sequence switch cam 703 (4). Counting relay 730, upon energizing, closes a locking circuit for itself extending through the winding of the No. 0' counting relay 731, through the armature and front contact of relay 730, and thence to ground over conductor 742 and the upper right-hand contact of sender sequence switch cam 703. Upon the first deenergization of sender stepping relay 719, relay 731 energizes in parallel with relay 720, and closes at its armature and front contact a circuit as previously traced for driving sequence switch 700 out of position 4 and into position 6. Upon leaving position 4 the locking circuit extending through the windings of counting relays 730 and 731 is opened at sequence switch cam 703, and these relays thereupon deenergize. Relay 720, upon energizing, opens the fundamental circuit at its armature and back contact, thereby

causing the deenergization of line relay 228 of the district selector switch as soon as brush 248 engages the next insulating portion of segment 249.

Relay 228, upon deenergizing, opens at its inner right-hand armature and front contact the previously traced circuit of the updrive magnet 238, thereby arresting the upward movement of the switch shaft for positioning the tripped set of brushes beneath the first group of terminals in the bank. At its inner right-hand armature and back contact relay 228 closes the previously traced circuit for driving sequence switch 200 out of position 6 and into position 7. In position 7 relay 228 energizes over a circuit extending from grounded battery through its right-hand winding, the upper contacts of sequence switch cam 204, the right-hand armature and front contact of relay 226, and thence to ground at the upper right-hand contact of sequence switch cam 205 (17 to 15). Relay 228, upon energizing, closes a circuit for driving sequence switch 200 out of position 7 and into position 8, which circuit may be traced from grounded battery through the magnet winding of the sequence switch, the lower right-hand contact of sequence switch cam 206, the inner right-hand armature and front contact of relay 228, the upper left-hand contact of sequence switch cam 207 (7 to 8), and thence to ground at the right-hand armature and front contact of relay 227.

As soon as sequence switch 200 leaves position 7 the initial energizing circuit of relay 228 is opened at the contact of sequence switch cam 204, but relay 228 locks up over a circuit extending from grounded battery through its left-hand winding, its left-hand armature and front contact, the upper left-hand and lower right-hand contacts of sequence switch cam 216, and front contact of relay 228, the lower contact of cam 224, to the test brush 252, and if the first trunk of the selected group is busy to ground at the test terminal 253 of such busy trunk. Upon reaching position 8 with relay 228 energized, a circuit is established for the updrive magnet 238, which may be traced from grounded battery through the magnet 238, the upper right-hand contact of sequence switch cam 208 (8), the inner right-hand armature and front contact of relay 228, and to ground at the upper right-hand contact of sequence switch cam 207. The updrive magnet 238, upon energizing, again drives the switch shaft upwardly in search of an idle trunk in the selected group. So long as the test brush 252 encounters the terminals of busy trunks, relay 228 remains locked up. When, however, an idle trunk is encountered, which, it will be assumed, is the trunk terminating in terminals 255, 256 and 257, the locking circuit of relay 228 is opened

and relay 228 deenergizes as soon as the brushes 252, 258 and 259 have been properly centered on the bank terminals 255, 256 and 257. Until the brushes are so centered, relay 5 228 remains locked up over a circuit extending through its right-hand winding, the right-hand contacts of sequence switch cam 217, the brush centering segment 260, brush 261, the upper left-hand contact of sequence 10 switch cam 208, the inner right-hand armature and front contact of relay 228, and thence to ground at the right-hand contact of sequence switch cam 207. Upon deenergizing the circuit of the updrive magnet 238 15 is opened at the inner right-hand armature and front contact of relay 228, and the upward movement of the switch shaft is thereby arrested and a circuit is closed at the inner right-hand armature and back contact 20 of relay 228 for driving sequence switch 200 out of position 8 and into position 9. Upon reaching position 8½ busy ground potential is connected to the multiples of test terminal 255 of the selected trunk over brush 252, 25 commutator brush 251, overflow segment 279, and to ground through the upper right-hand and lower left-hand contacts of sequence switch cam 216.

Relay 228 again energizes when sequence 30 switch 200 reaches position 9 over the circuit extending from grounded battery through its right-hand winding, the upper contacts of sequence switch cam 217, the upper contact of sequence switch cam 218 35 (1 to 10), and thence to ground at the armature and front contact of relay 261. Relay 261 is at this time energized over a circuit extending from grounded battery through its winding, the left-hand contacts of sequence switch cam 215, wiper 245 of sender 40 finder SF, thence to ground at the contact of sequence switch cam 614 over the circuit previously traced. Relay 228, upon energizing in the circuit previously traced, closes 45 a circuit through its inner right-hand armature and front contact for driving sequence switch 200 out of position 9 and into position 10, in which position the fundamental circuit is extended through contacts of sequence switch cams 219 and 220, through 50 brushes 258 and 259, respectively, of the district selector switch to the line relay of the office selector switch 350. This fundamental circuit may be traced from grounded battery 55 through the right-hand winding of relay 312, the lower contacts of sequence switch cam 302, the upper trunk conductor 313, bank terminal 257 and brush 259 of the district selector switch, the upper left-hand and lower right-hand contacts of sequence 60 switch cam 220, conductor 262, the outer right-hand armature and front contact of relay 230, wiper 237, conductor 645, the armature and back contact of relay 647, the left-hand contact of sequence switch cam 611

(9 to 12), conductor 654, the contact of sequence switch cam 705 (6), the left-hand winding of polarized overflow relay 734, conductor 735, the winding of sender stepping relay 719, the armature and back contact of relay 720, the right-hand winding of relay 734, the winding of relay 746, conductor 747, the right-hand contacts of sequence switch cam 706, conductor 736, conductor 653, the lower contact of sequence switch cam 615 (9 to 12), the left-hand armature and back contact of advance relay 658, conductor 659, wiper 263 of the sender finder switch FS, the left-hand armature and front contact of relay 244, conductor 264, the lower right-hand and upper left-hand contacts of sequence switch cam 219, brush 258 and bank terminal 256 of the district selector switch, trunk conductor 314, and thence to ground through the left-hand contacts of sequence switch cam 303.

Office brush selection.

Relay 312 associated with the office selector switch 350 and the sender stepping relay 719 energizes in this circuit. Relay 312, upon energizing, closes a circuit for driving sequence switch 300 out of its normal position into position 2, this circuit extending from grounded battery through the magnet winding of switch 300, the upper left-hand contact of sequence switch cam 304 (1), conductor 315, and thence to ground through the left-hand armature and front contact of relay 312. Sequence switch 300 upon leaving position 1 opens the initial energizing circuit of relay 312 extending over the fundamental circuit, as previously traced, but relay 312 locks itself to the fundamental circuit through its right-hand winding, its inner right-hand armature and front contact, and the upper left-hand contact of sequence switch cam 305 (1 to 4). When the sequence switch 300 reaches position 2 a circuit is closed for the updrive magnet 316, which may be traced from grounded battery through the winding of this magnet, the upper right-hand contact of sequence switch cam 304 (2), conductor 315, and thence to ground at the left-hand armature and front contact of relay 312. Magnet 316, upon energizing, presses the depending portion of the switch shaft 317 against the constantly rotating updrive drum 318, and thereby causes the upward movement of the switch shaft. As the switch shaft approaches its first brush tripping position the brush 322 engages a conducting portion of segment 320 of the commutator 321, and a circuit is closed in shunt of the winding of the sender stepping relay 719. This shunt circuit may be traced from grounded battery through the right-hand winding and inner right-hand armature and front contact of relay 312, the left-hand contact of sequence switch cam 303

tact of sequence switch cam 305, the right-hand contacts of sequence switch cam 302, conductor 319, brush selection segment 320, brush 322, conductor 323, and thence to ground at the left-hand contact of sequence switch cam 306 (7 to 5). As the switch shaft continues to advance upwardly, the brush 322 engages an insulating portion of segment 320, and the previously traced shunt circuit is opened. In this manner, as the switch shaft 317 moves upwardly, the shunt circuit is intermittently established and opened. Upon each establishment of the shunt circuit relay 312 is maintained energized over the shunt but sender stepping relay 719 becomes deenergized.

The office sender relay 746 energizes over the fundamental circuit in series with sender stepping relay 719, and at its armature and front contact closes a circuit for relay 748, which in turn closes a circuit for driving the sequence switch 700 out of position 6 and into position 8. This latter circuit extends from grounded battery through the magnet winding of sequence switch 700, conductor 732, the upper right-hand contact of sequence switch 704 (6) to ground at the outer left-hand armature and front contact of relay 748. With the sender sequence switch in position 8 and the sender stepping relay 719 energized over the fundamental circuit, as previously traced, and under the assumption that the code dialed by the calling subscriber has caused the energization of office brush register relay 1014, a circuit is established for the No. 2 counting relay 737. This circuit may be traced from grounded battery through the winding of the No. 2 counting relay 737, the armature and back contact of the No. 2' counting relay 738, lead 739, lead 1044 Fig. 10, the inner right-hand armature and front contact of office brush register relay 1014, the right-hand armature and back contact of office brush register relay 1027, conductor 1028, the lower contact of route switch 1310 (1), the lower right-hand contact of sequence switch cam 708 (8), conductor 740, right-hand contact of translator control sequence switch cam 613 (9 to 12), conductor 741, the lower left-hand and upper right-hand contacts of sequence switch cam 702, armature contacts of stepping relay 719, and thence to ground through the lower left-hand contact of sequence switch cam 703. In the manner previously described the counting relays are successively energized upon successive energizations and de-energizations of stepping relay 719 until No. 0' counting relay 731 energizes, when a circuit is closed for driving sequence switch 700 out of position 8 and into position 10. Relay 720 energizes in parallel with relay 731 and opens the fundamental circuit. When sequence switch 700 leaves

position 8 the locking circuits of the counting relays are opened at cam 703.

As soon following the opening of the fundamental circuit as the brush 322 engages the next insulating portion of commutator segment 320, relay 312 deenergizes, opening at its left-hand armature and front contact the circuit previously traced through the winding of the updrive magnet 316 for arresting the upward movement of the switch shaft, and at its left-hand armature and back contact closes a circuit for driving sequence switch 300 out of position 2 and into position 3. This circuit may be traced from grounded battery through the winding of the magnet of sequence switch 300, conductor 324, the left-hand contact of sequence switch cam 307 (2), conductor 325, thence to ground at the left-hand armature and back contact of relay 312. The switch shaft of the office selector has now moved upwardly to position the third set of brushes in such a position as to be tripped upon a subsequent upward movement of the switch shaft. With sequence switch 300 in position 3 a circuit is now closed for the tripping magnet 326 for tripping the selected set of brushes, which circuit may be traced from grounded battery through the winding of the tripping magnet 326, and thence to ground through the upper right-hand contact of sequence switch cam 308 (3 to 4).

Office group selection.

With sequence switch 300 in position 3 and sender sequence switch 700 in position 10, the fundamental circuit previously traced is again closed and relay 312 of the office selector and stepping relay 719 of the office sender again energize. The energization of relay 746 and the consequent energization of relay 748 is without effect at this time since the previously traced circuit extending through the upper right-hand contact of sequence switch cam 704 for advancing the sequence switch is not closed in position 10 of the sequence switch. Relay 312, upon energizing, closes the circuit previously traced extending through the upper left-hand contact of sequence switch cam 304 for driving sequence switch 300 out of position 3 and into position 4. Upon leaving position 3 the initial energizing circuit of relay 312 is opened but relay 312 remains energized over the locking circuit previously traced extending through the left-hand contact of sequence switch cam 305. Sequence switch 300, upon reaching position 4, again closes the circuit of the updrive magnet 316, which, upon energizing, drives the switch shaft upwardly. During the initial upward movement of the switch shaft the selected set of brushes, in this instance the third set of brushes, is tripped and the

brushes thereafter wipe over the terminals of the bank to which they have access during the continued upward movement of the switch shaft.

5 As the switch shaft approaches its first group selection position the brush 329 engages a conducting portion of the commutator segment 328, and a circuit is established in shunt of the winding of the 10 sender stepping relay 719, which may be traced from grounded battery through the right-hand winding, the inner right-hand armature and front contact of relay 312, the left-hand contact of sequence switch cam 15 305, the lower right-hand and upper left-hand contacts of sequence switch cam 302, conductor 327, segment 328, brush 329, conductor 323, and thence to ground at the left-hand contact of sequence switch cam 20 306 (7 to 5). As the switch shaft continues in its upward movement, the brush 329 engages an insulating portion of segment 328 and the previously traced shunt circuit is again opened. In this manner, as 25 the switch shaft moves upwardly, the shunt around the winding of sender stepping relay 719 is intermittently established and opened and the sender stepping relay 719 is intermittently energized and deenergized. Relay 312, however, is maintained 30 energized over the previously traced shunt circuit.

Upon the first closure of the fundamental circuit with sender sequence switch 700 in 35 position 10 and with the office group register relay 1016 energized, a circuit is established upon the initial energization of sender stepping relay 719 for the No. 2 counting relay 737, which circuit may be traced from grounded battery through the winding of relay 737, the armature and back contact of the No. 2' counting relay 738, lead 739, lead 1045 Fig. 10 the inner right-hand armature and front contact of office 40 group register relay 1016, the right-hand armature and back contact of office group register relay 1029, conductor 1030, the lower contact of route switch cam 1311 (1), the lower left-hand contact of sequence 45 switch cam 708 (10), conductor 740, and thence over the circuit previously traced to ground at sequence switch cam 703. In the manner previously described, the counting relays are successively energized through 50 the intermittent operation of stepping relay 719 until the upper No. 0' counting relay 731 energizes in parallel with relay 720, when a circuit as previously described, is established through the upper left-hand contact of sequence switch cam 704 (10), for driving sequence switch 700 out of position 55 10 and into position 12. Upon leaving position 10 the locked up counting relays become deenergized through the opening of 60 the upper contact of sequence switch cam

703 in the well-known manner. Relay 720, upon energizing, opens the fundamental circuit, as previously traced, and as soon thereafter as the brush 329 engages the next insulating portion of commutator segment 328, relay 312 of the office selector switch deenergizes opening the circuit of the up-drive magnet 316, and closing the previously traced circuit for driving sequence switch 300 out of position 4 and into position 5.

Upon reaching position 5 sequence switch 300 closes a local circuit for the relay 312, which may be traced from grounded battery through the left-hand winding of relay 312 and to ground through the lower contacts of sequence switch cam 303. Relay 312, upon energizing, closes a locking circuit for itself extending from its right-hand winding, through its right-hand armatures and front contacts, the lower contact of sequence switch cam 309 (5 to 6), test brush 330, and to ground on the multiples of the test terminal of the first trunk of the group to which the selected set of 90 brushes has been moved, if this trunk is at the time busy. Relay 312, upon energizing, also closes the previously traced circuit for driving sequence switch 300 out of position 5 into position 6. Upon leaving position 5 95 the initial energizing circuit of relay 312 is opened at cam 303, but relay 312 is still maintained energized over the previously traced locking circuit if the first trunk in the selected group is busy.

As soon as sequence switch 300 leaves position 6, the previously traced circuit is closed for energizing the updrive magnet 316, which thereupon causes the selected set of brushes to be driven upwardly over the selected group of trunk terminals to which it has access. As soon as the test brush 330 engages the test terminal of an idle trunk, which, it will be assumed, is the trunk 419, 420 shown in the drawing, relay 312 deenergizes opening at its left-hand armature and front contact the circuit of the updrive magnet 316, thereby arresting the upward movement of the switch shaft. Relay 312 does not deenergize, however, until the brushes of the switch have been centered upon the terminals of the idle trunk since it is held energized over a locking circuit extending from grounded battery through its left-hand winding, the left-hand contacts of sequence switch cam 303, centering segment 331 of the commutator 321, brush 332, conductor 323, the lower left-hand contact of sequence switch cam 304 (6), conductor 315, and thence to ground at the left-hand armature and front contact of relay 312.

Relay 312, upon deenergizing, closes a circuit extending from its left-hand armature and back contact, over conductor 325 and the

lower left-hand contact of sequence switch cam 307 (6) for driving sequence switch 300 out of position 6 and into position 7. Upon reaching position 7 relay 312 is again energized over a circuit extending through its left-hand winding and the lower contacts of sequence switch cam 303, and closes a locking circuit for itself extending from grounded battery through its right-hand winding, its inner right-hand armature and front contact, the lower right-hand contact of sequence switch cam 305, and thence to ground at the lower contact of sequence switch cam 308 (2 to 7½). As soon as sequence switch 300 leaves position 7½, relay 312 is maintained energized over a circuit extending over sleeve conductor 333, test terminal 255 and brush 252 of the district selector switch, and thence to ground over the circuit previously traced at the lower left-hand contact of sequence switch cam 216. Ground potential from conductor 333 is also connected over the right-hand contacts of sequence switch cam 305 and test brush 330 to the multiples of test terminal 334 of the selected trunk circuit for marking the trunk circuit busy to all other office selector switches having access thereto. Relay 312, upon energizing, also closes a circuit for driving sequence switch 300 out of position 7 and into position 8, in which position the fundamental circuit is extended through contacts of sequence switch cams 310 and 311, switch brushes 334 and 335, bank terminals 336 and 337 to trunk conductors 419 and 420 of the selected trunk circuit terminating in incoming selector switch 450.

Upon the extension of the fundamental circuit to the incoming selector switch a circuit is closed from grounded battery through the right-hand winding of relay 421, conductor 422, the upper contacts of sequence switch cam 402, conductor 423, resistance element 424, the upper contact of sequence switch cam 403 (1 to 10), trunk conductor 419, and thence over the fundamental circuit previously traced through the winding of sender stepping relay 719 and the winding of relay 746, back over conductor 420, the lower contact of sequence switch cam 404 (1 to 10), resistance element 425, conductor 426, and thence to ground through the lower contact of sequence switch cam 405 (1 to 8). Relay 421 energizes in this circuit and at its left-hand armature and front contact closes a circuit for driving sequence switch 400 out of its normal position 1 and into position 2, this circuit extending from grounded battery through the magnet winding of sequence switch 400, the lower right-hand contact of sequence switch cam 406 (1), the outer left-hand armature and front contact of relay 421, conductor 427, and thence to ground at the lower contact of sequence switch cam 407 (1 to 10). As soon

as sequence switch 400 leaves position 1 the initial energizing circuit of relay 421 is opened at the upper left-hand contact of sequence switch cam 402, but relay 421 remains energized over the fundamental circuit through a locking branch of the fundamental circuit, which may be traced from grounded battery through the right-hand winding of relay 421, the right-hand contacts of sequence switch cam 402, conductor 428, the right-hand armature and front contact of relay 421, conductor 429, the left-hand contacts of sequence switch cam 408 (1 to 4), and thence over the fundamental circuit, as previously traced. 70 75 80 85 90 95 100

Incoming brush selection.

In position 2 of sequence switch 400 a circuit is closed for the updrive magnet 430, which may be traced from grounded battery through the winding of this magnet, the upper right-hand contact of sequence switch cam 409 (2), conductor 431, the outer left-hand armature and front contact of relay 421, and thence to ground at the lower contact of sequence switch cam 407. Magnet 430, upon energizing, presses the depending portion of the switch shaft 432 against the constantly rotating updrive drum 433, causing thereby the upward movement of the switch shaft. As the switch shaft approaches its first brush selection position a circuit is established in shunt of the winding of the sender stepping relay 719, which may be traced from grounded battery through the right-hand winding of relay 421, conductor 422, the right-hand contacts of sequence switch cam 402, conductor 428, the right-hand armature and front contact of relay 421, conductor 429, the upper left-hand and lower right-hand contacts of sequence switch cam 408, segment 434 of commutator 435, brush 436, conductor 437, and thence to ground at the lower contact of sequence switch cam 410 (7 to 5). As the switch shaft continues in its upward movement the brush 436 engages an insulating portion of commutator segment 434, and the previously traced shunt circuit is opened. In this manner, during the upward movement of the switch shaft, the shunt circuit is intermittently established and opened, whereby the sender stepping relay 719 is intermittently energized and deenergized. Relay 421, however, remains energized over the shunt circuit. 110 115 120 125 130

Upon the establishment of the fundamental circuit through the winding of the sender stepping relay 719 and the winding of relay 746, these relays energize and relay 746 closes the previously traced circuit for relay 748, and relay 748 closes the previously traced circuit extending through the upper right-hand contact of sequence switch cam 704 for driving sequence switch 700 130

out of position 12 and into position 14. Sequence switch 700 upon reaching position 14 closes a circuit for relay 749, which circuit extends from grounded battery through the winding of relay 749, and thence to ground through the contacts of sender sequence switch cam 710 (14). A circuit is now established for sequence switch 700 which may be traced through the magnet of sequence switch 700, conductor 763, the upper contacts of sequence switch cam 616 (9), conductor 764, the armature and front contact of relay 749, and thence to ground through the lower contacts of class switch cam 754 (4), it being remembered that the class switch was set in position 4 for the establishment of a full mechanical connection.

With the sender sequence switch 700 in position 16 and relay 719 energized over the fundamental circuit, as previously traced, through the winding of relay 421 of the incoming selector switch, and assuming the calling subscriber has dialed the thousands digit 9, a circuit is closed upon the first energization of stepping relay 719 for the No. 4 counting relay 764, this circuit extending from grounded battery through the winding of the lower No. 4 counting relay 764, the armature and back contact of the upper No. 4' counting relay 765, lead 766, lead 766 Fig. 9, connected to the No. 9 terminal 903 of the thousands register TH, wiper 904, which has been positioned in engagement with this terminal, conductor 905, lower left-hand contact of sequence switch cam 711 (16), conductor 740, and thence over the circuit previously traced to ground at the contact of sequence switch cam 703. Counting relay 764, upon energizing, closes a locking circuit for itself extending through the winding of the No. 4' counting relay 765 in the manner previously described, and relay 765 becomes energized in this locking circuit as soon as the stepping relay 719 deenergizes upon the first upward step of the incoming selector switch shaft 432. In the manner previously described, the counting relays are energized and locked up in succession until the upper No. 0' counting relay 731 energizes in parallel with relay 720, when a circuit is established for driving sequence switch 700 out of position 16 and into position 17. This circuit extends through the magnet winding of sequence switch 700, conductor 732, the lower left-hand and upper right-hand contacts of sequence switch cam 712 (16), the right-hand contacts of sequence switch cam 617 (9 to 12), and thence to ground at the armature and front contact of counting relay 731. Relay 720, upon energizing, opens the fundamental circuit and as soon thereafter as the brush 436 engages the next insulating portion of com-

mutator segment 434, the circuit of relay 421 is opened and relay 421 deenergizes.

Relay 421, upon deenergizing, opens, at its outer left-hand armature and front contact, the circuit of the updrive magnet 430, 70 thereby arresting the upward movement of switch shaft 432, and at its inner left-hand armature and back contact closes a circuit for driving sequence switch 400 out of position 2 and into position 3, this circuit extending from grounded battery through the magnet winding of sequence switch 400, the upper left-hand contact of sequence switch cam 406 (2), and thence to ground at the inner left-hand armature and back contact of relay 421. Upon reaching position 3 sequence switch 400 closes a circuit for the trip magnet 438 extending from grounded battery through the winding of magnet 438, and thence to ground through the right-hand contacts of sequence switch cam 405. Trip magnet 438, upon energizing, rotates the tripping spindle 439 into such a position as will trip the selected set of brushes, which in the case assumed is the 90 fifth set of brushes, upon the subsequent upward movement of switch shaft 432.

Incoming group selection.

Upon reaching position 3 the fundamental circuit extending through the winding of relay 421 and winding of stepping relay 719 is again established over the circuit previously traced. Relay 421, upon energizing in this circuit, again closes the circuit previously traced for driving the sequence switch 400 out of position 3 and into position 4, and at its right-hand armature and front contact closes the locking circuit previously traced for maintaining itself energized over the fundamental circuit after sequence switch 400 leaves position 3. With sequence switch 400 in position 4 and relay 421 energized, the circuit previously traced through the up-drive magnet 430 is again closed and the switch shaft 432 is again driven upwardly. During the initial upward movement of the switch shaft the fifth set of brushes is tripped by the tripping spindle 439, and during the subsequent upward movement of the switch shaft the tripped set of brushes travels in engagement with the terminals of the bank with which it is associated. As the switch shaft approaches the first group selection position a circuit is established in shunt of the winding of the sender stepping relay 719, which may be traced from grounded battery through the right-hand winding of relay 421, the right-hand contacts of sequence switch cam 402, conductor 428, the right-hand armature and front contact of relay 421, conductor 429, the upper contacts of sequence switch cam 408, commutator segment 440, brush 441, conductor 437, and thence to ground at the lower con-

tact of sequence switch cam 410. As the switch shaft continues in its upward movement, brush 441 comes into engagement with an insulating portion of segment 440, and the previously traced shunt circuit is opened. Thus, during the continued upward movement of the switch shaft, the shunt circuit is intermittently established and opened, and in consequence thereof the sender stepping relay 719 is intermittently energized and de-energized. Relay 421, however, is maintained energized over the shunt circuit.

Upon the establishment of the fundamental circuit through the windings of relays 421 and 719, relay 719 energizes closing a circuit for driving sequence switch 700 out of position 17 and into position 18, this circuit extending from grounded battery through the magnet winding of sequence switch 700, through the lower right-hand and upper left-hand contacts of sequence switch cam 702, the armature contacts of sender stepping relay 719, and thence to ground through the lower right-hand contact of sequence switch cam 703. The energization of the sender stepping relay with sequence switch in position 18 closes a circuit for the No. 2 counting relay 737, assuming that the calling subscriber has dialed the second digit No. 5, which may be traced from grounded battery through the winding of relay 737, the armature and back contact of the No. 2' counting relay 738, lead 739, and thence to lead 906 Fig. 9, the right-hand armature and back contact of relay 907, which relay is not energized at this time since it is assumed that the hundreds digit of the desired line is 5, and wiper 931 of hundreds register H is therefore positioned in the first half of its bank of terminals No. 9, terminal 908 of the thousands register TH, wiper 909, which has been positioned in engagement therewith, conductor 910, the lower left-hand contact of sequence switch cam 711 (18), conductor 740, and thence over the circuit previously traced to ground at sequence switch cam 703. Counting relay 737 energizes in this circuit and locks up in the manner previously described through the counting relay 738, which latter relay energizes on the first deenergization of stepping relay 719 in the well-known manner. The counting relays are successively energized through the intermittent operation of sender stepping relay 719 until the No. 0' counting relay 731 energizes in parallel with relay 720, when a circuit is established for driving the translator control sequence switch out of position 12 and into position 13, and the fundamental circuit is opened at the armature and back contact of relay 720. The translator control sequence switch was moved out of position 9 and into position 12 over a circuit closed in position 18

of the sender sequence switch 700, which circuit extends from grounded battery through the magnet winding of sequence switch 600, the upper right-hand contact of sequence switch cam 607 (9 to 10), conductor 660, and thence to ground through the upper left-hand contact of sequence switch cam 713 (15 to 18). The circuit for advancing translator control sequence switch 600 out of position 12 and into position 13 may be traced from grounded battery through the magnet winding of sequence switch 600, the lower right-hand contact of sequence switch cam 607 (12), conductor 661, right-hand contacts of sequence switch cam 714 (18), and thence to ground at the armature and front contact of relay 731. The purpose of driving the translator control sequence switch into position 13 at this time is to prepare circuits for permitting a second rotation of sequence switch 700 for controlling the circuits of the sender during the final brush, final group, and units selection movements of the final selector switch and the talking selection movement of the district selector. With the translator control sequence switch in position 13 a circuit is now closed for driving the sender sequence switch 700 out of position 18 and into position 1, this circuit extending from grounded battery through the magnet winding of sequence switch 700, conductor 732, conductor 769, the right-hand contacts of sequence switch cam 618, (13), conductor 660, and thence to ground at the upper left-hand contact of sequence switch cam 713. Upon reaching position 1 a circuit is closed over conductor 733 and the lower right-hand contact of sequence switch cam 704, as previously described, for driving sequence switch 700 out of position 1 and into position 2, in which position the circuits of the sender are in condition for controlling brush selection at the final selector switch. As soon following the opening of the fundamental circuit at the armature and back contact of relay 720 as the brush 441 engages an insulating portion of commutator segment 440, relay 421 deenergizes and opens the previously traced circuit for the updrive magnet 430 and closes the previously traced circuit for advancing the sequence switch 400 out of position 4 and into position 5. In position 5 relay 421 is again energized by a circuit extending from grounded battery through its left-hand winding, and thence to ground through the right-hand contacts of sequence switch cam 411. Relay 421 now closes a circuit extending from ground at sequence switch cam 407 and through the outer left-hand armature and front contact of relay 421 for driving sequence switch 400 out of position 5 and into position 6. Upon leaving position 5 the initial energizing circuit of relay 421 is opened at sequence switch cam 411, but

relay 421 remains energized over a locking circuit extending from grounded battery through its right-hand winding, the right-hand contacts of sequence switch cam 402, conductor 428, the right-hand armature and front contact of relay 421, conductor 429, the right-hand contacts of sequence switch cam 412, and thence through test brush 442 to ground on the test terminal of the first trunk of the group to which the brush set has been moved during the group selection movement of the switch shaft, if the first trunk in the group is at the time busy.

When the sequence switch 400 reaches position 6 the previously traced circuit for the updrive magnet 430 is again established for driving the switch shaft upwardly in its trunk hunting movement. This movement continues so long as the test brush 442 encounters ground potential on the multiple test terminals of the trunks of the group over which this brush moves. As soon, however, as an idle trunk is found, which it will be assumed is the trunk disclosed, the locking circuit of relay 421 will be opened and relay 421 will deenergize as soon as the brushes are properly centered on the terminals of the selected idle trunk, relay 421 being maintained energized until the brushes are so centered by an additional locking circuit extending from grounded battery through the left-hand winding of relay 421, the upper right-hand and lower left-hand contacts of sequence switch cam 411, conductor 443, centering segment 444 of the commutator 435, brush 445, conductor 437, the upper left-hand contact of sequence switch cam 410 (6), conductor 431, the outer left-hand armature and front contact of relay 431, and thence to ground through the sequence switch cam 407. As soon as relay 421 deenergizes the circuit of the updrive magnet is opened and the previously traced circuit is closed for advancing sequence switch 400 out of position 6 and into position 7. In position 7 relay 421 again energizes in a circuit extending through its left-hand winding and the right-hand contacts of sequence switch cam 411, and closes a circuit for driving the sequence switch out of position 7 and into position 8, in which position the tip conductor of the fundamental circuit is extended over conductor 423, the upper left-hand contact of sequence switch cam 413 (8), brush 446 and bank terminal 447, trunk conductor 517, the lower left-hand contact of sequence switch cam 502 (15 to 6), the lower left-hand contact of sequence switch cam 503 (1), the right-hand winding of relay 518, and thence to grounded battery through the upper left-hand contact of sequence switch cam 504 (1 to 10). The ring conductor of the fundamental circuit extends, as previously described, to ground at the lower right-hand contact of

sequence switch cam 405 (1 to 8). Upon the extension of the connection to the final selector switch, relay 421 of the incoming selector switch, which was energized in position 7 of sequence switch 400, is maintained energized in position 8 of sequence switch 400 over a circuit extending from grounded battery through its right-hand winding, conductor 422, the right-hand contacts of sequence switch cam 402, conductor 428, the right-hand armature and front contact of relay 421, conductor 429, the lower right-hand contact of sequence switch cam 414 (7 to 8), brush 448 and terminal 449 of the incoming selector switch, trunk conductor 519, the upper left-hand and lower right-hand contacts of sequence switch cam 505, resistance element 520, and thence to ground through the lower left-hand contact of sequence switch cam 506 (1 to 8½). Busy ground potential is placed on the multiples of test terminal 451 of the selected trunk over test brush 442 and the lower right-hand and upper left-hand contacts of sequence switch cam 412.

At the office sender the fundamental circuit extends from tip conductor 645 through the armature and back contact of relay 647, the right-hand contact of sequence switch cam 611 (13 to 18), the sequence switch 600 being now in position 13, the upper contacts of sequence switch cam 717, the left-hand winding of overflow relay 734, conductor 735, the windings of sender stepping relay 719, the armature and back contact of relay 720, the left-hand contact of sequence switch cam 612 (13 to 18), conductor 736, the left-hand contacts of sequence switch cam 714 (1 to 16), the upper contact of sequence switch cam 615 (13 to 18), the left-hand armature and back contact of relay 658, and thence to the ring conductor 659 of the fundamental circuit.

Final brush or hundreds selection.

Upon the extension of the fundamental circuit to the final selector switch 500 with the sender sequence switch 700 in position 2, relay 518 of the final selector switch and stepping relay 719 at the office sender both energize. It is to be noted that at this time relay 746 is not included in the fundamental circuit and that therefore when the sender sequence switch reaches positions 6 and 12, the sender sequence switch 700 is not advanced through the operation of relay 748. Relay 518 closes a circuit for relay 521 which may be traced from grounded battery through the left-hand winding of this relay, conductor 522, the upper left-hand contact of sequence switch cam 507 (1), conductor 523, the left-hand armature and front contact of relay 518, and thence to ground through the upper contact of sequence switch cam 508 (1 to 11). Relay 521 ener-

gizes in this circuit and at its left-hand armature and front contact closes a locking circuit for itself extending from grounded battery through its left-hand winding, the 5 armature and back contact of test relay 524, the left-hand armature and front contact of relay 521, sleeve conductor 525, bank terminal 451 and brush 442 of the incoming selector switch, and thence to ground at 10 the sequence switch cam 412. Relay 521, upon energizing, closes a circuit for driving sequence switch 500 into position 2, which circuit may be traced from grounded battery through the magnet winding of sequence switch 500, through the lower contacts of sequence switch cam 509 to ground at the right-hand armature and front contact of relay 521. When sequence switch 500 moves out of position 1 the initial energizing circuit of relay 518 is opened at the 15 lower right-hand contact of sequence switch cam 503, but relay 518 remains energized over the fundamental circuit by reason of a locking circuit extending from grounded battery through the upper left-hand contact of sequence switch cam 504, the right-hand winding of relay 518, the lower right-hand contact of sequence switch cam 510 (15 to 10), the right-hand armature and front contact of relay 518, the lower right-hand contact of sequence switch cam 503 (1 to 6), and thence to the lower left-hand contact of sequence switch cam 502, and over the 25 fundamental circuit, as previously traced. Relay 518, upon energizing with sequence switch 500 in position 2, closes a circuit for the high speed updrive magnet 526, which may be traced from grounded battery the winding of updrive magnet through the upper right-hand contact of sequence switch cam 511 (2), conductor 523, the left-hand armature and front contact of relay 518, and thence to ground at the upper left-hand contact of sequence switch cam 508. Magnet 526, upon energizing, presses the 30 pending portion of the switch shaft 527 against the constantly rotating high speed drum 528, thereby causing the switch shaft to be moved upwardly at a high speed in its brush selection movement. As the switch shaft approaches its first brush selection position, the brush 532 engages a conducting portion of the commutator segment 530 of the commutator 531, and a circuit is established in shunt of the windings of the sender stepping relay 719, which may be traced from grounded battery through the left-hand contact of sequence switch cam 504, the right-hand winding of relay 518, the 35 lower right-hand contact of sequence switch cam 510, the right-hand armature and front contact of relay 518, the lower right-hand contact of sequence switch cam 503, the upper right-hand contact of sequence switch cam 503, the upper right-hand contact of

sequence switch cam 502 (1 $\frac{3}{4}$ to 2), conductor 529, segment 530, brush 532, conductor 533, and thence to ground at the upper left-hand contact of sequence switch cam 506 (13 to 11). As the switch shaft continues in its up- 70

ward movement, the brush 532 engages an insulating portion of segment 530 and the previously traced shunt circuit is opened. Thus, as the switch shaft continues in its up- 75

ward movement, the previously traced shunt 80

circuit is established and opened and in conse- 85

quence thereof the sender stepping relay 719 is intermittently energized and deener- 90

gized. Relay 518, however, is maintained 95

energized over the shunt circuit. 100

On the initial closure of the fundamental 105

circuit through the winding of relay 518 and the windings of sender stepping relay 719, with sequence switch 700 in position 2, a circuit is closed for the No. 4 counting 110

relay 764 extending from grounded bat- 115

ttery through the winding of relay 764, the 120

armature and back contact of the No. 4' 125

counting relay 765, lead 766, lead 970 Fig. 130

9, terminal 911 and wiper 912 of the hun- 135

dreds register H, which was set in position 140

5 by the calling subscriber, conductor 913, 145

the lower right-hand contact of sequence 150

switch cam 715 (2), conductor 771, contact 155

753 (4) of class switch 750, conductor 772, 160

the left-hand contact of translator control 165

sequence switch cam 613 (13 to 18), con- 170

ductor 741, and thence to ground through 175

the contacts of sequence switch cams 702 180

and 703, and the armature and contact of 185

stepping relay 719. Counting relay 764 en- 190

ergizes in this circuit closing a locking 195

circuit for itself extending through the wind- 200

ing of counting relay 765, as previously de- 205

scribed, and in the well-known manner, un- 210

der the control of stepping relay 719, the 215

counting relays energize and lock up in suc- 220

cession until the No. 0' counting relay 731 225

energizes in parallel with relay 720. Upon 230

the energization of relay 731, the previously 235

traced circuit is established for driving se- 240

quence switch 700 out of position 2 and into 245

position 4. Upon leaving position 2 the 250

locking circuits of the energized counting 255

relays are opened at sequence switch cam 260

703 and the counting relays become deener- 265

gized. Upon the energization of relay 720, 270

the fundamental circuit is opened at the ar- 275

mature and back contact of this relay and 280

as soon thereafter as the brush 532 engages 285

the next insulating portion of commutator 290

segment 530, relay 518 deenergizes opening 295

the circuit of updrive magnet 526 to arrest 300

the upward movement of the switch shaft 305

and closing at its left-hand armature and 310

back contact a circuit for driving sequence 315

switch 500 out of position 2 and into posi- 320

tion 3. This circuit may be traced from 325

grounded battery through the winding of se- 330

quence switch magnet 500, the upper right- 335

hand contact of sequence switch cam 512 (2), the left-hand armature and back contact of relay 518, and thence to ground at the upper contact of sequence switch cam 508. The fifth set of brushes has now been positioned with relation to the tripping fingers on the tripping spindle 534 so that upon a subsequent upward movement of the switch shaft this set will be tripped for engagement with the bank of 100 terminals with which this brush set is associated. With sequence switch 500 in position 3 a circuit is closed for the trip magnet 535 extending from grounded battery through the winding of magnet 535, and thence to ground at the lower right-hand contact of sequence switch cam 506 (3 to 5).

Final group of tens selection.

When sequence switch 500 reaches position 3 the energizing circuit of relay 518 is again established over the fundamental circuit, as previously described, and relay 518 and stepping relay 719 of the office sender energize in series. Relay 518, upon energizing, again closes the previously traced circuit for driving sequence switch 500 out of position 3 and into position 4. With sequence switch 500 in position 4 the previously traced circuit for the updrive magnet 526 is again established and the switch shaft is driven upwardly in its group or tens selection movement. Relay 518 also establishes the previously traced locking circuit for itself extending through its right-hand armature and front contact for maintaining itself energized over the fundamental circuit after sequence switch 500 leaves position 3 and opens the initial energizing circuit at the lower left-hand contact of sequence switch cam 503. During the initial portion of the group selection movement of the switch shaft, the fifth set of brushes is tripped by the tripping spindle 534, and during the remaining portion of the group selecting movement the tripped set of brushes travels upwardly in contact with the terminals of the bank with which the brush set is associated. As the switch shaft approaches its first group selection position the brush 538 engages the lowermost conducting portion of commutator segment 537 and a circuit is closed in shunt of the windings of the sender stepping relay 719, which may be traced from grounded battery through the left-hand contact of sequence switch cam 504, the right-hand winding of relay 518, the lower right-hand contact of sequence switch cam 510, the right-hand armature and front contact of relay 518, the right-hand contacts of sequence switch cam 503, conductor 536, commutator segment 537, brush 538, conductor 533, and thence to ground through the upper left-hand contact of sequence switch cam 506 (13 to 11). As

the switch shaft continues in its upward movement the brush 538 engages an insulating portion of segment 537 and the previously traced shunt circuit is opened. Thus, as the switch shaft continues in its upward movement the previously traced shunt circuit is intermittently established and opened, and in consequence thereof the sender stepping relay 719 is intermittently energized and deenergized.

Stepping relay 719 of the sender, when initially energized over the fundamental circuit previously traced with sequence switch 700 in position 4, closes a circuit for the No. 3 counting relay 768 over a circuit extending from grounded battery through the winding of relay 768, the armature and back contact of the No. 3' counting relay 773, lead 774, lead 974 Fig. 9, terminal 914 and wiper 915 of the tens register T, which was set in position 3 by the calling subscriber dialing digit 3, thence over conductor 916, through the upper right-hand contact of sequence switch cam 715 (4), and over the circuit previously traced to ground at the contact of sequence switch cam 703. In the manner previously described the counting relays energize in succession until the upper No. 0' counting relay 731 energizes in parallel with relay 720.

Relay 731, upon energizing, closes the previously traced circuit for driving sequence switch 700 out of position 4 and into position 6. Sequence switch 700, upon leaving position 4, opens the locking circuits of the energized counting relays and these counting relays restore to normal position. Relay 720, upon energizing, opens the fundamental circuit and as soon thereafter as brush 538 engages the next insulating portion of segment 537, relay 518 deenergizes opening the circuit of the up-drive magnet 526 and closing the circuit previously traced for driving sequence switch 500 out of position 4 and into position 5.

In position 5 the fundamental circuit is again established and relay 518 and the sender stepping relay 719 again energizes. Relay 518, upon energizing, closes the previously traced locking circuit for itself and closes the circuit for driving sequence switch 500 out of position 5 and into position 6.

Final units selection.

As soon as sequence switch 500 reaches position 6 a circuit is established for the low speed updrive magnet 539, which circuit may be traced from grounded battery through the winding of magnet 539, the lower left-hand contact of sequence switch cam 507 (6), conductor 523, the left-hand armature and front contact of relay 518, and thence to ground at the upper left-hand contact of sequence switch cam 508. The low speed up-drive magnet 539, upon ener-

gizing, presses the depending portion of switch shaft 527 against the constantly rotating low speed drum 540, thereby causing the upward movement of the switch shaft in its units selecting movement. During this upward movement of the switch shaft an intermittent circuit is established in shunt of the windings of the sender stepping relay 719, which may be traced from 10 grounded battery through the left-hand contact of sequence switch cam 504, the right-hand winding of relay 518, the lower right-hand contact of sequence switch cam 510, right-hand armature and front contact of 15 relay 518, the lower right-hand contact of sequence switch cam 503, the upper right-hand contact of sequence switch cam 502 (5 $\frac{1}{2}$ to 6), conductor 529, units selection portion of segment 530 of the commutator 531, 20 brush 532, conductor 533, and thence to ground at the upper left-hand contact of the sequence switch cam 506. In response to the intermittent establishment of the previously traced shunt circuit, the sender stepping relay 719 is intermittently energized and deenergized, the relay 518 being maintained energized over the shunt circuit.

The stepping relay 719 of the office sender, upon energizing in the fundamental 30 circuit with the sender sequence switch 700 in position 6, a circuit is established for the No. 2 counting relay 737, which circuit may be traced from grounded battery through the winding of relay 737, the armature and back contact of the No. 2' counting relay 738, lead 739, lead 917 Fig. 9, terminal 918 and brush 919 of the units register, which was set in position 2 when the calling subscriber dialed digit 2, conductor 920, the 35 upper left-hand contact of sequence switch cam 715, and thence over the circuit previously traced to ground at the contact of sequence switch cam 703. In response to the successive energizations and deenergizations 40 of relay 719, the counting relays energize in succession until the upper counting relay 731 energizes in parallel with relay 720, whereupon a circuit is closed at the armature and contact of relay 731 for driving sequence switch 700 out of position 6 and into 45 position 8. Relay 720, upon energizing, opens the fundamental circuit. As soon thereafter as the brushes of the final selector switch are positioned accurately 50 upon the terminals of the selected line and brush 532 is in engagement with an insulating portion of segment 530, relay 518 deenergizes opening the circuit of the updrive magnet 539 and closing the previously 55 traced circuit for driving the sequence switch 500 out of position 6 and into position 9.

Testing the called line.

65 The brushes of the final selector switch

550 have now been positioned upon the terminals of the desired line and sequence switch 500, upon reaching position 9, closes a circuit for reenergizing relay 518, which may be traced from grounded battery 70 through the left-hand contact of sequence switch cam 504 (1 to 10), the right-hand winding of relay 518, the lower right-hand and upper left-hand contacts of sequence switch cam 510, and thence to ground at the 75 right-hand armature and front contact of relay 521. Relay 518, upon energizing, closes a locking circuit for itself extending from grounded battery through its right-hand winding, the lower right-hand contact of sequence switch cam 510, the right-hand armature and front contact of relay 518, and thence to ground through the upper contacts 80 of sequence switch cam 513. This locking circuit will be maintained through position 85 10 of sequence switch 500. Relay 518, upon energizing, also closes a circuit as previously traced for driving sequence switch 500 out of position 9 and into position 12. Upon reaching position 10 a new holding circuit 90 is established for relay 518 extending from grounded battery through the left-hand winding of this relay, the lower right-hand contact of sequence switch cam 515 (10 to 95 11), the left-hand armature and front contact of relay 518, and thence to ground at the upper left-hand contact of sequence switch cam 508. Upon reaching position 11 sequence switch 500 establishes a new holding 100 circuit for relay 518 extending from ground through the winding of test relay 524, conductor 541, the upper left-hand contact of sequence switch cam 502, the lower left-hand contact of sequence switch cam 503 (11 to 105 13), the right-hand winding of relay 518, the upper right-hand contact of sequence switch cam 510 (11 to 12 $\frac{1}{2}$), the right-hand armature and front contact of relay 518, the right-hand contacts of sequence switch cam 513, test brush 542, and thence to battery on 110 the test terminal of the called line if the called line is busy. If the called line is busy as a calling line this battery potential will be connected to test terminal 543, as previously described, in connection with the 115 trunk hunting switch 100 through the off normal contact of the trunk hunting switch, and if the called line is busy as a called line battery potential will be connected to the terminal 543 from grounded battery through 120 the upper right-hand contact of a sequence switch cam corresponding to cam 504 of the final selector switch, which is in engagement with the terminals of the called line, the lower contacts of the cam corresponding to 125 cam 513 and the test brush of such final selector switch.

Called line a direct line and busy.

If the called line is a direct line and busy, 130

- relay 518 remains energized when sequence switch 500 reaches position 12 and relay 524 also energizes in the locking circuit previously traced through the right-hand winding of relay 518. The energization of relay 524 opens the previously traced holding circuit of relay 521, which relay thereupon de-energizes closing a circuit extending from grounded battery through the magnet winding of sequence switch 500, the lower right hand and upper left-hand contacts of sequence switch cam 509, and the right-hand armature and back contact of relay 521, for driving sequence switch 500 into position 13.
- When sequence switch 500 leaves position 12½ the testing circuit traced through relays 524 and 518 is opened but relay 518 remains locked over a circuit extending through its left-hand winding, the lower right-hand contact of cam 515 (12¾ to 14), the left-hand armature and front contact of relay 518, and to ground at the upper contact of cam 508 (12¾ to 16). When sequence switch 500 reaches position 13, relay 521 is again energized over a circuit extending from grounded battery through its left-hand winding, conductor 522, and thence to ground through the upper right-hand contact of sequence switch cam 506 (13), and upon energizing locks itself to conductor 525 through the back contact and armature of test relay 524, and closes a circuit for driving sequence switch 500 out of position 13 and into position 14. This circuit may be traced from grounded battery through the magnet winding of switch 500, the lower contacts of sequence switch cam 509, and thence to ground at the right-hand armature and front contact of relay 521. When sequence switch 500 reaches position 14 a circuit is established for the downdrive magnet 544, which may be traced from grounded battery through the winding of magnet 544, the lower right-hand contact of sequence switch cam 511 (14), conductor 523, the left-hand armature and front contact of relay 518, and thence to ground through the upper left-hand contact of sequence switch cam 508.
- Upon the energization of downdrive magnet 544, the depending portion of switch shaft 527 is pressed against the constantly rotating downdrive drum 545, thereby causing the downward movement of switch shaft 527 into normal position. When the switch shaft reaches normal position a circuit is established for driving the sequence switch 500 out of position 14 and into position 17, this circuit extending from grounded battery through the magnet winding of sequence switch 500, the upper right-hand contact of sequence switch cam 512 (3 to 16), conductor 546, normal segment 547 of commutator 531, brush 538, conductor 533, and thence to ground through the upper left-hand contact of sequence switch cam 506. Upon leaving position 14 the locking circuit of relay 518 is opened but in position 17 a circuit is closed which extends from grounded battery through the left-hand winding of relay 518, and thence to ground through the upper left-hand contact of sequence switch cam 515 (17) and through interrupter 548, whereby relay 518 is intermittently energized. Upon the intermittent energization of relay 518 a circuit is established for transmitting a busy tone back to the calling subscriber, which may be traced from the source of tone current 549, the lower right-hand contact of sequence switch cam 508 (17), the left-hand armature and front contact of relay 518, conductor 523, the left-hand contact of sequence switch cam 511 (17), resistance element 520, the lower right-hand and upper left-hand contacts of sequence switch cam 505, trunk conductor 519, bank terminal 449 and brush 448 of the incoming selector switch, the upper contact of sequence switch cam 414, and thence to battery and ground through the lower right-hand winding of repeating coil 458, the sequence switch of the incoming selector switch having at this time advanced into the talking position in a manner to be described hereinafter. The tone current flowing in this circuit is inductively transmitted over the inter office trunk to the right-hand winding of repeating coil 265 at the district selector switch, and from thence to the calling subscriber's line over the conductors shown in heavy lines, the district selector sequence switch having been advanced in a manner hereinafter described into the talking selection position following the completion of the units selection movement of the final selector switch. The calling subscriber receiving this busy tone restores his receiver to the switch hook, thereby causing the restoration of the central station apparatus in the manner to be described hereinafter.
- Called line a direct line and idle.*
- If in testing the called line is found to be idle, ground potential will be encountered on the test terminal 543, this ground potential being supplied through a wiper of the called subscriber's trunk finding switch corresponding to wiper 110, shown in Fig. 1, and the windings of the called subscriber's cut-off relay corresponding to relay 102. Therefore, when the test circuit through the test brush 542 is established to this idle line, the circuit previously traced through the winding of relay 518 and the winding of relay 524 will extend from ground, and relay 518 will therefore become deenergized as soon as sequence switch 500 leaves position 11, and relay 524 will therefore not energize. When therefore relay 518 deenergizes it closes a circuit for driving sequence

switch 500 out of position 12 and into position 13, this circuit extending from grounded battery through the upper right-hand contact of sequence switch cam 512, the left-hand armature and back contact of relay 518, the lower left-hand contact of sequence switch cam 508, and thence to ground at the right-hand armature and front contact of relay 521. Upon reaching position 13 a circuit is established over the lower contacts of sequence switch cam 509 and the right-hand armature and front contact of relay 521 for driving sequence switch 500 out of position 13 and into position 14, and in position 14 a circuit is established, as previously traced, through the winding of sequence switch magnet 500, the right-hand armature and back contact of relay 518, and thence to ground at the upper contact of sequence switch cam 508 for driving the sequence switch into the talking position 15, in which position the trunk conductors 517 and 519 are connected respectively to the brushes 552 and 553 over the lower contacts of sequence switch cam 502 and the upper contacts of sequence switch cam 505. The testing of a line in a P. B. X. group will not be described herein, this testing feature of the final selector switch is fully described in the patent to F. A. Stearn and F. J. Scudder, No. 1,395,977, dated November 1, 1921.

Talking selection.

Following the test of the called line, assuming that the called line is found to be idle, sequence switch 500 moves into the talking position 15. Upon leaving position 8½, when the sequence switch moved into position 9 preparatory to testing the called line, the circuit previously traced extending through the winding of relay 421 of the incoming selector switch was opened. Relay 421, upon deenergizing, closes a circuit for driving sequence switch 400 out of position 8 and into position 9, this circuit extending from grounded battery through the winding of the magnet of sequence switch 400, the upper left-hand contact of sequence switch cam 406 (8), and thence to ground at the inner left-hand armature and back contact of relay 421. With sequence switch 400 in position 9, relay 421 is again connected to the fundamental circuit extending through the windings of sender stepping relay 719 and the windings of overflow relay 734, but at this time the winding of relay 421 is connected to the ring conductor of the fundamental circuit rather than to the tip conductor, as herebefore described, so that current flowing in the fundamental circuit now flows in a direction reverse to the direction in which it originally flowed, and, consequently, polarized overflow relay 734 at the office sender energizes in series with relays

719 and 421. The connection of relay 421 to the ring conductor 420 of the fundamental circuit may be traced from grounded battery through the right-hand winding of relay 421, the lower contacts of sequence switch cam 415 (9), resistance element 425, and the lower contact of sequence switch cam 404 (1 to 10). The tip conductor 419 of the fundamental circuit is connected to ground at the incoming selector over a circuit which may be traced from conductor 419 through the upper contact of sequence switch cam 403 (1 to 10), resistance element 424, the left-hand contacts of sequence switch cam 408 (9), and thence to ground through the upper contacts of sequence switch cam 412.

Following the completion of units selection, the sequence switch 700 of the sender moves from position 8 to position 14, since at this time counting relay 731 is locked up to maintain the driving circuit of the magnet of sequence switch 700 until the sequence switch reaches position 14. The locking circuit of relay 731 may be traced from grounded battery through the windings of relays 730 and 731, the armature and front contact of relay 730, conductor 742, the upper left-hand and lower right-hand contacts of sequence switch cam 712 (6 to 12), contacts of class switch cam 756 (4), conductor 775, and thence to ground through the upper right-hand contact of sequence switch cam 619.

When sequence switch 700 reaches position 14 the locking circuit for relay 731 is opened and a circuit is established for relay 749, which may be traced from grounded battery through the winding of relay 749, and thence to ground through the contacts of sequence switch cam 710 (14). Relay 749, upon energizing, closes a circuit for driving the translator control sequence switch 600 out of position 13 and into position 14, which circuit may be traced from grounded battery through the magnet winding of sequence switch 600, the lower contact of sequence switch cam 616 (13), the upper left-hand contact of sequence switch cam 616, conductor 764, the armature and contact of relay 749, and thence to ground through the contacts of class switch cam 754 (4). A circuit is also established at this time for driving the sender sequence switch 700 into position 16, this circuit extending from grounded battery through the magnet winding of switch 700, conductor 763, the upper contacts of sequence switch cam 616, and thence to ground at class switch cam 754 over the circuit previously traced.

With sequence switch 400 of the incoming selector 450 in position 9 and the sequence switch 700 of the office sender in position 16, the line relay 421 of the incoming selector, stepping relay 719 and the polarized overflow relay 734 of the office sender be-

come energized. Relay 734, upon energizing, closes a circuit for relay 776, which may be traced from grounded battery through the left-hand winding of this relay, the contact of sequence switch cam 716 (16), and thence to ground through the armature and front contact of relay 734. Relay 776, upon energizing, closes a locking circuit for itself extending from grounded battery through 5 its right-hand winding, its right-hand armature front contact, and thence to ground at the upper left-hand contact of translator control sequence switch cam 606 (13 to 18). A circuit is now closed for the No. 0 counting relay 730, which may be traced from grounded battery through the winding of 10 relay 730, the contact of sequence switch cam 709 (11 to 18), lead 745, the lower left-hand contact of sequence switch cam 715 (16), conductor 771, class switch cam 755 (4), conductor 772, the left-hand contact of sequence switch cam 613 (13 to 18), conductor 741, the lower left-hand and upper right-hand contacts of sequence switch cam 702, the 15 armature and contact of relay 719, and thence to ground at the lower left-hand contact of sequence switch cam 703. Relay 730, upon energizing, closes a locking circuit for itself extending through the winding of the 20 No. 0' counting relay 731 in the manner hereinbefore described.

At its left-hand armature and front contact, relay 776 closes a circuit for advance relays 648 and 658, which circuit may be 25 traced from grounded battery through the windings of these relays in parallel, conductor 662, the left-hand armature and front contact of relay 776, and thence to ground at the armature and front contact 30 of counting relay 731. Relay 776 also closes a circuit for advancing sequence switch 700 into position 17, which circuit may be traced from grounded battery through the magnet winding of sequence 35 switch 700, the upper right-hand contact of sequence switch cam 704 (16), the left-hand armature and front contact of relay 776, and thence to ground at the armature and contact of relay 731. As soon as 40 sequence switch 700 leaves position 17, the locking circuit of counting relays 730 and 731 is opened at sequence switch cam 703.

When sequence switch 700 reaches position 55 45 the sender stepping relay 719 becomes energized in a circuit which may be traced from grounded battery through the winding of relay 749, the right-hand contacts of sequence switch cam 717, the left-hand winding of relay 734, conductor 735, the windings of sender stepping relay 719, the armature and back contact of relay 720, the left-hand contacts of sequence switch 60 cam 706, and thence to ground through resistance element 722. Relay 719, upon energizing, closes a circuit for advancing se-

quence switch 700 out of position 17 and into position 18, this circuit extending from grounded battery through the winding of the magnet of sequence switch 700 conductor 732, the lower right-hand and upper 70 left-hand contact of sequence switch cam 702, the contacts of relay 719, and thence to ground through the lower right-hand contact of sequence switch cam 703. The energization of advance relay 658 closes a 75 circuit for locking both relays 648 and 658 independently of the circuit previously traced over conductor 662. The locking circuit may be traced from grounded battery through the windings of relays 648 and 658 in parallel, the right-hand armature and front contact of relays 658, and thence to ground at wiper 635 of the time measure switch TM. The energization of advance 80 relay 648 opens the shunt which normally exists around the left-hand winding of relay 663, whereupon the left-hand winding of this relay is connected into the circuit previously traced through the winding of relay 261 at the district selector switch. Relay 261 does not now receive sufficient current over this circuit to maintain its energization, and it thereupon deenergizes 85 opening the circuit of relay 228, which thereupon deenergizes and advances sequence switch 200 out of position 10 and into position 11. The energization of relay 648 also opens the circuit of relay 663 which has, during the setting up of the connection, been held energized over a circuit 90 extending from battery through its right-hand winding, the right-hand armature and back contact of relay 648, and to ground at sequence switch cam 614, and this relay upon deenergizing opens the circuit of relay 644 which establishes a new fundamental circuit extending through the windings 95 of relays 228 and 719. This circuit may be traced from battery through the left-hand winding of relay 228, the lower left-hand contact of sequence switch cam 210 (11), the upper left-hand contact of sequence switch cam 210 (11 to 14), conductor 262, the outer right-hand armature and front contact of relay 230, wiper 237 of 100 switch SF, conductor 645, the armature and back contact of relay 647, the right-hand contact of sequence switch cam 611 (13 to 18), the upper contacts of sequence switch cam 717, the left-hand winding of relay 734, conductor 735, the winding of sender stepping relay 719, the armature and back contact of relay 720, conductor 721, the outer 105 right-hand armature and back contact of relay 644, conductor 651, and thence to 110 ground through the resistance element 722. Relay 228, upon energizing, closes a circuit, as previously traced, for driving sequence switch 200 out of position 11 and into position 15 unless this circuit is interrupted 115 120 125 130

at the armature contacts of relay 228 prior to the sequence switch reaching position 15. As soon as sequence switch 200 leaves position 11, relays 230 and 244 are maintained energized over a circuit which may be traced from grounded battery through the winding of stepping magnet 229, of switch SF, the windings of relays 230 and 244 in parallel, the lower contact of sequence switch cam 214 (11 to 14), the right-hand armature and front contact of relay 244, the upper right-hand contact of sequence switch cam 215 (11 to 14), the outer right-hand armature and front contact of relay 228, and thence to ground through the lower contacts of sequence switch cam 216.

During the rotation of sequence switch 200 from position 11 and into position 15, an intermittent ground is connected to the circuit extending through the windings of relays 719 and 228 between the windings of these two relays in such a manner as to hold the relay 228 energized and to shunt out relay 719. This shunt circuit may be traced from grounded battery through the left-hand winding, left-hand armature and front contact of relay 228, and thence to ground through the left-hand contacts of sequence switch cam 216, and is closed in positions 11 $\frac{1}{2}$, 12 $\frac{1}{2}$ and 13 $\frac{1}{2}$.

With the sender sequence switch 700 in position 18 and sender relay 719 energized, a circuit is closed for the No. 0 counting relay 730, it being assumed that the talking selection relays have been so set by the code letters dialed by the calling subscriber as to energize talking selection register relay 1017. The circuit of relay 730 may be traced from grounded battery through the winding of relay 730, the contact of sequence switch cam 709 (11 to 18), lead 745 Fig. 7, lead 1031 Fig. 10, the inner left-hand armature and front contact of talking selection register relay 1017, the right-hand armature and back contact of talking selection register relay 1032, conductor 1033, the inner right-hand armature and back contact of relay 1305, conductor 1312, the lower left-hand and upper right-hand contacts of sequence switch cam 718 (18), and thence to ground through the armature and contacts of stepping relay 719 and the contacts of sequence switch cam 703, as previously traced. Relay 730 energizes in this circuit and closes a locking circuit for itself extending through its winding, the winding of the upper No. 0' counting relay 731, the armature and front contact of relay 730, conductor 727, conductor 742, and thence to ground through the upper contact of sequence switch cam 703. Upon the first deenergization of relay 719, when the sequence switch 200 is passing through position 11 $\frac{1}{2}$, counting relay 731 energizes in parallel with relay 720. Relay 720, upon energizing, opens

the circuit previously traced extending through the windings of relays 719 and 228, and relay 228, upon deenergizing, opens the previously traced circuit extending through the winding of sequence switch magnet 200 70 for arresting sequence switch 200 in position 12.

Relay 731, upon energizing, closes a circuit for driving the translator control sequence switch 600 out of position 14 and 75 into position 15, this circuit extending from grounded battery through the magnet winding of sequence switch 600, the lower right-hand contact of sequence switch cam 607 (14), conductor 661, the right-hand contacts of sequence switch cam 714 (18), and thence to ground at the armature and front contact of relay 731. Sequence switch 600, upon reaching position 15, closes a circuit for advancing the sender sequence switch 700 out of position 18 and into normal position 1. This circuit may be traced from grounded battery through the winding of sequence switch magnet 700, the lower left-hand contact of sequence switch cam 704 (18), the contact of route switch cam 1320 and thence to ground through the lower right-hand contact of sequence switch cam 606 (15 to 1). Sequence switch 700 upon moving out of position 18 opens the locking circuit of counting relays 730 and 731 and these relays thereupon deenergize.

Ringing the called substation.

At the time the fundamental circuit was 100 established through the winding of relay 421 at the incoming selector switch and the windings of relays 719 and 734 at the office 105 sender for advancing the district selector sequence switch out of position 10, relay 421 energized and as sequence switch 400 of the incoming selector switch was at the time in position 9 a circuit was established for 110 energizing relay 451, which circuit may be traced from grounded battery through the winding of relay 451, the right-hand contact of sequence switch cam 416 (9 to 10), the right-hand armature and front contact of relay 421, conductor 429, and thence to ground through the upper contacts of sequence switch cam 412. Relay 451, upon energizing, closes a circuit for driving sequence switch 400 out of position 9 and into position 10, this circuit extending from 115 grounded battery through the winding of the magnet of sequence switch 400, the armature and front contact of relay 451, and thence to ground through the left-hand contacts of sequence switch cam 412. Upon leaving position 9 the fundamental circuit 120 previously traced through the winding of relay 421 is opened and relay 421 deenergizes opening the circuit of relay 451 to arrest the sequence switch 400 in position 10.

As soon as sequence switch 400 reaches 130

position 10, if at this time the sequence switch 200 of the district selector is advanced to the selected talking position, a circuit is established for relay 421 extending through the right-hand winding of this relay, the upper contacts of sequence switch cam 402 (10), conductor 423, resistance element 424, the upper contact of sequence switch cam 403 (1 to 10), trunk conductor 419, bank terminal 336 and brush 334 of the office selector switch, the contact of sequence switch cam 310 (8), trunk conductor 313, bank terminal 257 and brush 259 of the district selector switch, the left-hand contacts of sequence switch cam 220, the upper right-hand winding of repeating coil 265, the lower contacts of sequence switch cam 221, the winding of polarized relay 266, the upper left-hand contact of sequence switch cam 222, the lower right-hand winding of repeating coil 265, the upper contacts of sequence switch cam 219, brush 258 and bank terminal 256 of the district selector switch, trunk conductor 314, the contact of sequence switch cam 311 (8), brush 335 and bank terminal 337 of the office selector switch, trunk conductor 420, the lower contact of sequence switch cam 404 (1 to 10), resistance element 425, conductor 426, and thence through the lower contact of sequence switch cam 405 (10) to ground. Relay 421, upon energizing, locks to ground on sleeve conductor 464 over a circuit extending from grounded battery through its left-hand winding, the armature and back contact of relay 455, the upper left-hand contact of cam 409, conductor 431 the outer left-hand armature and front contact of relay 421, conductor 427, and thence to conductor 465 through the upper contact of cam 407. The current flowing through the winding of polarized relay 266 at the district selector switch is not in the proper direction to effectively energize this relay at this time.

Relay 421, upon energizing, again establishes the previously traced circuit for relay 451, which relay, upon energizing, establishes a circuit for driving sequence switch 400 into position 11. As soon as sequence switch 400 leaves position 10, relay 451 deenergizes but when relay 400 reaches position 11, relay 451 reenergizes over a circuit which may be traced from grounded battery through its winding, the upper left-hand contact of sequence switch cam 416 (11), and the upper contact 452 of interrupter cam 453 as soon as the cam 453 has advanced to such a position as to close the upper contact 452. A circuit is also established in position 11 of sequence switch 400 for applying a steady flow of ringing current to the line of the called subscriber. The circuit over which ringing current is transmitted may be traced from the source of ringing current 454 through the lower

left-hand and upper right-hand contacts of sequence switch cam 417 (11 to 12), through the winding of ringing cut-off relay 455, the lower contacts of sequence switch cam 402 (11 to 13), conductor 428, the right-hand armature and front contact of relay 421, conductor 429, the lower right-hand contact of sequence switch cam 414, brush 448 and terminal 449 of the incoming selector switch, trunk conductor 519, the upper contacts of sequence switch cam 505, brush 553 and terminal 557 of the final selector switch, and thence over the called subscriber's line loop through the called subscriber's bell 558, and back over terminal 559 and brush 552 of the final selector switch, the lower contacts of sequence switch cam 502, trunk conductor 517, bank terminal 447 and brush 446 of the incoming selector switch, and thence to ground at the upper right-hand contact of sequence switch cam 413. As soon as relay 451 energizes in position 11 of sequence switch 400, the circuit previously traced through the outer armature and front contact of relay 451 is again established for driving sequence switch 400 out of position 11 and into position 12. Upon leaving position 11 relay 451 deenergizes but is again energized as soon after sequence switch 400 reaches position 12 as the cam 453 advances to such a position as to engage cam spring 452 with its lower contact, the circuit of relay 451 then being established over the lower contact of cam spring 452 and the lower contact of sequence switch cam 416 (12). Relay 451, upon energizing, drives sequence switch 400 out of position 12 and into position 13. In position 13 the source of ringing current 454 is connected to the circuit previously traced through the interrupter 456 and the right-hand contacts of sequence switch cam 417, and the called subscriber's bell 558 is operated intermittently until the called subscriber responds. During the intermittent application of ringing current a ringing tone is transmitted back to the calling subscriber through the lower left-hand contact of sequence switch cam 414, condenser 457, and the lower right-hand and upper left-hand contacts of sequence switch cam 418.

Response of the called subscriber.

In response to the ringing of bell 558 the called subscriber removes his receiver from its switch hook, thereby cutting the bell 558 from the line loop and connecting a direct current bridge across the line loop at the substation through the transmitter. Current flowing over the subscriber's line loop from the source 454 now causes the operation of marginal ringing cut-off relay 455, which, upon energizing, opens, at its armature and back contact, the locking circuit previously traced extending through

the left-hand winding of relay 421. Relay 421 thereupon deenergizes and opens the circuit over which ringing current has been applied to the called line at its right-hand 5 armature and front contact, and at its inner left-hand armature and back contact closes a circuit extending through the upper left-hand contact of sequence switch cam 406 for driving sequence switch 400 out of 10 position 13 and into the talking position 16. When sequence switch 400 passes through position 14, relay 421 again energizes over a circuit extending from grounded battery through its left-hand winding and the right-hand contacts of sequence switch cam 411, and closes a locking circuit for itself extending through its left-hand winding, the armature and back contact of ringing cut-off relay 455, which relay becomes deenergized as soon as sequence switch 400 leaves 15 position 13, the upper left-hand contact of sequence switch cam 409, conductor 431, the upper left-hand armature and front contact of relay 421, conductor 427, the upper contact of sequence switch cam 407, and thence over the sleeve conductor of the trunk, and to ground connected as previously described to this conductor.

As soon as sequence switch 400 leaves 20 position 14 a direct current path is established through the right-hand winding of repeating coil 458, and thence over the called subscriber's line loop for supplying the called subscriber with talking current. This 25 path may be traced from the non-grounded pole of battery through the lower right-hand winding of repeating coil 458, the winding of supervisory relay 459, the upper left-hand contact of sequence switch cam 414, thence over the circuit previously 30 traced, through the called subscriber's substation loop, and returning through the lower contact of sequence switch cam 413 and upper right-hand winding of repeating coil 458 to the grounded pole of battery. Supervisory relay 459 energizes in this 35 circuit and connects the terminals of central station battery between the left-hand windings of repeating coil 458 in such a manner as to cause current to flow over the trunk line extending through the incoming selector switch, through the office selector switch to the district selector switch, in such 40 a direction as to effectively energize the polarized supervisory relay 266 at the district selector switch. This circuit may be traced from the non-grounded pole of central office battery, over conductor 460, the upper left-hand contact of sequence switch cam 405 (11 to 16), conductor 426, resistance element 425, the upper contacts of sequence switch cam 415 (11 to 16), the lower left-hand winding of repeating coil 458, the upper contact of sequence switch cam 404 (11 to 16), trunk conductor 461, bank terminal 337 and brush 335 of the office selector switch, the contact of sequence switch cam 311 (8), trunk conductor 314, bank terminal 256 and brush 258 of the district selector switch, the upper contacts of sequence switch cam 219, the lower right-hand winding of repeating coil 265, the upper contact of sequence switch cam 222, the winding of polarized relay 266, the lower right-hand and upper 55 left-hand contacts of sequence switch cam 221, the upper right-hand winding of repeating coil 265, the left-hand contacts of sequence switch cam 220, brush 259 and bank terminal 257 of the district selector switch, trunk conductor 313, the contact of sequence switch cam 310, brush 334 and bank terminal 336 of the office selector switch, trunk conductor 419, the lower contact of sequence switch cam 403 (11 to 16), the upper left-hand winding of repeating coil 458, resistance element 424, and thence through the armature and front contact of relay 459 to ground.

Relay 266, upon energizing in the previously traced circuit, closes a circuit for relay 267 as soon as cam 268 has rotated to such a position as to close cam spring 269. This circuit may be traced from grounded battery through the contact of cam spring 269, the winding of relay 267, the left-hand contacts of sequence switch cam 217, the contact of polarized relay 266, and thence to ground at the right-hand contact of sequence switch cam 209. Relay 267, upon energizing, closes a locking circuit for itself from grounded battery through its right-hand armature and front contact, and thence to ground over the circuit previously traced independently of cam spring contact 269. As soon as cam 268 rotates to such a position as to open the spring contact 269 and close spring contact 270, a circuit is established for relay 261, which may be traced from grounded battery through the winding of relay 261, the left-hand armature and front contact of relay 267, and thence to ground at spring contact 270. Relay 261, upon energizing, closes a locking circuit for itself independent of cam spring 270, which may be traced from grounded battery through the winding of relay 261, the left-hand contact of sequence switch cam 218 (12 to 18), and thence to ground through the right-hand armature and front contact of relay 261. At its left-hand armature and front contact relay 261 prepares a call charging circuit which is effective to charge a call against the calling subscriber following the termination of the conversation, and the advancement of sequence switch 200 into position 17. With sequence switch 200 in position 12 for talking, talking current is supplied to the calling subscriber over a circuit which may be traced 125

from the non-grounded pole of central office battery through the lower left-hand winding of repeating coil 265, the upper right-hand contact of sequence switch cam 213, the winding of supervisory relay 234, conductor 116, wiper 111, the innermost lower armature and front contact of relay 102, conductor 103, thence over the subscriber's line loop, conductor 104, the upper armature and front contact of relay 102, wiper 113, conductor 117, the lower right-hand contact of sequence switch cam 212, and thence to the grounded pole of battery through the upper left-hand winding of repeating coil 265. Relay 234 energizes in this circuit and at its armature and front contact closes a locking circuit to maintain relay 227 energized, which may be traced from grounded battery through the left-hand winding of relay 227, the armature and front contact of relay 234, and thence to ground at the right-hand armature and front contact of relay 227. The calling and called subscribers are now connected over a talking circuit shown in the drawings by the heavy conductors, the calling subscriber receiving talking current over the circuit previously traced through the left-hand windings of repeating coil 265, and the called subscriber receiving talking current through the right-hand windings of repeating coil 458.

Restoration of the office sender.

It will be recalled that following the completion of the dialing of the seven digits designating the number of the called line, the register steering switch RS advanced its wipers into contact with the No. 7 terminals of the banks to which the wipers have access. Since the calling subscriber has caused the setting of the class switch into position 4 for a full mechanical connection, then as soon as the translator control sequence switch reaches position 9 in which position the sender first functions to set the district selector switch, with the time measure switch TM in position 16, a circuit is established for advancing the register steering switch out of position 7 and into position 8. This circuit may be traced from grounded battery through the winding of stepping magnet 817, wiper 844, the No. 7 terminal 845 with which the wiper 844 is in engagement, conductor 846, the contact of class switch cam 757 (13 to 11), the upper right-hand and lower left-hand contacts of translator control sequence switch cam 620 (9 to 13) to ground through the No. 16 terminal 664 and wiper 632 of the time measure switch TM. Upon reaching position 8 a similar circuit is established for advancing the register steering switch into position 9, which circuit may be traced through the winding of stepping magnet 817, wiper 844, the No. 8 terminal 855, con-

ductor 778, and thence to ground at the right-hand contact of class switch cam 758 (13 to 11). Upon reaching position 9 the register steering switch is advanced into position 10 by a circuit extending through the winding of magnet 817, wiper 844, terminal 856, conductor 779, and thence to ground at the left-hand contact of class switch cam 758 (13 to 11).

Upon reaching position 10 a circuit is established over wiper 804 of the steering switch and bank terminal 857 for advancing the monitoring time measure switch M out of position 7, through the energization of relay 1210. The circuit for relay 1210 may be traced from grounded battery through the right-hand winding of relay 1210, wiper 1217, the No. 7 terminal of the bank with which this wiper is in engagement, conductor 1228, bank terminal 857, wiper 804, and thence to ground at the right-hand armature and front contact of relay 802. Upon the energization of relay 1210, a circuit is established for stepping magnet 1218, which may be traced from grounded battery through the winding of magnet 1218, the armature and contact of magnet 1218, the right-hand armature and front contact of relay 1210, and thence to ground at the right-hand armature and front contact of relay 802 over the circuit previously traced. Magnet 1218 advances the wipers of switch M until wiper 1217 leaves the No. 8 terminal of its bank when relay 1210 deenergizes and opens the circuit of magnet 1218. A new stepping circuit for switch M is now established from grounded battery through the winding of magnet 1218, the right-hand armature and back contact of relay 1210, the slow interrupter 1219, the inner left-hand armature and back contact of relay 1220, the No. 9 terminal of the bank with which wiper 1277 is in engagement, wiper 1277, the inner left-hand armature and back contact of relay 1210, and thence to ground at the intermediate right-hand armature and front contact of relay 1205. Under the influence of interrupter 1219, switch M is advanced into position 11.

As the wipers of switch M pass through positions 9 and 10, a circuit is established for relay 1200, which may be traced from battery on conductor 1211 through the winding of relay 1229, the winding of relay 1200, the outer left-hand armature and front contact of relay 1216, the Nos. 9 and 10 terminals of the bank with which wiper 1223 engages, wiper 1223, the outer right-hand armature and back contact of relay 1210, and thence to ground at the intermediate right-hand armature and front contact of relay 1205. Relay 1200, upon energizing in this circuit, closes a locking circuit for itself independent of wiper 1223, which may be traced from battery on conductor 1211,

through the winding of relay 1229, winding of relay 1200, the inner right-hand armature and front contact of relay 1200, conductor 1230, the contacts of sequence switch cam 621, sequence switch 600 not having advanced out of position 13 at the time the subscriber finishes dialing, thence to ground at the armature and front contact of relay 626.

- 10 At the back contacts of its outer right-hand and outer left-hand armatures, relay 1200 opens the circuit previously traced extending from the subscriber's line through the windings of register stepping relay 800 and balancing coil 638, and connects the subscriber's line with the windings of marginal differential relays 1214 and 1231. The disconnection of the winding of relay 800 from the subscriber's line loop does not cause 15 the release of relay 800 since this relay is maintained energized over a locking circuit, which may be traced from grounded battery through the winding of relay 800, conductor 801, the inner left-hand armature and front contact of relay 1200, conductor 1232, and thence to ground at the right-hand armature and front contact of relay 302. The energizing circuit for relays 1214 and 1231 may now be traced from the source 20 1260 of negative current through the left-hand armature and front contact of relay 1229, the inner right-hand armature and back contact of relay 1212, the outer right-hand armature and back contact of relay 1215, the left-hand windings of relays 1214 and 1231, wiper 1206, the outer right-hand armature and front contact of relay 1200, the 25 outer right-hand armature and back contact of relay 1201, conductor 1202, the inner left-hand armature and front contact of relay 630, conductor 636, wiper 232, the outer left-hand armature and front contact of relay 230, conductor 233, the lower left-hand contact of sequence switch cam 212, conductor 117, wiper 113, the upper armature and front contact of relay 102, the winding of coin collection magnet 126, and thence to ground through the contacts 127 which were 30 operated upon the deposit of the coin. Relay 1214 energizes in series with the winding of magnet 126, but relay 1231, being marginally wound, does not energize and polarized magnet 126 does not receive sufficient current through the windings of relays 1214 and 1231 to energize at this time. Relay 1214, upon energizing, opens the previously traced locking circuit of relay 1209 at the armature and back contact of relay 1214, and relay 1209, upon deenergizing, 35 opens the circuit of relay 1216, which in turn opens the circuit of relay 647, so that when the sender sequence switch 700 reaches position 6, preparatory to controlling units selection, relay 647 will not become energized to hold the fundamental circuit open at its armature and contact. If the calling subscriber had not deposited the coin then relay 1214 would not have energized as previously 40 described, and when sequence switch 700 of the sender reached position 5 a circuit would have been established for relay 647 which may be traced from grounded battery through the contact of sequence switch cam 781, conductor 782, the left-hand contacts of translator control sequence switch cam 617, which advanced to position 13 following the setting of the incoming selector switch, thence through the winding of relay 647, 45 conductor 665, and thence to ground at the right-hand armature and front contact of relay 1216.

- 50 It has been assumed in tracing the establishment of the connection to the called subscriber's line L, that the calling subscriber deposited the required coin or token either before dialing the number or immediately following the dialing of the number, and that therefore at the time dialing was completed and the monitoring time measure switch M reached position 9, an effective 55 energizing circuit for relay 1214 is estab-

lished which may be traced from the source 1260 of negative current through the left-hand armature and front contact of relay 1229, the inner right-hand armature and back contact of relay 1212, the outer right-hand armature and back contact of relay 1215, the left-hand windings of relays 1214 and 1231, wiper 1206, the outer right-hand armature and front contact of relay 1200, the outer right-hand armature and back contact 70 of relay 1201, conductor 1202, the inner left-hand armature and front contact of relay 630, conductor 636, wiper 232, the outer left-hand armature and front contact of relay 230, conductor 233, the lower left-hand contact of sequence switch cam 212, conductor 117, wiper 113, the upper armature and front contact of relay 102, the winding of coin collection magnet 126, and thence to ground through the contacts 127 which were 75 operated upon the deposit of the coin. Relay 1214 energizes in series with the winding of magnet 126, but relay 1231, being marginally wound, does not energize and polarized magnet 126 does not receive sufficient current through the windings of relays 1214 and 1231 to energize at this time. Relay 1214, upon energizing, opens the previously traced locking circuit of relay 1209 at the armature and back contact of relay 1214, and relay 1209, upon deenergizing, 80 opens the circuit of relay 1216, which in turn opens the circuit of relay 647, so that when the sender sequence switch 700 reaches position 6, preparatory to controlling units selection, relay 647 will not become energized to hold the fundamental circuit open at its armature and contact. If the calling subscriber had not deposited the coin then relay 1214 would not have energized as previously 85 described, and when sequence switch 700 of the sender reached position 5 a circuit would have been established for relay 647 which may be traced from grounded battery through the contact of sequence switch cam 781, conductor 782, the left-hand contacts of translator control sequence switch cam 617, which advanced to position 13 following the setting of the incoming selector switch, thence through the winding of relay 647, 90 conductor 665, and thence to ground at the right-hand armature and front contact of relay 1216.

95 If the calling subscriber has not deposited the coin at the time the time measure switch M reaches position 11, the coin lamp 1234 is caused to flicker over a circuit which may be traced from grounded battery through the lamp 1234, the outer left-hand armature and back contact of relay 1212, the inner left-hand armature and front contact of relay 1216, interrupter 1235, the normally closed contacts associated with the inner right-hand armature of relay 1215, bank terminal 1236, wiper 1223, the outer left- 100

hand armature and back contact of relay 1210, and thence to ground at the intermediate right-hand armature and front contact of relay 1205. The flickering of lamp 1234 signals the monitoring operator that either the calling subscriber has deposited no coin or that the coin has stuck in the coin chute and the monitoring operator may then take such steps as are necessary to obtain the deposit of the coin or the clearing of the trouble at the calling subscriber's substation. During the operation of coin lamp 1234 the pilot lamp 1224 is operated over a circuit which may be traced through lamp 1224, bank terminal 1237, wiper 1277, the inner left-hand armature and back contact of relay 1210, and thence to ground at the intermediate right-hand armature and front contact of relay 1205.

If when the time measure switch M reaches position 9 the calling subscriber has properly deposited the coin and consequently the circuits of relays 1209 and 1216 are opened by the energization of relay 1214, a circuit is closed for advancing the time measure switch M from position 9 into position 15 through the operation of relay 1210. The circuit of relay 1210 may be traced from grounded battery through the right-hand winding of the relay, wiper 1217 and bank terminals 9 to 14 with which it contacts during its advancement, and thence to ground at the right-hand armature and back contact of relay 1216. Relay 1210, upon energizing, closes the previously traced circuit for the stepping magnet 1218, which circuit is maintained until wiper 1217 leaves terminal 14 of its bank when relay 1210 deenergizes and opens the circuit of magnet 1218. In position 15 relay 1210 is again energized over wiper 1217, the inner left-hand armature and back contact of relay 1215 to ground at relay 1205 and drives switch M into position 18. Relay 1210, upon deenergizing, when switch M reaches position 18 closes a new circuit for advancing the time measure switch M into position 20, which circuit may be traced from grounded battery through the winding of magnet 1218, the right-hand armature and back contact of relay 1210, interrupter 1219, the inner left-hand armature and back contact of relay 1220, the bank contacts with which wiper 1277 is associated, wiper 1277, the inner left-hand armature and back contact of relay 1210, and thence to ground at the intermediate right-hand armature and front contact of relay 1205. Under the control of interrupter 1219, the stepping magnet 1218 advances the wipers of switch M into position 20 when the previously traced stepping circuit is opened at wiper 1277. If at the time the wipers of the time measure switch M reach position 20 the sender has not functioned to set up the desired connection, the sender monitor-

ing lamp 1221 is flickered to denote a stuck sender. The circuit of lamp 1221 may be traced from grounded battery through the lamp, the inner left-hand armature and back contact of relay 1216, interrupter 1235, bank terminal 1238, the wiper 1223, the outer left-hand armature and back contact of relay 1210, and thence to ground at the intermediate right-hand armature and front contact of relay 1205. The pilot lamp 1224 is also lighted at this time over a circuit which may be traced through conductor 1239, wiper 1277, and thence as previously traced to ground at the intermediate right-hand armature and front contact of relay 1205.

Restoration of the office sender.

Under the assumption that the establishment of the connection proceeded without interruption in the manner hereinbefore described, as soon following units selection as the sequence switch of the district selector advances out of position 10, the impulse leads 233 and 235, which up to the time sequence switch 200 leaves position 10₁, are connected with the windings of stepping relay 800 and balancing coil 638 are disconnected from the district selector trunk conductors 116 and 117 at the contacts of sequence switch cams 212 and 213. Upon the opening of the circuit over impulse leads 233 and 235, stepping relay 800 deenergizes opening the circuit of slow releasing relay 802, which, upon deenergizing, closes a circuit extending from ground through the normal contacts of its right-hand armature over wiper 842, the terminals of the restoring bank 843 of the switch RS, the armature and back contact and winding of stepping magnet 817, thence to grounded battery through the winding of relay 816. Stepping magnet 817 thereupon causes the restoration of the steering switch from position 10 to its normal position.

Upon the completion of talking selection and the deenergization of relay 228 of the district selector switch, relays 230 and 244 become deenergized since their locking circuit is now opened at the outer right-hand armature and front contact of relay 228, and relay 230, upon deenergizing, opens the circuit of relay 626. Relay 626, upon deenergizing, closes a restoring circuit for the time measure switch TM which may be traced from grounded battery through the winding of stepping magnet 627 of the switch TM, the armature and back contact of this magnet, wiper 667, the terminals of the restoring bank with which this wiper is associated, and thence to ground at the armature and back contact of relay 626. Under the influence of magnet 627, the time measure switch is restored into its normal position. Upon the deenergization of relay 626, the holding circuits of relays 630 and 1205 are

opened at the armature and front contact of relay 626 and these relays thereupon become deenergized. The deenergization of relay 630 disconnects the impulse leads 636 and 637 and the deenergization of relay 1205 closes a circuit for restoring the monitoring time switch M into its normal position. Upon the deenergization of relay 1205 a circuit is established for relay 1210 extending from grounded battery through the winding of relay 1210, the off normal terminals of the restoring bank 1240 of the switch M, wiper 1241, and thence to ground at the outer left-hand armature and back contact of relay 1205. Relay 1210, upon energizing, establishes a circuit for the stepping magnet 1218 extending from grounded battery through the winding of magnet 1218, the armature and back contact of the magnet, the right-hand armature and front contact of relay 1210, the terminals of bank 1240, wiper 1241, and thence to ground at the outer left-hand armature and back contact of relay 1205. As soon as the switch M reaches normal position the circuit of magnet 1218 is opened at wiper 1241 and the switch M is arrested in its normal position.

When the time measure switch TM reaches normal position a circuit is closed for driving the translator sequence switch 600 out of position 15 and into position 18, which circuit may be traced from grounded battery through the winding of magnet 600, the contact of sequence switch cam 622 (2 to 17), and thence to ground at the normal terminal and wiper 635 of the time measure switch TM. If the translator switch TS has reached normal position at this time a circuit is completed for continuing the movement of the sequence switch 600 out of position 18 and into normal position. This circuit may be traced from grounded battery through the magnet winding of sequence switch 600, the lower left-hand contact of sequence switch cam 607 (18), conductor 666, and thence to ground at the armature and back contact of relay 1169.

In the movement of the translator control sequence switch 600 through positions 12 to 18, a circuit was established for restoring the code registers to normal position. The circuit for restoring register A may be traced from grounded battery through the left-hand armature and back contact of relay 808, conductor 809, winding of relay 810, the winding of stepping magnet 807 of register A, the armature and contact of stepping magnet 807, the terminals of the restoring bank 847 and wiper 848 of register A, conductor 849, and thence to ground at the upper contact of sequence switch cam 623. When register A reaches normal position a similar circuit is established for stepping magnet 819 of register B extending through the winding of this magnet, the

armature and contact of the magnet, terminals of restoring bank 850, wiper 851, conductor 852, the normal contact of restoring bank 847 of register A, wiper 848, conductor 849, and thence to ground through sequence switch cam 623. Register B, upon reaching normal position, transfers the restoring circuit extending from sequence switch cam 623 from the winding of stepping magnet 819 to the winding of stepping magnet 822 through the terminals of restoring bank 855 and wiper 854 of the register C and the normal terminal and wiper 851 of register B.

When the translator control sequence switch 600 passes through positions 14 to 18 a circuit is closed for restoring the thousands, hundreds, tens and units registers in succession. The circuit for restoring the thousands register TH may be traced from grounded battery through the left-hand armature and back contact of relay 808, conductor 809, the winding of relay 810, conductor 811, thence through the winding and armature contacts of magnet 921, the terminals of restoring bank 922, wiper 923, conductor 924, and thence to ground at the lower right-hand contact of sequence switch cam 623. When the thousands register reaches normal position the restoring conductor 924 becomes connected through wiper 923 and the normal terminal of the restoring bank 922 of the thousands register to conductor 925, wiper 926, and the terminals of the restoring bank 927 of the hundreds register, and thence through the armature contacts and magnet winding 928 of the hundreds register to grounded battery over the circuit previously described. In a similar manner the hundreds register, upon reaching normal position, establishes a restoring circuit extending through the winding of the stepping magnet 929 of the tens register, and the tens register, upon reaching normal position, extends a restoring circuit through the stepping magnet 930 of the units register.

As soon as the translator control sequence switch leaves position 11 battery is removed at sequence switch cam 610 from the circuit extending through the winding of skip office register relay 1012 to unlock this relay if it is at the time energized. Upon leaving position 13 battery is disconnected from conductor 647 for unlocking the energized district brush, office brush, district group and office group register relays which have been locked up, and upon leaving position 14 battery is disconnected from conductor 646 for unlocking the talking selection relay 1017 which was energized and locked up for controlling talking selection. Upon leaving position 18 the translator control sequence switch opens the locking circuit for relay 776 of the sender, restoring this relay. The circuits of the entire office send-

er are now restored to normal condition and the office sender may be taken for use in establishing other connections.

5 *Restoration of the connection between the calling line and the called line.*

Upon the termination of the conversation both the calling and called subscribers restore their respective receivers to their switch hooks. At this time relay 261 is energized since this relay was energized, as previously described, upon the response of the called subscriber. Upon the restoration of the calling subscriber's receiver to its switch hook, supervisory relay 234 deenergizes opening the holding circuit of relay 227, and since the holding circuit through the right-hand winding of relay 227 is now opened, the sender having been disassociated from the district selector, relay 227 deenergizes closing a circuit for driving sequence switch 200 out of position 12 and into position 16, this circuit extending from grounded battery through the winding of sequence switch magnet 200, the lower left-hand contact of sequence switch cam 206 (12 to 17), the left-hand contacts of sequence switch cam 223, and thence to ground at the normal contacts associated with the right-hand armature of relay 227. At its left-hand armature relay 227 opens the previously traced locking circuit for relay 226 extending over the upper contact of sequence switch cam 203 and establishes a new locking circuit for relay 226 which may be traced through the left-hand winding of relay 226, the normal contacts associated with the left-hand armature of relay 227, the lower right-hand contact of sequence switch cam 203, and thence over sleeve conductor 118 and to ground through the winding of cut-off relay 102, as previously traced.

As soon as sequence switch 200 reaches position 16 a circuit is closed for relay 228 which may be traced from grounded battery through the right-hand winding of relay 228, the upper contacts of sequence switch cam 204, the right-hand armature and front contact of relay 226, the upper right-hand and lower left-hand contacts of sequence switch cam 223, and thence to ground at the normal contact associated with the right-hand armature of relay 227. Relay 228, upon energizing, closes a circuit for driving sequence switch 200 out of position 16 and into position 17, which circuit may be traced from grounded battery through the magnet winding of sequence switch 200, the lower right-hand contact of sequence switch cam 206 (16), the inner right-hand armature and front contact of relay 228, and thence to ground at the right-hand contact of sequence switch cam 207. Relay 228, upon energizing, establishes a locking circuit for itself extending through its left-hand winding,

its left-hand armature and front contact, the lower right-hand contact of sequence switch cam 210, the lower left-hand contact of sequence switch cam 211 (16 to 17), the outer left-hand armature and front contact of relay 226, wiper 231, and thence to ground on the contact of the bank with which wiper 231 is then in engagement, if the sender associated with the multiples upon which the wipers of the 75 sender finder SF are then resting is at the time employed. When sequence switch 200 reaches position 17, a circuit is established for the stepping magnet 229 of the sender finder SF extending from grounded battery 80 through the armature contacts and winding of stepping magnet 229, the lower contact of sequence switch cam 208 (16 $\frac{1}{2}$ to 17), the inner right-hand armature and front contact of relay 228, and thence to ground at the right-hand contact of sequence switch cam 207 (7 $\frac{1}{2}$ to 6). Under the influence of magnet 229 the wipers of switch SF are advanced over the multiples of conductors extending to office senders assigned to the group of district selector switches in which the district selector 250 is located, until the test wiper 231 encounters a bank terminal corresponding to an idle office sender when the previously traced locking circuit of relay 228 95 is opened and relay 228 becomes deenergized opening the circuit of stepping magnet 229. A circuit is now established for relays 230 and 244 which may be traced from grounded battery through the armature and back contact and winding of stepping magnet 229, the windings of relays 230 and 244 in parallel, the lower right-hand and upper left-hand contacts of sequence switch cam 204, the right-hand armature and front contact 100 of relay 226, and thence to ground at the upper right-hand contact of sequence switch cam 205 (17 to 15).

Upon the energization of relay 230 the circuit previously traced for relay 626 is 110 established and relay 626 energizes closing the previously traced circuit for advancing the time measure switch TM from normal position into position 2. With the time measure switch TM in position 2 a circuit 115 is established for relay 630 in the manner previously described, and relay 630, upon attracting its armatures, closes the previously traced circuit for advancing the time measure switch into position 6 and for 120 extending the dialing leads through the contacts of relay 230, wipers 232 and 236 of the sender finder switch and through the windings of relay 800 of the register steering switch and the balancing coil 638. 125 Since the subscriber's receiver has been restored to its switch hook, the dialing circuit is without effect. Upon the advancement of the time measure switch to position 6 with the register stepping relay 800 deenergized, a 130

circuit is established for the wipe out relay 668 which may be traced from grounded battery through the winding of this relay, the No. 6 terminal of bank 669 of the time 5 measure switch, wiper 670, conductor 671, the normally closed contacts associated with the left-hand armature of relay 802, and thence to ground at the armature and back contact of relay 800. Relay 680, upon energizing, 10 also closes the previously traced circuit for relay 1205, which, upon energizing, closes the previously traced locking circuit for itself extending over conductors 1208 and 1207 to the armature and front 15 contact of relay 626.

Immediately upon the extension of the connection from the district selector switch 250 to the office sender, assuming that the established connection has been successful, 20 a circuit is established for the coin collection relay 1212 which may be traced from grounded battery through the winding of relay 1212, conductor 1242, the upper right-hand and lower left-hand contacts of translator 25 control sequence switch cam 620 (1), conductor 672, the contacts of route switch cam 1313 (1), the lower contact of translator control sequence switch cam 615 (1), the left-hand armature and back contact of 30 advance relay 658, conductor 659, wiper 263 of the sender finder switch SF, the left-hand armature and front contact of relay 244, the lower right-hand contact of sequence 35 switch cam 218 (16 to 17), and thence to ground at the armature and front contact of charging relay 261. It is to be noted in this connection that since the subscriber's receiver is upon its switch hook at the time the sender is seized, and since no digits have 40 been dialed, the translator control sequence switch 600 and the sequence switch 700 of the sender are therefore in normal position.

Upon the energization of relay 1205, a circuit is established for relay 1209 extending from grounded battery at the outer right-hand armature and back contact of relay 1302, conductor 1036, the right-hand armature and back contact of relay 1035, conductor 1211, the winding of relay 1209, 50 the normal contact of the bank with which wiper 1277 is in engagement, the inner left-hand armature and back contact of relay 1210, and thence to ground at the intermediate right-hand armature and front 55 contact of relay 1205. Relay 1209, upon energizing, closes a locking circuit for itself independently of the wiper 1277 extending from grounded battery on conductor 1211, through the winding of relay 1209, the left-hand armature and front contact of relay 1209, the outer right-hand armature and front contact of relay 1212, and thence to ground at the armature and back contact of relay 1243. At its right-hand armature and

front contact relay 1209 establishes a circuit for relay 1210 which may be traced from grounded battery through the right-hand winding of relay 1210, wiper 1217 and the normal contact of the bank with which it is associated, and thence to ground at the right-hand armature and front contact of relay 1209. Relay 1210, upon energizing, closes a circuit for the stepping magnet 1218 of the switch M which may be traced from grounded battery through the winding of magnet 1218, the armature and back contact of magnet 1218, the right-hand armature and front contact of relay 1210, wiper 1217 and the normal contact with which it is in engagement, and thence to ground at the right-hand armature and front contact of relay 1209.

As soon as the switch M reaches position 1 a circuit is established for relays 1215 and 1220 which may be traced from grounded battery through the windings of these relays in parallel, conductor 1244, the inner right-hand armature and front contact of relay 1205, the position 1 terminal of bank 1246, brush 1241, the outer left-hand armature and front contact of relay 1205, the normally closed contacts associated with the outer left-hand armature of relay 1220, conductor 1245, the outer left-hand armature and back contact of advance relay 648, the outer left-hand armature and back contact of relay 639, and thence to ground at the armature and front contact of relay 668. Relay 1220, upon energizing, establishes a locking circuit for both relays 1215 and 1220 independent of wiper 1241 which may be traced through the windings of relays 1215 and 1220 in parallel, thence through the outer left-hand armature and front contact of relay 1220, and to ground at the armature and front contact of relay 668 over the circuit previously traced. Upon the energization of relay 1209 a circuit is also established for relay 1216 extending from grounded battery on conductor 1211, thence through the winding of relay 1216 to ground at the right-hand armature and front contact of relay 1209.

Upon the energization of relay 1215 a circuit is established for relay 1200 which may be traced from grounded battery on conductor 1211, through the winding of relay 1229, the winding of relay 1200, the inner left-hand armature and front contact of relay 1215, and thence to ground at the outer right-hand armature and front contact of relay 1205. Relay 1200, upon energizing, closes a locking circuit for itself extending from grounded battery on conductor 1211 over the circuit previously traced, through the winding of relay 1200, the inner right-hand armature and front contact of relay 1200, conductor 1230, the contacts of

sequence switch cam 621 (1 to 13), and thence to ground at the armature and front contact of relay 626.

As soon as switch M leaves its normal position the circuit of relay 1210 is opened at wiper 1217, but when the switch reaches position 1 a new energizing circuit for relay 1210 is established extending from grounded battery through the right-hand winding of relay 1210, wiper 1217, conductor 1246, the outer right-hand armature and front contact of relay 1229, and thence to ground at the outer right-hand armature and front contact of relay 1205. Relay 1210, upon energizing, closes a circuit for the stepping magnet 1218 extending from grounded battery through the winding, armature and back contact of magnet 1218, the right-hand armature and front contact of relay 1210, wiper 1217, and thence to ground at the outer right-hand armature and front contact of relay 1205 over the circuit previously traced. Through the operation of magnet 1218, the switch M is rapidly advanced to position 5 when the circuit of relay 1210 is opened at brush 1217 and the circuit of stepping magnet 1218 is opened. With relay 1210 deenergized a new circuit for stepping magnet 1218 is established extending from grounded battery through the winding of magnet 1218, the right-hand armature and back contact of relay 1210, the fast interrupter 1247, the inner left-hand armature and front contact of relay 1220, thence over position 5 bank terminal with which wiper 1277 is in engagement, wiper 1277, the inner left-hand armature and back contact of relay 1210, and thence to ground at the intermediate right-hand armature and front contact of relay 1205. Under the influence of interrupter 1247 the stepping magnet 1218 advances the wipers of switch M to position 7 in which position the stepping circuit of magnet 1218 is extended over the circuit previously traced to the inner left-hand armature and front contact of relay 1220, thence through the right-hand armature and front contact of relay 1220 to the position 7 terminal of the bank with which wiper 1277 is in engagement, and thence to ground as previously traced. Upon reaching position 8 the circuit of magnet 1218 is completed over the circuit previously traced through the inner left-hand armature and front contact of relay 1220 for continuing the advance of switch M into position 11.

When the wipers of switch M reach position 5 a circuit is closed for applying coin collection current from the source 1261 of positive current through the inner right-hand armature and front contact of relay 1229, the winding of relay 1243, the inner left-hand armature and front contact of

coin collection relay 1212, the outer right-hand armature and front contact of relay 1215, thence in parallel through bank terminals 1248 and 1249, wipers 1206 and 1233, the outer right-hand armature and front contact and outer left-hand armature and front contact of relay 1200, the outer right-hand armature and back contact and outer left-hand armature and back contact of relay 1201, thence over conductors 1202 and 1203 and over the circuit previously traced to conductors 103 and 104 of the subscriber's line K. Current from the source 1261 now flows through the coin magnet 126 and through contacts 127 to ground in such a direction as to cause the energization of polarized magnet 126 in such a manner as to collect the deposited coin. Relay 1243 also energizes in series with coin box magnet 126 and at its armature and back contact opens the previously traced locking circuit of relay 1209, and relay 1209, upon deenergizing, opens the previously traced circuit of relay 1216.

When wipers 1206 and 1233 of the switch M reach position 7 both conductors of the subscriber's line are connected over the circuit previously traced through wipers 1206 and 1233, bank terminals 1251 and 1252 to ground through condenser 1250 for the purpose of discharging the subscriber's line from the charge of collection current which was applied for collecting the deposited coin.

When the wipers of switch M reach position 9 the right-hand and left-hand windings of differential relay 1253 are connected respectively to the tip and ring conductors of the subscriber's line over the circuit previously traced from the subscriber's line to wipers 1206 and 1233, and thence through bank terminals 1254 and 1255 to grounded battery through the windings of relay 1253. If the calling subscriber, following the collection of the coin, has immediately removed his receiver from the switch hook to initiate another call, or if the receiver is still on the hook and the coin has been properly collected, relay 1253 does not energize over the circuit previously traced. If, however, the coin has stuck in the coin chute and ground is still maintained on the tip conductor 104 of the subscriber's line at coin box contacts 127, relay 1253 becomes energized and closes a circuit for relay 1209 which may be traced from grounded battery on conductor 1211, through the winding of relay 1209, and thence to ground at the armature and front contact of relay 1253. Relay 1209, upon energizing, locks up over the circuit previously traced to ground at the armature and back contact of relay 1243, this relay having deenergized as soon as switch M moved out of position 6, and also

closes the previously traced circuit for relay 1216. When switch M now reaches position 11 the circuit of stepping magnet 1218 is opened at brush 1277 and the switch is arrested. A circuit is now established for 5 flashing the coin lamp 1234 which may be traced from grounded battery through lamp 1234, interrupter 1256, the inner right-hand armature and front contact of relay 1215, bank terminal 1236, wiper 1223, the outer left-hand armature and back contact of relay 1210, and thence to ground at the intermediate right-hand armature and front contact of relay 1205. The flashing of the coin lamp 10 1234 at this time signifies to the monitoring operator that the coin has stuck in the coin chute at the calling subscriber's substation and the operator will thereupon initiate the necessary steps to clear the trouble.

If the coin is properly collected relay 1253 does not energize and consequently relays 1209 and 1216 do not energize at this time. Therefore, when switch M reaches position 15 15 a circuit is established for rapidly advancing the switch M into position 15 through the operation of relay 1210 which energizes in a circuit which may be traced from grounded battery through the right-hand winding of relay 1210, wiper 1217, position 9 terminal of the bank with which wiper 1217 is associated, and thence to ground at the right-hand armature and back contact of relay 1216. This circuit is maintained until the wipers of switch M advance out of 20 position 14.

As soon as the wipers of the switch reach position 15 a circuit is established for relay 227 of the district selector switch which may be traced from grounded battery through the right-hand winding of relay 227, the upper contact of sequence switch cam 214 (17), the right-hand armature and front contact of relay 244, the lower contact of sequence switch cam 215 (17), wiper 245, the inner 25 left-hand armature and back contact of relay 648, conductor 674, position 15 terminal of the bank with which wiper 1223 is in engagement, wiper 1223, the outer left-hand armature and back contact of relay 1210, and thence to ground at the intermediate right-hand armature and front contact of relay 1205. This circuit is maintained while the switch M is advancing through positions 16 and 17 under the control of interrupter 1247. 30 Relay 227, upon energizing, opens the previously traced locking circuit of relay 226 at the normally closed contacts associated with its left-hand armature. Relay 226, upon deenergizing, opens the locking circuit 35 over which relays 230 and 244 have been maintained energized and these relays thereupon deenergize. Relay 230, upon deenergizing, opens the circuit of relay 626, which, in the manner previously described, closes 40 a circuit extending through bank 667 of switch TM and the winding of stepping magnet 627 for restoring the time measure switch TM to normal position. As soon as switch TM reaches normal position the circuit of relay 668 is opened and the previously traced locking circuit of relays 1215 and 1220 is opened. When the time measure switch TM reaches normal position the locking circuit of relay 630 is opened and dialing leads 636 and 637 are thereupon disconnected 45 from conductors 1202 and 1203. Relay 626, upon deenergizing, also opens the locking circuit of relay 1205, which, upon deenergizing, closes a circuit for relay 1210 which may be traced from grounded battery through the right-hand winding of relay 1210, the contacts of bank 1240, wiper 1241, and thence to ground at the left-hand armature and back contact of relay 1205. Relay 1210, upon energizing, closes a circuit for 50 stepping magnet 1218 which may be traced from grounded battery through the winding, armature and back contact of magnet 1218, the right-hand armature and front contact of relay 1210, contacts of bank 1240, wiper 1241, and thence to ground at the outer left-hand armature and back contact of relay 1205. As soon as switch M reaches normal position the circuit of relay 1210 is opened and relay 1210, upon deenergizing, 55 opens the circuit of stepping magnet 1218. As the switch M passes through positions 18 and 19 a circuit is closed for shunting the winding of relay 1200 extending from conductor 1230, through the inner right-hand 60 armature and front contact of relay 1200, position 18 terminal of the bank with which wiper 1223 is associated, wiper 1223, the outer left-hand armature and back contact of relay 1210, and thence to ground at the intermediate right-hand armature and front contact of relay 1205. This circuit is effective prior to the deenergization of relay 1205 for insuring the deenergization of relay 1200 and the consequent deenergization of 65 relay 1229 which is held locked up in series with relay 1200. The circuits of the central office sender are now in normal position. 70 At the district selector switch, upon the deenergization of relay 226, a circuit is closed for advancing the sequence switch 200 out of position 17 and into position 18 which may be traced from grounded battery through the magnet winding of sequence switch 200, the lower left-hand contact of sequence switch cam 206 (12 to 17), the right-hand armature and back contact of relay 226, and thence to ground at the upper right-hand contact of sequence switch cam 205 (17 to 15). As soon as sequence switch 75 200 leaves position 17 the energizing circuit of relay 227 is opened and relay 227 deenergizes. With sequence switch 200 in position 18 a circuit is closed for the down-drive magnet 271 which may be traced from 80

grounded battery through the winding of magnet 271, the lower contacts of sequence switch cam 223, and thence to ground at the normally closed contacts associated with the right-hand armature of relay 227. Magnet 271, upon energizing, presses the depending portion of switch shaft 239 against the constantly rotating downdrive drum 272 and in the well-known manner causes the restoration 5 of the switch shaft to its normal position. Upon reaching its normal position a circuit is established for sequence switch magnet 200 which may be traced from grounded battery through the winding of 10 the sequence switch magnet, the upper right-hand contact of sequence switch cam 206, normal commutator segment 273, brush 248, and thence to ground at the lower contact of 15 sequence switch cam 209. The sequence switch magnet is energized in this circuit and advances the sequence switch into normal position. As soon as the sequence switch leaves position 18 the locking circuit of relay 261 is opened at sequence switch cam 218. 20 The circuits of the district selector switch are now in normal condition.

Upon the opening of the circuit extending through the winding of sleeve relay 226 and the winding of cut-off relay 102, relay 102 becomes deenergized and at its lowermost 30 armature and back contact closes the circuit of stepping magnet 105 for restoring the line switch 100 into its normal position. The circuit of magnet 105 may be traced 35 from grounded battery through the winding, armature and back contact of magnet 105, conductor 106, the lowermost armature and back contact of relay 102, the right-hand armature and back contact of relay 101, 40 conductor 125, wiper 112, and thence to ground on segment 124. As soon as the switch 100 reaches normal position the circuit of magnet 105 is opened at wiper 112.

As soon as sequence switch 200 leaves 45 position 14½ holding ground potential is removed from test brush 252 at the lower left-hand contact of sequence switch cam 216 (8½ to 14½) and the circuit extending over bank terminal 255, sleeve conductor 50 333, the lower right-hand contact of sequence switch cam 305, the inner right-hand armature and front contact and right-hand winding of relay 312 is opened and relay 312 deenergizes. At the same time the circuit 55 of relay 421 of the interoffice selector switch 450 is opened, this circuit extending from conductor 333 through the right-hand contacts of sequence switch cam 305, brush 330 and bank terminal 334 of the office selector switch, the upper contact of sequence switch cam 407, conductor 427, the outer left-hand armature and front contact of relay 421, conductor 431, the upper left-hand contact of sequence switch cam 409, the 60 armature and back contact of relay 455, and

thence to grounded battery through the left-hand winding of relay 421.

Relay 312 of the office selector, upon deenergizing, closes a circuit for placing busy ground potential upon the bank terminal 70 255 and its multiples appearing in the banks of all district selector switches which have access to this office selector to prevent the seizure of the office selector until it has completely restored to normal. This ground potential is applied over a circuit extending from sleeve conductor 333 through the lower right-hand contact of sequence switch cam 305 (6½ to 18), inner right-hand armature and back contact of relay 312, and thence 75 to ground through the upper left-hand contact of sequence switch cam 308 (5½ to 18). At its left-hand armature and back contact relay 312 closes a circuit for driving sequence switch 300 out of position 8 and 80 into position 18, this circuit extending from grounded battery through the magnet winding of sequence switch 300, conductor 324, the lower left-hand contact of sequence 85 switch cam 307, conductor 325, and thence 90 to ground through the left-hand armature and back contact of relay 312. Upon reaching 95 position 18 a circuit is closed for the downdrive magnet 338, which circuit extends from grounded battery through the winding of magnet 338, and thence to ground through the contacts of sequence switch cam 306. The energization of magnet 338 presses the depending portion of 100 switch shaft 317 against the constantly rotating downdrive drum 339, thereby causing the movement of the switch shaft into normal position. As soon as the switch shaft reaches normal position a circuit is closed for driving sequence switch 300 out 105 of position 18 and into position 1, this circuit extending from grounded battery through the winding of sequence switch magnet 300, conductor 324, the lower right-hand contact of sequence switch cam 307, 110 normal segment 340 of commutator 321, brush 329, conductor 323, and thence to ground at the lower left-hand contact of sequence switch cam 306. As soon as sequence 115 switch 300 leaves position 18 the circuit of the downdrive magnet 338 is opened to arrest the downward movement of the switch shaft. The office selector and its associated circuits are now in normal position.

Upon the deenergization of relay 421 of 120 the incoming selector switch 450 busy ground potential is connected to the sleeve conductor of the trunk 419, 420 over the upper contact of sequence switch cam 407, conductor 427, the outer left-hand armature and back contact of relay 421, and thence to ground through the upper right-hand and lower left-hand contacts of sequence switch cam 411 for preventing the 125 seizure of the trunk until after the incoming 130

selector switch has been completely restored to normal. At its inner left-hand armature and back contact relay 421 closes a circuit extending through the upper left-hand contact of sequence switch cam 406 for driving sequence switch 400 out of position 16 and into position 18. As soon as sequence switch 400 reaches position 18 a circuit is closed through the winding of the down-drive magnet 461, extending from grounded battery through the winding of magnet 461, and thence to ground through the right-hand contacts of sequence switch cam 410. Magnet 461, upon energizing, presses the 10 pending portion of the switch shaft 432 against the constantly rotating downdrive drum 462, thereby restoring the switch shaft to normal position. As soon as the switch shaft reaches its normal position a circuit is 15 closed for driving sequence switch 400 out of position 18 and into normal position. This circuit may be traced from grounded battery through the magnet winding of sequence switch 400, the upper right-hand contact of sequence switch cam 406, normal segment 463 of the commutator 435, brush 441, conductor 437, and thence to ground through the lower contact of sequence switch cam 410. As soon as sequence switch 400 leaves 20 position 18 the circuit of the downdrive magnet 461 is opened to arrest the downward movement of the switch shaft and busy ground potential is removed from the sleeve conductor 464.

When sequence switch 400 of the incoming selector switch leaves position 16₁ the circuit previously traced through the contacts of sequence switch cam 412 over brush 442 and terminal 451 of the incoming selector, 25 sleeve conductor 525, the left-hand armature and front contact of relay 521, the armature and back contact of relay 524 and through the left-hand winding of relay 521, over which circuit relay 521 has been energized, 30 is opened and relay 521, upon deenergizing, closes a circuit for energizing relay 518. This latter circuit may be traced from grounded battery through the left-hand winding of relay 518, the upper contacts of sequence switch cam 509, and thence to ground at the armature and back contact of relay 521. Relay 518, upon energizing, 35 closes a circuit for driving sequence switch 500 out of position 15 and into position 16. This circuit may be traced from grounded battery through the winding of magnet 500, the lower right-hand contact of sequence switch cam 512, the left-hand armature and front contact of relay 518, and thence to ground at the upper right-hand contact of cam 508. 40

When the sequence switch 500 leaves position 15, the energizing circuit of relay 518 is opened but relay 518 is maintained locked up over a circuit extending from grounded

battery through the left-hand contact of sequence switch cam 504, the right-hand winding of relay 518, the lower contact of sequence switch cam 510, the right-hand armature and front contact of relay 518, the lower left-hand and upper right-hand contacts of sequence switch cam 505, brush 553, bank terminal 557, over the subscriber's line loop, bank terminal 559, brush 552, the lower right-hand contact of sequence switch cam 502, and thence to ground at the upper left-hand contact of sequence switch cam 503. This locking circuit for relay 518 is maintained until the called subscriber restores his receiver to its switch hook and the restoration of the final selector does not take place until the called subscriber has hung up.

In order to render relay 518 more sensitive for releasing upon the restoration of the called subscriber's receiver to its switch hook, 85 a shunt path is closed around the winding of relay 518 from grounded battery through resistance element 560 and the contact of sequence switch cam 516 (16).

When the called subscriber does restore 90 his receiver, relay 518 becomes deenergized and at its left-hand armature and back contact closes a circuit for driving sequence switch 500 out of position 16 and into position 17. This circuit may be traced from 95 grounded battery through the winding of sequence switch magnet 500, the upper right-hand contact of sequence switch cam 512, the left-hand armature and back contact of relay 518, and thence to ground at the upper 100 right-hand contact of sequence switch cam 508. Upon reaching position 17 sequence switch 500 is driven into position 18 over a circuit extending through its magnet winding, the lower right-hand and upper left-hand contacts of sequence switch cam 509, and to ground at the right-hand armature and back contact of relay 521. When sequence switch 500 reaches position 18 a circuit is closed for downdrive magnet 544 extending from grounded battery through the winding of magnet 544, the lower right-hand contact of sequence switch cam 511 (18), the upper right-hand contact of sequence switch cam 507 (18), and thence to ground 110 through the upper left-hand contact of sequence switch cam 506. As soon as switch shaft 527 reaches normal position a circuit is closed for driving sequence switch 500 out of position 18 and into normal position, this circuit extending from grounded battery through the winding of the magnet of sequence switch 500, the upper left-hand contact of sequence switch cam 512, conductor 546, normal segment 547 of commutator 531, 115 brush 538, conductor 533, and thence to ground at the upper left-hand contact of sequence switch cam 506. The final selector and its associated circuits are now in normal position. During the restoration of the 120

130

final selector to normal position the trunk extending to multiple terminals in banks of all incoming selector switches having access thereto is held busy by ground potential connected to the sleeve conductor 525 of the trunk over the left-hand armature and back contact of relay 521 and the upper left-hand contact of sequence switch cam 514. All apparatus which has been employed in the establishment of the connection has now been restored to normal condition and may be employed for establishing other calls.

If the connection established to the called line had been unsuccessful, that is, the called subscriber failed to respond, then the call charging relay 261 of the district selector switch would not have energized when sequence switch 200 of the district selector was in position 12, and, consequently, no circuit for the coin collection relay 1212 would have been established upon the reassociation of the office sender with the district selector upon the termination of the call. Therefore, when switch M reaches position 5 current from the refunding source 1260 becomes connected through the left-hand armature and front contact of relay 1229 through the inner right-hand armature and back contact of relay 1212, and thence, as previously traced, to the subscriber's line. This current being of negative polarity causes the energization of polarized coin box magnet 126 in such a direction as to refund the coin.

35 II. THE ESTABLISHMENT OF FREE CONNECTIONS.

To special lines.

40 If the calling subscriber dials the number of a subscriber's line to which he is entitled to have free service, as to the police station or fire headquarters, register relay 1035 will be energized at the time the class 45 register relays are energized and relay 1035 will thereupon close a locking circuit for itself extending through its left-hand winding, its left-hand armature and front contact, and thence to battery lead 647. Relay 50 1035, upon energizing, opens the circuit previously traced extending from grounded battery through the outer right-hand armature and back contact of relay 1302, conductor 1036, the right-hand armature and back 55 contact of relay 1035, and thence to conductor 1211 so that upon the energization of relay 1205 no circuit will be effective for relay 1209, and, consequently, relay 1216 does not become energized. When therefore the 60 sender sequence switch 700 reaches position 5 during its second revolution, preparatory to controlling units selection, the previously traced circuit for relay 647 extending from grounded battery through the contact of sequence switch cam 781 (5 to 6), conductor

782, the left-hand contacts of sequence switch cam 617, the winding of relay 647, conductor 665 and to the armature and front contact of relay 1216, is not effective and therefore the fundamental circuit extending between the stepping relay 719 at the sender and relay 518 of the final selector will be established and the establishment of the connection will proceed in the same manner as though the calling subscriber had deposited a coin in his coin box, as soon as sender sequence switch 700 reaches position 6.

To the zero operator.

If the calling subscriber desires to establish a connection with the zero operator he may do so and obtain a complete connection to the operator's position without first depositing a coin. To obtain a connection with a zero operator the subscriber removes his receiver from the switch hook and becomes connected with the office sender in the manner previously described and then dials a single digit 0 for setting the register A into position 10 in the manner substantially set forth hereinbefore. With register A in position 10 a circuit is established for relays 1302 and 1305 associated with the route switch which may be traced from grounded battery through the windings of these relays in parallel, conductor 1314, terminal 858, wiper 859 of register A, conductor 860, and thence to ground through the lower left-hand contact of the translator control sequence switch cam 623 (1 to 11).

Relay 1302, upon energizing, closes a circuit for driving route switch 1300 into position 3 which may be traced from grounded battery through the magnet winding of switch 1300, the lower contact of cam 1315, (4 to 2), and thence to ground through the inner right-hand armature and front contact of relay 1302. At its left-hand armature and front contact relay 1302 establishes a circuit for advancing the class switch 750 into position 13, which circuit may be traced from grounded battery through the magnet winding of class switch 750, the contact of the class switch cam 783 (14 to 12), and thence to ground at the left-hand armature and front contact of relay 1302. At its outer right-hand armature and back contact relay 1302 disconnects grounded battery from conductor 1036, and thereby disconnects battery from conductor 1211 to prevent the energization of relays 1209 and 1216 and the opening of the fundamental circuit in the manner previously described. The circuits rendered effective by relay 1305 will be described hereinafter.

During the setting of the route switch 1300, relay 1316 is maintained energized in parallel with the winding of the route switch and relay 760 is maintained energized during the operation of class switch

over a circuit extending in parallel through the winding of the magnet of switch 750. As soon as the route switch and class switch have been set through the operation of relay 1302, a circuit is established for advancing the sequence switch 700 of the sender into position 2, which circuit may be traced from grounded battery through the winding of magnet 700, conductor 732, the 10 lower right-hand contact of sequence switch cam 704 (1), conductor 733, conductor 1039, the lower contacts of route switch cam 1303 (3), the right-hand armature and back contact of relay 1316, and to ground at the 15 armature and back contact of relay 760.

Since the register steering switch RS, following the setting of register A, does not advance beyond position 1 the circuit traced hereinbefore over conductor 1228 for 20 advancing the monitoring time measure switch M is not effective. A new circuit is therefore provided for advancing the switch M which may be traced over conductor 1228, conductor 675, the contact of class switch cam 784, conductor 785, the contacts of route switch cam 1317, and thence to ground at the left-hand armature and back contact of relay 1316.

With the route switch set in position 3 30 and the class switch in position 13, the counting relay leads, which are normally connected to the register relay contacts through the lower contacts of route switch cams 1308, 1309, 1310 and 1311, are disconnected from the register relays and the counting relay leads are connected directly through the upper contacts of these route switch cams and the district brush, district group, office brush and office group selections are controlled from the upper contacts of the afore-mentioned route switch cams in positions 2, 4, 8 and 10 of the sender sequence switch 700. Following office group 40 selection, sequence switch 700 of the office sender advances in the manner previously described into position 12. The brushes of the office selector switch now hunt in the manner previously described for an idle trunk and in this instance, since the route 45 switch has been set for routing the connection to the zero operator, brushes of another brush set corresponding to brushes 330, 334 and 335 of the office selector switch 350 will be set upon the terminals 341, 342 and 343 connected to a trunk circuit terminating in a jack J, Fig. 3, in the position of the zero operator.

Upon the extension of the connection to 50 the trunk circuit the fundamental circuit is established through stepping relay 719 and trunk test relay 746 of the office sender. This fundamental circuit may be traced in part from conductor 659 through the left-hand armature and back contact of relay 658, the lower contact of sequence switch

cam 615 (1), conductor 653, the right-hand contacts of sequence switch cam 706, conductor 747, the winding of relay 746, the contact of class switch cam 786 (13 to 18), the contact of sequence switch cam 787 (12 to 14), the armature and back contact of relay 720, the winding of relay 719, the left-hand winding of relay 734, the contact of sequence switch cam 705 (12), conductor 654, left-hand contact of sequence switch cam 611 (1), the armature and back contact of relay 647, conductor 645, and from thence as previously traced to brush 334 of selector 350. Relay 746, upon energizing, closes the previously traced circuit for 55 relay 748, which in turn advances sequence switch 700 into position 14 in the manner hereinbefore described. With sequence switch 700 in position 14 a circuit is established for relay 749 in the manner hereinbefore described, and a circuit for relays 648 and 658 extending through these relays conductor 662, class switch cam 790 (13 to 14) to ground at cam 710 (14). Upon the energization of relays 648 and 658 the 60 sequence switch of the district selector is advanced out of position 10 for talking selection.

Talking selection is controlled in the manner hereinbefore described with the exception that the No. 2 counting relay is employed and the lead 739 from the No. 2 counting relay is connected to ground through the inner right-hand contact of relay 1305 instead of through the contacts of talking selection register relays 1017 and 1032. The circuit of the No. 2 counting relay may be traced from grounded battery through No. 2 counting relay 737, the armature and back contact of No. 2' counting relay 738, lead 739 lead 1318 Fig. 13, the inner right-hand armature and front contact of relay 1305, conductor 1312, the upper contact of sequence switch cam 711 (14), conductor 740, the right-hand contact of sequence switch cam 613 (1), conductor 741, and thence to ground, as previously described, at sequence switch cam 703 (14).

Following talking selection the No. 0' counting relay energizes and in the manner previously described advances the sender sequence switch 700 into position 16. The sequence switch of the district selector is now in position 14 for establishing a talking circuit to the operator, and the district selector now functions as set forth in the patent to F. A. Stearn and F. J. Scudder hereinbefore referred to. When the sequence switch 200 of the district selector switch leaves position 10₁, relays 800 and 802 deenergize and a circuit is closed for restoring the register steering switch RS to normal position, which may be traced from ground at the normally closed contact association with the right-hand armature of re- 125 130

lay 802, wiper 842, the terminals of restoring bank 843, the armature and back contact and winding of stepping magnet 817 and thence to grounded battery through the 5 winding of relay 816. Following the talking selection, relay 228 at the district selector switch deenergizes and opens the holding circuit of relays 230 and 244 as previously described, and relay 230 upon its deenergization 10 opens the holding circuit of relay 626. Until the route switch 1300 has been restored to its normal position, busy potential is maintained on the test terminal of sender finder switch SF to mark the sender 15 busy over a circuit extending from conductor 625, through the right-hand winding of relay 626 and to ground at the left-hand contacts of route switch cam 1319. Relay 626 upon deenergizing causes the restoration 20 of time measure switch TM and the restoration of the monitor time measure switch M in the manner previously described in connection with the establishment of a full mechanical connection.

25 When the time measure switch TM reaches its normal position, a circuit is closed for restoring the code register A, which may be traced from grounded battery, through the left-hand armature and back contact of relay 808, the winding of relay 810, conductor 811, the winding, armature and back contact of register stepping magnet 807, the terminals of restoring bank 847, wiper 848, conductor 849, conductor 676, the left-hand contact of sequence switch 624 (1), and thence to ground at the normal contact and wiper 632 of time measure switch TM. The register A is restored through the operation of magnet 807 and upon reaching normal position, the previously traced restoring circuit is opened at wiper 848. As soon as the register A leaves position 10, the circuit previously traced through relays 1302 and 1305 is opened, and relay 1305 upon deenergizing 40 closes a circuit for advancing the route switch into normal position, which circuit may be traced from grounded battery, through the magnet winding of route switch 1300, the upper contact of route switch cam 1315 (2 to 18), the inner left-hand armature and back contact of relay 1305, and thence to ground at the lower contact of translator control sequence switch cam 619 (12 to 1). When the route switch reaches 45 normal position, the previously traced circuit for holding the sender busy is opened at the contacts of cam 1319 and the sender is then made available for controlling the establishment of other connections.

50 With route switch 1300 in position 1 a circuit is established for advancing sequence switch 700 into position 17, which circuit may be traced from grounded battery through the winding of the magnet of sequence switch 700, the lower left-hand con-

tact of sequence switch cam 704, the contact of route switch cam 1320, and thence to ground at the lower right-hand contact of translator control sequence switch cam 606 (15 to 1). When sequence switch 700 reaches position 17 a circuit is established for relay 719 which may be traced from grounded battery through the winding of relay 749, the right-hand contacts of sequence switch cam 717 (17), the left-hand winding of relay 734, the winding of relay 719, the armature and back contact of relay 720, the outer right-hand armature and back contact of relay 644, conductor 651, and thence to ground through resistance element 722. Relay 719, upon energizing, closes a circuit for advancing sequence switch 700 into position 18, which may be traced from grounded battery through the winding of sequence switch magnet 700, conductor 732, the lower right-hand and upper left-hand contacts of sequence switch cam 702 (17), the armature and front contact of relay 719, and thence to ground through the lower right-hand contact of sequence switch cam 703. As soon as sequence switch 700 reaches position 18 the previously traced circuit extending through route switch cam 1320 is again established for advancing the sender sequence switch into position 1. The office sender is now in normal condition and the connection has been extended from the calling subscriber's line to the jack J and through plug P to the operator's set. Inasmuch as this invention does not directly involve the circuits at the operator's position, only the answering plug of the operator's cord circuit has been illustrated.

III. THE ATTEMPTED ESTABLISHMENT OF A CONNECTION OUTSIDE THE LOCAL AREA. 105

If the calling subscriber attempts to establish a connection outside the local area in which he is entitled to call by the deposit of five cents, zoning register relays shown 110 at 1040 and 1041 become energized and locked up at the time the district group register relays are operated from the pulse machine. It will be assumed that the calling subscriber has attempted to establish a call 115 in a zone outside of his restricted area and that register relay 1040 is energized and locked. The class switch 750 is set into position 13 for controlling the sender in the establishment of a connection to an operator's position by the class register relays as 120 previously described. Upon the energization of relay 1040 with relay 1041 deenergized, a circuit is established for relays 1302 and 1305 which may be traced from the 125 windings of these relays, conductor 1321, conductor 1322, the outer right-hand armature and back contact of relay 1041, the right-hand armature and front contact of relay 1040, conductor 1038, the 130

contacts of route switch 1307 (1), conductor 1020, and thence to ground at the armature and front contact of relay 760, relay 760 having been energized in parallel with class switch magnet 750. Relays 1302 and 1305 energize in this circuit and in the manner previously described cause the setting of the route switch 1300 into position 3 for controlling the routing of the call to the zero operator in the manner previously described.

IV. THE ESTABLISHMENT OF A CONNECTION TO THE SPECIAL SERVICE LINE.

If the calling subscriber dials a code, for example, for establishing connection to the telegraph office, the register relay 1042 is operated and locked up at the time the talking selection register relays are operated and a circuit is established for energizing relays 1302 and 1305 for setting the route switch into position 3 and the class switch into position 13 in the manner previously described. The circuit over which relays 1302 and 1305 are energized may be traced from conductor 1322 through the right-hand armature and front contact of relay 1042, conductor 1038, contacts of route switch cam 1307, conductor 1020, and thence to ground at the armature contact of relay 760. It is to be noted that whenever a call is routed to the zero operator's position either when the calling subscriber dials the number of a connection outside his restricted area or dials the number of a special service line, battery is removed at the outer right-hand armature and back contact of relay 1302 in the manner previously described for preventing the energization of relays 1209 and 1216 associated with the monitor's time measure switch M.

V. THE ESTABLISHMENT OF A CONNECTION TO A TOLL OR LONG DISTANCE OPERATOR.

If the calling subscriber desires a connection with the toll or long distance operator, three code digits are dialed for setting the code registers A, B and C, and the translator control sequence switch 600 and the register relays are set as hereinbefore described in connection with the establishment of a full mechanical connection. In this case, however, the class switch will be set in position 14 through the operation of the class register relays. As it is desirable to route the connection to the toll operator over a special trunk circuit so that the operator may be apprized of the fact that the call originated on a coin box line, routing register relay 1323 is energized at the time the pulse machine sets the office brush register relays, and, consequently, a circuit will be established for advancing the route switch 1300 out of position 1 and into position 4. This circuit may be traced from grounded battery through the magnet winding of

route switch 1300, the right-hand contact of cam 1325 (5 to 3), the outer left-hand armature and front contact of relay 1323, the right-hand armature and back contact of relay 1324, conductor 1020, and thence to ground at the armature and front contact of relay 760. With the route switch 1300 in position 4 leads from the counting relays are connected directly to the contacts of sender sequence switch cam 708 for controlling the setting of the district and office switches and the operation of the district brush, district group, office brush and office group register relays is rendered ineffective.

In a similar manner if the calling subscriber attempts to establish a connection with a long distance operator, both register relays 1323 and 1324 become energized and a circuit is established for driving route switch 1300 into position 5, which circuit may be traced from grounded battery through the magnet winding of route switch 1300, the left-hand contact of cam 1325 (6 to 4), the right-hand armature and front contact of relay 1323, the right-hand armature and front contact of relay 1324, conductor 1020, and thence to ground at the armature contact of relay 760. With route switch 1300 in position 5 the counting relays are connected directly to the contacts of sender sequence switch cam 708 over the contacts of route switch cams 1326, 1327, 1328 and 1329 and the setting of the district brush, district group, office brush and office group register relays is rendered ineffective. The establishment of connections to the toll operator or long distance operator proceeds in much the same manner as previously described in connection with the establishment of a connection to the zero operator. The supervision of the toll charge is thus transferred to the toll or long distance operator.

What is claimed is:

1. In a telephone exchange system, a calling line, a service charging device on said calling line, automatic switches for extending effective talking connections from said calling line, central office means for controlling the extension of connections, means associated with said central office means for arresting the completion of certain of said connections from said calling line until after the operation of said charging device and means operative for rendering said arresting means ineffective during the extension of other of said connections from said calling line.

2. In a telephone exchange system, a calling line, a coin device on said calling line, automatic switches for extending effective talking connections from said calling line, central office means for controlling said connections, means associated with said central office means for arresting the completion of certain of said connections from said call-

ing line until after the deposit of a coin in said coin device and means operative for rendering said arresting means ineffective during the extension of other of said connections from said calling line.

3. In a telephone exchange system, a calling line, a service charging device on said calling line, called lines, automatic switches for extending connections from said calling line to any one of said called lines, central office means for controlling said connections, means associated with said central office means for arresting the completion of an effective talking connection between said calling line and certain of said called lines until after the operation of said charging device and means operative for rendering said arresting means ineffective during the extension of connections to other of said called lines.

4. In a telephone exchange system, a calling line, a coin device on said calling line, called lines, automatic switches for extending connections from said calling line to any one of said called lines, central office means for controlling said connections, means associated with said central office means for arresting the completion of an effective talking connection between said calling line and certain of said called lines until after the deposit of a coin in said coin device and means operative for rendering said arresting means ineffective during the extension of connections to other of said lines.

5. In a telephone exchange system, a calling line, a service charging device on said calling line, called lines, automatic switches for extending connections from said calling line to any one of said called lines, means for controlling the setting of said switches comprising a plurality of registers adapted to be selectively operated in accordance with the designation of the called line, means for arresting the completion of an effective talking connection between said calling line and certain of said called lines until after the operation of said charging device and means operated when said registers are set in certain positions for controlling the extension of effective talking connections to other of said called lines to render said arresting means ineffective.

6. In a telephone exchange system, a calling line, a service charging device on said calling line, automatic switches for extending connections from said calling line, subscriber controlled means for controlling the extension of effective talking connections, central office means for arresting the completion of certain of said connections from said calling line until after the operation of said charging device, and means operative for rendering said arresting means ineffective during the extension of other of said connections from said calling line.

7. In a telephone exchange system, a calling line, a service charging device on said calling line, called lines, automatic switches operable in a plurality of switching stages to extend connections between said lines, a sending mechanism, a control circuit extending between said mechanism and said switches, means for opening said control circuit subsequent to the operation of said sending mechanism for controlling said switches in certain of said switching stages and prior to the completion of its controlling function, and means controlled by the operation of said device for rendering said circuit opening means ineffective, and means operative for rendering said circuit opening means ineffective to permit the completion of connections to certain of said lines without the operation of said charging device.

8. In a telephone exchange system, a calling line, a service charging device on said calling line, called lines, automatic switches operable in a plurality of switching stages to extend connections between said lines, a sending mechanism, a control circuit extending between said mechanism and said switches, means for opening said control circuit immediately prior to the operation of said sending mechanism for controlling said switches in the last of said switching stages and until after the operation of said charging device, means controlled by the operation of said device for rendering said circuit opening means ineffective and means operative for rendering said circuit opening means ineffective to permit the completion of connections to certain of said lines without the operation of said charging device.

9. In a telephone exchange system, a calling line, a service charging device on said calling line, called lines, automatic switches for extending connections from said calling line to any one of said called lines, a central office register sender for controlling said switches, subscriber controlled means for setting the registers of said sender in accordance with the designation of a desired called line independent of the operation of said charging device, means associated with said sender for arresting the completion of a connection between said calling line and certain of said called lines until after the operation of said charging device and means operative for rendering said arresting means ineffective during the extension of connections to other of said called lines.

10. In a telephone exchange system, a calling line, a service charging device on said calling line, called lines, automatic switches for extending connections from said calling line to any one of said called lines, means for controlling the setting of said switches, a control circuit extending between said switches and said controlling

- means, means for opening said control circuit to prevent the complete establishment of a connection until after the operation of said charging device and means associated with said controlling means for rendering said circuit opening means ineffective to permit the completion of connections to certain of said lines without the operation of said charging device.
11. In a telephone exchange system, a calling line, a service charging device on said calling line, called lines, automatic switches for extending connections from said calling line to any one of said called lines, means for controlling the setting of said switches, a control circuit extending between said switches and said controlling means, a relay for opening said control circuit to prevent the complete establishment of a connection until after the operation of said charging device and means associated with said controlling means for rendering said relay ineffective to permit the completion of connections to certain of said lines without the operation of said charging device.
12. In a telephone exchange system a calling subscriber's line, a plurality of called subscribers' lines, automatic switches for extending connections from said calling line to any one of said called subscribers' lines, a sending mechanism common to said switches and under the control of the calling subscriber for controlling said switches, means effective to cause said mechanism to control the complete establishment of said connections, a special service line, an operator's position and means effective when the calling subscriber controls said sending mechanism to establish a connection with the special service line to extend the connection from said calling line to said operator's position irrespective of the subscriber's control.
13. In a telephone exchange system, a calling subscriber's line, a plurality of called subscribers' lines, automatic switches for extending connections from said calling line to any one of said called lines, means for controlling the setting of said switches comprising a plurality of registers adapted to be selectively operated in accordance with the office designation of the desired line and a plurality of locking relays selectively operated in accordance with the adjustment of said registers, said controlling means operating to effect the complete establishment of a desired connection when said relays have been selectively operated to extend the connection to certain of said called lines, an operator's position and means controlled by one of said relays operative when said registers are operated in accordance with the designation of certain other lines to render said relays ineffective for controlling the routing of the connection and to cause the extension of the connection to said operator's position.
14. In a telephone exchange system, a calling line, a service charging device on said calling line, means for extending a connection from said line, central office means for controlling the operation of said service charging device, a differential signaling device and means for associating said signaling device with said line for determining whether said charging device has been properly operated by said controlling means.
15. In a telephone exchange system, a calling line, a service charging device on said calling line adapted to be partially operated by the calling subscriber whereby a ground connection is established with one conductor of said line, means for extending a connection from said line, central office means for further controlling the operation of said device, whereby said ground connection is disestablished, a differential relay, means for associating said relay with the conductors of said line, said relay operative if said controlling means fails to disestablish said ground connection and a signaling device under the control of said relay.
16. In a telephone exchange system, a calling line, a coin device on said calling line having a coin chute, means associated with said device for connecting one conductor of said line to ground upon the deposit of a coin in said coin chute, means for extending a connection from said line, central office means for controlling said device to remove said coin from said coin chute whereby said ground connection is disestablished, a differential relay, means for associating said relay with the conductors of said line, said relay operative if said controlling means fails to disestablish said ground connection and a signaling device under the control of said relay.
17. In a telephone exchange system, a calling line, a coin device on said calling line having a coin chute, means associated with said device for connecting one conductor of said line to ground upon the deposit of a coin in said coin chute, means for extending a connection from said line, central office means for controlling said device to remove said coin from said coin chute whereby said ground connection is disestablished, a differential relay, means for associating said relay with the conductors of said line after the operation of said controlling means, said relay operative if a ground connection then exists on either conductor of said line and a signaling device under the control of said relay.
18. In a telephone exchange system, a calling line, a substation on said line having

a receiver and switchhook, a coin device at said substation having a coin chute, means associated with said device for connecting one conductor of said line to ground upon the deposit of a coin in said coin chute, 5 means for extending a connection from said line, central office means operative upon the restoration of said receiver to the switchhook for controlling said device to release 10 said coin from said chute whereby said ground connection is disestablished, a differential relay, means for associating said relay with the conductors of said line, after the operation of said controlling means, 15 said relay operative if a ground connection then exists on either conductor of said line and a signaling device under the control of said relay.

19. In a telephone exchange system, a 20 calling line, a substation on said line having a receiver and switchhook, a coin device at said substation having a coin chute, means

associated with said device for connecting one conductor of said line to ground upon the deposit of a coin in said coin chute, 25 means for extending a connection from said line, central office means operative upon the restoration of said receiver to the switchhook for controlling said device to remove said coin from said chute whereby said 30 ground connection is disestablished, a differential relay, means for associating said relay with the conductors of said line after the operation of said controlling means, said 35 relay operative only when a ground connection exists on either conductor of said line and said receiver is on the switchhook and a signaling device under the control of said relay.

In witness whereof, I hereunto subscribe 40 my name this 28th day of December, A. D. 1920.

ELLIS H. MILLS.
